UNITED STATES PATENT OFFICE.

FRANKLIN A. STEARN, OF PATERSON, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed June 3, 1921. Serial No. 474,702.

To all whom it may concern:

Be it known that I, FRANKLIN A. STEARN, a citizen of the United States, residing at Paterson, in the county of Passaic, State 5 of New Jersey, have invented certain new and useful Improvements in Telephone-Exchange Systems, of which the following is a full, clear, concise, and exact description.

This invention relates to telephone exchange systems in general and especially to 10 those systems wherein machine switching apparatus is employed in the central offices for the extension of conversational connections.

15 Districts embracing extensive and thickly populated areas, such as the territory of the larger cities, must be provided, in order to furnish adequate telephonic communication, with an exchange system consisting of a large number of individual central offices suitably distributed throughout 20 the entire area. The close relation that exists between the various parts or localities, served by their own individual central offices, which 25 collectively make up the exchange area, demands a communicating system in which quick and efficient service may be had in the interconnection of lines belonging to any two offices. To accomplish this universal 30 service by providing interoffice trunk groups between each office and every other office in the area is highly objectionable. The cost of installing and maintaining so intricate a 35 trunk network in congested city districts is prohibitive.

To obviate the expense incident to the provision of interoffice trunk groups for all offices in the system, and at the same time to give every office facilities for communicating 40 with every other office, the tandem switching basis is adopted as a satisfactory solution of the problem of furnishing efficient and economical service in communities of the character above mentioned. According 45 to the tandem plan a central switching office is selected at some convenient position in the area it serves and from this tandem point groups of trunks radiate to all of the outlying offices. Any office wishing to establish 50 a connection with any other office in the system may do so by routing the call first to the tandem switching point from whence it is directed to the desired terminating office. The economy in trunks made possible by this method is at once obvious.

Where all offices in the system, both originating and terminating are of the manual type the requirements placed upon the central tandem office are relatively simple. Operators located at this office receive, over 55 order wires, their instructions from the operators in the originating office. They then proceed to connect the assigned trunk incoming from the originating office to the proper outgoing trunk to the called office. In the 60 called office the connection may be completed to the desired line by the operator thereat. But the exchange systems to be considered hereinafter are those which have been converted partially from the manual basis to 65 the machine switching basis. In other words, complete connections between subscribers' lines in such a system are effected in some cases partly by manual operators' equipment and partly by machine switches, while in 70 other instances the completion of connections may be entirely automatic. Certain offices may be provided with manual operators' positions and equipment, other offices with 75 full mechanical apparatus and still other offices in the area equipped with call indicating mechanism for communicating to operators the designations of called lines. Consequently, the central tandem switching office must be adapted to perform the necessary 80 cooperation with these various kinds of outlying offices.

To this end the tandem office is equipped with automatic selective switches, a district and an office switch. The trunks incoming 85 from originating offices terminate in the district switches, which, together with the office selectors, are operable in accordance with the designation to extend the incoming trunk over a trunk outgoing from the tandem point 90 to the called office. The control of the district and office switches, to select trunks extending to any of the large number of outlying offices, is exercised by register senders 95 located at the tandem office. These senders are also adapted to control the apparatus 100 in the called office, whether such apparatus be automatic switches or call indicating mechanism. The complete record of a call designation, therefore, is comprised of two 105 or more distinct parts. One is the code which identifies the particular office for which the call is destined and governs the operation of the district and office switches at the tandem point to select a trunk lead- 110

ing to such office. Another part of the designation is that which determines the number of the called line in the office and serves either to control the movement of switches 5 to select the line or to operate indicating mechanism to advise an operator of the line's identity.

In some cases the complete designation 10 may have three functions. This occurs where the final terminating office is one of a smaller group of offices lying at a distance from the central tandem point so far as to make it undesirable to provide a separate trunk group from the tandem point to each 15 such office. Instead, one large group of trunks are provided between the central or mechanical tandem office and a second or sub-tandem office. From the sub-tandem office, trunks radiate to each of the terminating 20 offices in said smaller group. Hence, the first or code portion of the designation may be considered as having two functions. First it determines the selection of a trunk from the mechanical tandem point to the 25 sub-tandem office. Secondly it causes an indication to be given the operator at the sub-tandem office telling her which one of the outlying terminating offices contains the called line. As before, the numerical portion 30 of the designation, is given the tandem operator who communicates it to the final completing operator in the terminating office.

It will be seen that the register sender in 35 the mechanical tandem office, which first receives the entire designation of a called line, must be prepared to meet any of these varying requirements and must be able to differentiate a call of one class from a call of another class and to exercise the necessary 40 control in each case. The registered designation, and particularly that part which identifies the office, is what causes the sender to exercise its differentiating functions. This office code or designation is registered on the office registers of the 45 sender and the numerical designation is set up on the numerical registers. If the called line, represented by the designation thus registered, is one belonging to a mechanical office then the only function of the office record is to control the operation of the 50 district and office switches in the tandem office to select a trunk leading to such mechanical office. The numerical record determines the operation of the switches therein to select 55 the subscriber's line. Likewise, if the called line is one belonging to an office equipped with call indicators and connected directly to the tandem mechanical office, the 60 only function of the office record is to cause the selection of a trunk leading to the local call indicator office. But, where the called line belongs to an office which can only be reached through a sub-tandem office, there 65 the office designation recorded on the sender

has the additional function before explained. Although the office designation recorded in the sender may be used a plurality of times in the establishment of the same connection, it is not desirable that the office registers, 70 on which the designation is first registered, should be used to control both the switches in the mechanical tandem office and the call indicator in the distant sub-tandem office.

Hence, the present invention has for its 75 object to provide, in a telephone exchange system of the general character outlined above, an improved central office register sender adapted to exercise the necessary control in the establishment of connections 80 which involve either offices of a full mechanical or offices of a semi-mechanical nature.

A feature of the invention relates to a 85 sender wherein certain designations, when recorded on a set of registers, serve to control automatic switches to extend the connection in the proper direction, while other designations when recorded on said registers are automatically reproduced on a second set of registers, the record on one set of registers serving to control the switches as before to extend the connection in the proper direction and the equivalent record on the other set of registers serving to control mechanism over the extended connection 90 to assist in the further extension thereof.

Another feature of the invention relates to a sender in which certain designations 100 set up on an operator's keyboard are transferred to a set of registers there to control the selective movement of switches to extend connections, and wherein other designations transferred from the keyboard to said registers are automatically reproduced 105 on a second set of registers, one set of registers serving to control the switches and the other set of registers acting to control, in accordance with the same designation, indicating mechanism to assist in the further 110 extension of the connection.

Another feature of the invention relates to the provision of a variably operable switch which takes a setting in accordance with the designation on one set of registers 115 to reproduce such designation on a second set of registers, one set of registers controlling automatic switches to extend a connection to a call indicator position and the other registers serving to control the call 120 indicator over the extended connection.

A still further feature relates to means, in a system where connections are extended from a mechanical office to a tandem call indicator office, whereby the same designation 125 is registered on two separate sets of registers in the sender, one set of registers serving to determine the extension of the connection to the tandem office and the other set of registers serving to operate the call indicator to 130

indicate the designation of any one of a plurality of terminating offices.

Such other and further features as are contemplated by the present invention will be understood from a consideration of the following description and the appended claims:

Referring to the drawing Figs. 1 to 18 inclusive when arranged in the order illustrated by the diagram in Fig. 20 disclose in detail the circuits and apparatus of a tandem switching telephone exchange system embodying the principles of the present invention.

Fig. 1 shows a subscriber's line terminating before an operator's position in an originating manual office and also an operator's cord circuit for extending the calling lines to trunks outgoing to the distant tandem switching center.

Fig. 2 shows a district selector switch at the tandem switching office in which the interoffice trunk incoming from the originating manual office terminates. This figure also illustrates certain assignment and supervisory devices.

Fig. 3 shows an office selector switch in the tandem switching office which cooperates with the district selector to selectively extend incoming trunks to trunk lines outgoing to any one of the large number of terminating and sub-tandem offices in the outlying area.

Fig. 4 illustrates an incoming selector switch located in a distant full mechanical office and in which terminates the trunk incoming from the tandem switching center.

Fig. 5 shows a final selector switch in the mechanical office which, together with the incoming selector, serves to complete connections to the local subscribers' lines.

To the left of the vertical broken line in Fig. 6 there is shown a trunk incoming from the tandem switching office and terminating in a plug at an operator's position in a sub-tandem office. To the right of the broken line is illustrated one of a plurality of terminating manual offices served through the sub-tandem office. A trunk is shown leading from the sub-tandem operator's position and incoming before a completing operator at the terminating office. Also, there is shown a cord circuit by means of which the operator in the terminating office completes the incoming connection to a called line belonging to the terminating office.

Fig. 7 shows the relay switching mechanism of a call indicator which is located at the operator's position in the sub-tandem office. This figure also shows a part of the indicating lamps which give a visual indication to the sub-tandem operator of the designation of the desired line.

Fig. 8 shows the remaining lamps of the call indicator.

Fig. 9 shows a trunk selector and sen-

der selector unit comprising two selector switches which operate to associate any one of a plurality of register senders with the trunk circuits at the operator's position in the tandem switching office, such as the 70 trunk shown in Fig. 2 incoming from the originating manual office illustrated in Fig. 1.

Figs. 10, 11, 12, 13, 14 and 15 show the complete equipment of one of the register senders in the tandem switching office. Fig. 10 illustrates the counting relays and the control circuits of the sender proper. Fig. 11 shows the class switch, the tandem routing switch and a set of relay registers. Fig. 12 shows an impulse switch, the purpose of which is to transmit codes of impulses for controlling the call indicators in distant offices. Fig. 13 shows the register control switch which serves to direct the recording 85 impulses to the registers in succession during the registration of a designation. Figs. 14 and 15 illustrate the class, office, numerical and stations registers.

Fig. 16 shows a keyboard consisting of 90 office, numerical and stations keys located at the operator's position in the tandem switching office.

Fig. 17 shows a translator switch, the setting of which is governed by the office keys 95 and also an impulse machine which is connected in variable combinations to the terminals of the translator switch. This figure also shows a control sequence switch for assisting in the transfer of the numerical 100 record from the operator's keyboard to the registers of the sender.

Fig. 18 illustrates sets of class and office registers which are adjusted by impulses from the impulse machine in accordance 105 with the setting taken by the translator switch. This figure further shows a controlling sequence switch which cooperates with the sequence switch shown in Fig. 13 in transferring the class and office records from 110 the translator registers in Fig. 18 to the corresponding registers of the sender in Figs. 14 and 15.

Fig. 19 is a schematic diagram of the entire system showing the manner in which 115 connections are extended from originating offices through the tandem switching office and thence to any type of terminating office in the outlying area.

120

Description of apparatus.

The district, office, incoming and final selector switches shown in Figs. 2, 3, 4 and 5, respectively, are in general the same in construction and operation as the switch shown in the patent to Craft and Reynolds 1,123, 696, issued January 5, 1915. These switches comprise a vertical brush shaft upon which a plurality of sets of brushes are mounted, each set of brushes serving an individual 130

- section of the terminal bank. Normally, the brushes are withdrawn so as not to engage the terminals in their respective sections until released by a selective tripping mechanism. The brushes are propelled in their setting and releasing movements by means of constantly rotating power rolls against which the brush shaft is pressed by means of electromagnets.
- 10 The trunk selector switch 920 and the sender selector switch 940 shown in Fig. 9 are likewise switches of the power-driven type similar in many respects to the one shown in the patent to Craft and Reynolds above mentioned. In detail, however, these switches differ in that the brush tripping mechanism is dispensed with and only a single set of brushes in each case is provided on the brush shaft. Secondly, these brushes are in continual engagement with the terminals of the bank both in the advance and return movements of the switch. The translator switch 1700 shown in Fig. 17 is also a switch of the power-driven type.
- 25 The sequence switches 210, 310, 410, 510, 910, 980, 1010, 1110, 1120, 1210, 1310, 1710 and 1810 shown in their respective figures throughout the drawing are all similar to the one described in detail in the patent to Reynolds and Baldwin 1,127,808, patented February 9, 1915. Referring to Fig. 9, it should be noted that all sequence switch contacts there shown are a part of the sequence switch 910, with the exception of the contacts included in the space set off by broken lines in the upper part of the figure. The contacts shown in this space are controlled by the allotter sequence switch 980. Similarly, in Fig. 11 all sequence switch contacts shown above the broken horizontal line are a part of the tandem routing sequence switch 1120, while those below the horizontal broken line are controlled by the class sequence switch 1110. As to the remaining figures in which sequence switch contacts occur, all contacts in each of the respective figures are controlled by the sequence switch correspondingly shown.
- 50 The operator at the tandem switching office must be able to record on the register sender a wide range of called designations in order that connections incoming to the tandem office may be routed to any one of the large number of terminating offices. To this end, her position is equipped with a keyboard which may be considered as comprising two distinct parts. The first part of the operator's keyboard consists of two rows of coordinate office keys, the horizontal row 1600 and the vertical row 1610. As shown there are twenty keys in each of these two rows. By coordinating any key in the horizontal row with any one of the twenty different keys in the vertical row, that is, by depress-

ing one key in one row and one key in the other row the possibility of four hundred different combinations is obtained. This means that by assigning to each office in the area served through the tandem switching 70 sender, a code designation consisting of two digits, which may be either ordinals or letters, a total of four hundred different selections would be possible by the type of keyboard illustrated. In the present disclosure, 75 however, the capacity of the system is taken as two hundred offices in which the first ten keys in the horizontal row 1600 are employed in conjunction with the twenty keys in the vertical row 1610. The horizontal 80 keys 1600 are divided into four groups 1601, 1602, 1603, and 1604 of five keys each. The first two groups of five, 1601 and 1602 are effective groups as will be seen hereinafter for accomplishing the two hundred different 85 office selections. The act of actuating any horizontal key in either of the two groups 1601 or 1602 together with a vertical key in the row 1610 is to cause the operation of the translator switch 1700 to select any one 90 of its two hundred different sets of terminals.

The translator switch 1700 is provided with five sets of brushes, only one of which is shown, mounted on the brush shaft 1734. 95 Each set of brushes has access to a section of forty sets of terminals in the bank, the forty sets of terminals of each section being divided into two groups of twenty terminals each. The five different keys in the groups 1601 and 1602 correspond to the five sets of brushes on the translator switch, that is to say, the first key in group 1601 or the first key in group 1602 causes the selection and tripping of the first set of brushes, the second keys in the groups 1601 and 1602, the selection and tripping of the second set of brushes and so on. Inasmuch as each set of brushes has access to forty sets of terminals and there are only twenty vertical keys in the row 1610, it is necessary to make the selection of a group of twenty terminals dependent upon the horizontal 100 keys. This is done by so arranging the circuits that when any one of the five keys in the first horizontal group 1601 is actuated, the corresponding one of the five different sets of brushes of the translator is tripped and furthermore, is caused to search in the first group of twenty terminals. On the other hand, if a key is depressed in the second group of horizontal keys 1602, the proper set of brushes of the translator are tripped and are caused to automatically pass over the first group of twenty terminals in the section and to search for a set of terminals in the second group of twenty. The final selection of a set of terminals in either 105 group of twenty terminals is determined by 110 115 120 125 130

the particular one of the twenty vertical keys operated in conjunction with a horizontal key.

The two hundred different sets of terminals in the bank of the translator switch are variously and arbitrarily wired to the brushes 1771, 1772, 1773, 1774, etc., of the impulse machine. The impulse machine consists of a circular drum provided with 10 circumferential rows of contacts which cooperate with the brushes. This drum is constantly driven by any suitable source of power. As shown in the drawing the circular drum is developed to show the relative 15 positions of the contacts, and the brushes may be considered as movable in the direction of the arrow. Battery potential is connected to all of the contacts shown on the developed surface of the circular drum. 20 While only two sets of terminals in the translator bank are shown as wired to the brushes of the impulse machine and only the proper contacts upon the circular drum are illustrated to produce the desired record 25 for the calls which will be considered in this discussion, it will be understood, of course, that as many brushes and as many contacts will be used as are necessary to enable a total of two hundred different 30 combinations of connections between the terminal bank of the translator switch and the impulse machine.

After the translator switch has been positioned on the proper set of terminals 35 which gives the particular connection with the impulse machine corresponding to the combination of horizontal and vertical office keys depressed, circuits are prepared for recording the office record on the translator 40 register relays shown in Fig. 18. To accomplish this, impulses are sent from the impulse machine during its rotation through the terminal bank and brushes of the translator switch in such codes as to cause the 45 operation of the class and office translator register relays in Fig. 18 in combinations for setting up the record which corresponds to the office keys depressed and which will later become effective in controlling the 50 selective movements of the district and office switches in the tandem switching office to select a trunk leading to the desired outlying office.

The second part of the operator's key- 55 board shown in Fig. 16 consists of four rows of numerical keys, thousands, hundreds, tens and units and a row of stations keys. The numerical keys when depressed in accordance with the number of the called line 60 determine the nature of impulses sent by the controlling sequence switch 1710 through the sender selector 940 to the numerical registers of the sender shown in Figs. 14 and 15. As will be seen hereinafter the numerical 65 record is transferred from the keyboard im-

mediately that the translator switch has been operated and the office record set up on the translator register relays. The office record having thus been established on the translator register relays, the numerical 70 record is transferred to the register sender, following which operation, the office designation is transferred from the translator registers to the regular office registers of the sender. After this has taken place, the 75 translator switch, the operator's keyboard and all other associated mechanism are restored to their normal condition.

In Figs. 14 and 15, the class, office, numerical and stations registers are shown, 80 each register consisting of a plurality of relays. The class register comprises the four relays 1500, 1501, 1502 and 1503. The office routing registers comprise four groups of relays, the district brush register consisting 85 of relays 1411, 1401 and 1412; the district group register consisting of relays 1402, 1413, 1403 and 1419; the office brush register consisting of relays 1513, 1504 and 1514 and the office group register consisting 90 of relays 1507, 1506, 1505 and 1410. The numerical registers comprise five different groups of relays, the incoming brush register consisting of relays 1515, 1511 and 1512; the incoming group register consisting of relays 95 1417 and 1418; the final brush register consisting of relays 1508, 1509 and 1510; the final tens register consisting of relays 1415, 1407, 1408 and 1409 and the final units register consisting of relays 1404, 1405, 1406 100 and 1416. The stations register includes the three relays 1516, 1517 and 1518. Some of these register relays are wound so as to be sensitive to weak currents, while others are made marginal and will only respond to 105 strong currents. By use of these two operating conditions, resistances may be inserted or omitted from the impulse circuits to permit the operation of the register relays in any desired combination. The contacts 110 of certain ones of the register relays are shown as terminating in small circles which include the ordinals from 0 to 4. This convention indicates that the contacts of the relays are wired directly to the armatures 115 of the correspondingly designated counting relays of the sender in Fig. 10. The omission of the conductors between the registers and the counting relays has been made to avoid unnecessary confusion in the showing. 120

The function of the class sequence switch 1110 is to determine the class of the connection that is being established, as for example, the particular type of the office to which the connection is extended, and to 125 influence the operation of the sender to meet the particular requirements for controlling that type of connection. The class sequence switch 1110 takes its variable setting from the registration of the class registers 1500, 130

1501, etc., which registration has been transferred from the translator registers and is determined initially by the office code the operator sets up on the horizontal and vertical keys. For example, the codes which designate all offices of a particular class, although represented by as many different combinations of horizontal and vertical keys on the operator's keyboard, will result in 5 the setting of the class sequence switch 1110 in the same position, namely, the position for this particular class of offices. The same is true for all offices of each of the remaining classes.

15 The routing sequence switch 1120 is provided for causing in certain circumstances the reproduction of the office designation on the secondary registers 1100 originally registered on the office registers of the sender. 10 The occasion for using the routing switch 1120 and the secondary registers 1100 is one in which the desired connection must be routed through a sub-tandem office in order to finally reach the terminating office. In 15 this case the office record is required for two separate purposes, first to determine the operation of the district and office switches to choose a trunk leading to the sub-tandem office, and secondly, to control a call indicator in the sub-tandem office to display the 20 designation of the terminating office. Accordingly, the designation is first registered on the office registers and is then reproduced on the secondary registers 1100 through the agency of the routing switch 1120. The 25 routing switch 1120 is variably adjustable to any one of its several positions, the particular position to be assumed depending upon the setting of the office brush registers 1513, 1504 and 1514. Dependent upon the position taken by sequence switch 1120 in accordance with the designation registered on the office brush registers, one of the ten registers of the set 1100 is operated and by its 30 operation determines the brush and group selective movements of the district and office switches 230 and 330 to choose the proper outgoing trunk. Later, the same record on the office registers of the sender which cause 35 the selection of one of the secondary registers 1100 also serves to control, over the selected trunk, the relay call indicator shown in Figs. 7 and 8 located at the sub-tandem point. The sequence switch 1120 has ten 40 register selective positions, positions 2 to 11 inclusive. In each of these positions it selects and operates one of the ten secondary register relays 1100. The contacts of the secondary register relays 1100 are variously 45 connected to the five leads 1014, 1015, 1016, 1057 and 1058 at the counting relays. By this arrangement the ten relays of the secondary register enable ten different combined selections consisting of brush and 50 group movements by the district and office 55

switches 230 and 330 to connect certain contacts of springs 1136, 1137, 1138 and 1139 to ground. The sequence switch 1120 in addition to selecting the corresponding secondary register relay in these particular positions will also cause the energization of the translation relay 1005 of the sender during the group selecting movement of the district switch, the office switch or both. The relay 1005 as will later be explained 60 causes the district and office switches to pass over five additional group selecting positions. The purpose of operating the translation relay 1005 in connection with some of the secondary register relays 1100, to increase the group selecting movement of the district and office switches by five groups, is to permit flexibility in the wiring of the trunks between the terminal bank of the district switch and the office switches and 65 also to permit the trunks outgoing from the terminal bank of the office selector to be shifted from one part of the bank to another. While the set of ten secondary registers 1100, in conjunction with the routing switch 1120 having ten selective positions, will enable the selection of only ten trunk lines outgoing from the office selector to distant sub-tandem offices, the appearance of these trunks 70 in the terminal bank may be shifted, if desirable, from one part of the bank to another and also the appearance of the office selector trunks 247, 248 and 249 in the terminal bank of the district switch may likewise be transferred from one part of the bank to another by the arrangement wherein the routing switch 1120 in certain of its 75 positions causes the operation of the translating relay 1005.

The sequence switch 1210 shown in Fig. 12 is for the purpose of transmitting codes of impulses to either direct call indicator offices or to the call indicators at the sub-tandem offices where a tandem or office designation is required. The translation of the designation recorded on the registers of the sender into codes of impulses such as the sequence switch 1210 is designed to send is attained by wiring the contact springs of the switch 1210 to the contacts of the registers. Certain of the contacts of the impulse sequence switch 1210 are shown terminating in small circles containing the ordinals 1 to 4, which convention indicates that these contacts are wired to correspondingly designated contacts of the proper sender registers.

A plurality of register senders such as the one illustrated in Figs. 10 to 15 inclusive are common to all the operators in the tandem switching office and when idle may be taken for use by any one of these operators. The keyboard, translator switch and other equipment shown in Figs. 16, 17 and 18 are individual to a particular operator's position. An operator's position is fur-

ther provided with a plurality of trunk selector and sender selector units shown in Fig. 9. The trunk selector switch 920 of the unit operates to find the particular one of the incoming trunks 115, 116 over which a connection has been extended to the operator's position and the sender selector switch 940 is actuated simultaneously to select an idle one of the common senders. The key-board and translator equipment at the operator's position is then associated by means of relays in the trunk selector unit with the selected sender. Inasmuch as there are a plurality of the trunk selector sender selector units, these are allotted for use in rotation by means of an allotter switch 980 so that only one at a time is effective.

The sub-tandem office illustrated in the left-hand portion of Fig. 6 and Figs. 7 and 8 is equipped with operators' positions at which the incoming trunks 333 and 334 from the tandem switching office terminate in cord circuits such as the cord 601 602. The call indicator mechanism shown in detail in Figs. 7 and 8 is common to all the incoming trunks at an operator's position and may be associated with any one by means of an assignment key 622 individual to the trunk. The code impulses transmitted from the impulse switch 1210 in the tandem switching office to the call indicator mechanism are received by relays 700, 701 and 702. The first two of these relays are sensitive and oppositely polarized so that one responds to both strong and weak currents of a positive polarity and is not responsive to either strong or weak currents of the opposite polarity, while the other relay operates on both strong and weak currents of a negative polarity and remains inert to either strong or weak currents of a positive polarity. The third relay 702 responds to strong currents of either polarity, but is not actuated by weak currents. With these different operating characteristics, the three receiving relays, operating in conjunction with the series of switching relays 706, 707, 708, 709, etc., up to 720 and 721, are capable of receiving the incoming codes of impulses and of recording them on the indicating lamp register relays to select the proper lamps for displaying the designation represented by the code impulses transmitted. The indicating lamps and their selecting relays consist of eight different groups designated as tandem hundreds, tandem tens, tandem units, stations, thousands, hundreds, tens and units groups. The tandem hundreds, tandem tens and tandem units lamps are variably selected in accordance with the office designation initially recorded on the office registers of the sender to display to the sub-tandem operator a code of letters or ordinals identifying the terminating office to which she has to extend

the connection. One of these terminating offices is illustrated as hereinbefore mentioned in the right-hand portion of Fig. 6. As shown, the tandem lamps are labelled with the ordinals from 0 to 9, but letters 70 may be used equally as well. For instance, the letters displayed at the tandem lamps might be chosen to give an abbreviation of the name by which the terminating office is known and listed in the directory. The 75 thousands, hundreds, tens and units lamps are selected in accordance with the numerical portion of the designation initially recorded on the numerical registers of the sender in the tandem switching office and serve to display the number of the called line. The station's lamps in a similar manner identify the particular station desired in the event of a party line.

General description of operation.

Before proceeding with the description of the operations involved in the establishment of connections, it is believed that an explanation of the general layout of the entire system will be helpful to an understanding of the details which follow. The diagram of Fig. 19 illustrates a plurality of calling and called offices of varying types and the manner in which connections between these different offices is handled on the tandem switching basis. The central tandem switching office is illustrated at 1900 and is equipped with district selectors 1902, office selectors 1903, senders 1904, operators' keyboards 1905 and selecting units 1906, 1907. All originating offices in the area served through the tandem switch office, such as the office 1901, are provided with trunks 1922 incoming at the operators' positions and terminating in district selectors such as the district selector 1902 at the tandem switching office.

The district and office selectors have access to trunks 1918, 1917 and 1919 outgoing to terminating offices. The trunk 1917, for example, leads to a full mechanical office 1908 in which incoming selectors 1909 and final selectors 1910 are operable under the control of the sender 1904 to complete the connection to the called line in the mechanical office. Other trunks, such as the trunk 1918, lead to direct call indicator offices 1911 wherein a call indicator 1912 is operated to display to the operator the number of the called line to which she then completes the connection. Still other trunks, such as the trunk 1919, extend from the tandem switching office to an operator's position in a sub-tandem office 1913. Here the call indicator 1914 is operated to display to the operator the designation of the desired one of a plurality of outlying terminating offices 1915, 1916, etc., and also to indicate the numerical designation of the called line in such termi-

nating office. The sub-tandem operator may then extend the trunk 1919 over the trunk 1920, for instance to an operator's position in the terminating office and at the same time 5 communicate the numerical designation to the latter operator, who finally completes the extension to the called line.

When a call is initiated in an originating office for a subscriber's line in a full mechanical office which must be reached through the tandem switching center, the originating operator communicates with the operator in the tandem office over an order wire (not shown in the drawing), requests 10 the assignment of a trunk and also advises her of the complete designation of the desired line. The tandem operator assigns the trunk and actuates an individual assignment key 226, Fig. 2, which initiates 15 the movement of the trunk selector sender unit to associate with that trunk an idle register sender and the operator's keyboard. She thereupon records on the office and numerical keys the code designating the terminating mechanical office containing the called 20 line and also the number of said line. Translator switch 1700 operates to select the set of terminals corresponding to the combination of horizontal and vertical keys depressed, connecting the proper combination 25 of brushes at the impulse machine 1790 to the impulse leads extending to the translator register relays in Fig. 18. The rotation of the impulse machine 1790 through 30 a complete cycle causes the transmission of the code of impulses to cause the operation in the requisite combinations of the class, district brush, district group, office brush and office group translator register relays. 35 The record of the call initially set up on the two office keys is thus produced through the agency of the translator switch and the impulse machine on the register relays in Fig. 18.

40 Before anything further can happen with respect to the office designation, the numerical designation written on the operator's numerical keys is produced on the numerical registers in the selected sender by means of 45 impulses transmitted from the operator's individual equipment through the sender selector 940 to the register setting circuits in Fig. 13. Immediately that the numerical record has been produced on the registers 50 of the sender the office designation temporarily recorded on the translator registers is likewise transferred through the sender selector switch 940 to the corresponding class, district brush, district group, office 55 brush and office group registers of the sender. Now that the record is completely established in the register sender, the keyboard, the translator switch and all other 60 individual equipment at the operator's position 65 may be released for further use.

Since the connection about to be established is one intended for a full mechanical office having incoming and final switches 430 and 530, the class registration from the sender determines that the class sequence 70 switch 1110 takes up a setting in its position 10. Selection is now begun and the district and office switches are operated to choose a trunk 331 332 leading to the distant mechanical office and the incoming and 75 final switches therein are controlled by the register sender to complete the extension of the connection to the called subscriber's line 80 500. Following this the register sender in the tandem switching office is released and reverts to common use.

Should the call initiated in the originating office of Fig. 1 be for a subscriber's line terminating in a distant manual office, such as one of the offices 1915 1916 shown in Fig. 19, it would then be necessary to route the connection first through the tandem switching office to a distant sub-tandem office, thence to the final completing operator's position in the terminating office. The operator in the tandem switching office receives the designation from the originating operator as before and proceeds in the same manner to make a record thereof on her office and numerical keys. The translator 95 switch functions as before, taking a different setting however, and the designation is finally produced on the registers of the selected sender. In this case the class sequence switch 1110 assumes a setting in position 6, which is the position characterizing 100 calls of the class routed through a sub-tandem point.

Inasmuch as the class sequence switch 1110 advances to position 6, it renders the 105 routing switch 1120 effective to take up a position dependent upon the record registered on the office brush registers of the sender to select one of the relays of the secondary register 1100 to thereby reproduce the office record for the purpose of controlling the district and office switches. When the sender is ready to exercise its control over the switches, the selection begins and the district and office selectors 230 and 330 110 are operated in accordance with the registration on the secondary registers 1100 to pick a trunk 333 334 extending to the operator's position in the sub-tandem office 115 illustrated in Figs. 6, 7 and 8.

The class sequence switch 1110 also determines that the tandem and numerical code impulses must be sent to cause the setting of the relay call indicator. Consequently, the impulse switch 1210 is set 120 in operation at the proper time and transmits code impulses, the character of which are determined by the registration on the office and numerical registers of the 125 sender to set up the designation on the in- 130

5 dicator lamps before the operator in the
sub-tandem office. The sub-tandem operator
observing the indication upon the lamps
at her position communicates with the oper-
6 ator in the called terminating office
and requests the assignment of a trunk.
The sub-tandem operator then extends
7 the connection over the assigned trunk
605 606 and at the same time orally
10 gives to the terminating operator the
number of the wanted subscriber's line.
With this information the terminating op-
erator completes the connection to the line
600.

15 Another class of calls which will not be
considered in detail herein is one where
connections handled through the tandem
switching office are extended directly to
call indicator positions in the terminating
20 office. In this case the class sequence switch
1110 in the central office sender assumes
the proper position and in so doing deter-
mines that the impulse switch 1210 will
send out codes of impulses in accordance
25 with the numerical designation only of the
desired line and will omit to transmit the
tandem impulses.

30 *Detailed description of operation—Establish-
ment of a connection to a full mechanical
office.*

35 In taking up the detailed description of
the system, it will first be assumed that the
subscriber of the line 100 in an originating
40 office wishes to communicate with the sub-
scriber of the line 500 which terminates in a
full mechanical office and which must be
reached through the tandem switching cen-
45 ter. Upon the initiation of the call the an-
swering operator in the originating office re-
sponds by inserting the plug 102 of her cord
50 circuit 103 in the jack 101 of the calling
line and ascertains his wants. She then
converses with the operator in the tandem
55 switching office over an order wire (not
shown); requests the assignment of a trunk
60 to be used for the connection and communi-
cates to the tandem operator the name of
the terminating office and the number of the
65 called subscriber's line therein. The tan-
dem operator observing that the trunk 115
116 incoming at her position from the
originating office is idle, orally assigns the
70 same to the originating operator and de-
presses the assignment key 226 individual
thereto. The initiating operator thereupon
75 inserts the plug 105 of her cord circuit in
the jack 106 of the assigned trunk. The in-
sertion of the plug in the jack completes a
80 circuit from battery through the winding of
relay 107, sleeve of plug 105, sleeve of jack
106, through the two windings of relay 114
85 in series to ground. The left-hand winding
of relay 114 is of low resistance, but due to
90 the fact that the right-hand winding has a

high resistance, the current flowing in the
circuit traced is not sufficient to permit the
operation of marginal relay 107. Conse-
70 quently, the lamp 108 is illuminated in a
circuit from battery through said lamp, re-
sistance 110 and thence to ground through
the windings of relay 114. Relay 114 also
attracts its armature and in so doing es-
75 tablishes a circuit from battery through the
contact of sequence switch spring 216 of the
district selector sequence switch 210 closed
in positions 18 to 12, right-hand winding of
relay 200, conductor 115, repeating coil
80 windings 111 and 117, winding of polarized
relay 113, repeating coil windings 118 and
112, armature and contact of relay 114, con-
ductor 116, left-hand winding of relay 200,
contact of sequence switch spring 205 (18+
85 12), to ground. The flow of current over
the trunk 115 116 is not in the proper direc-
tion to permit the operation of the polar-
ized relay 113. Relay 200, however, is oper-
ated and closes an energizing circuit for re-
lay 201.

90 The actuation of the assignment key 226
completes a circuit from ground through
the left-hand contacts of said key, upper
right-hand contact of sequence switch
spring 207 (1), winding of sequence switch
95 magnet 210 to battery. Sequence switch
210 is energized and advances from posi-
tion 1 into position 2. In position 2 a cir-
cuit is closed from battery through the
100 lamp 231, lower left-hand contact of se-
quence switch spring 223 (2+11), inter-
rupter 229 to ground. The lamp 231 is
flashed by the constantly rotating inter-
rupter 229 until the district sequence switch
leaves position 11. The discontinuance of
105 the flashing signal at the end of this period
indicates to the operator that the register
sender which was taken for use has com-
pleted its controlling functions and is de-
tached from the trunk circuit. In position
110 2 of sequence switch 210 a circuit is
also closed from battery through the lamp
243, upper left-hand contact of sequence
115 switch spring 213 (1+5), upper right-
hand contact of said spring (2+12), to
ground. The lamp 243 burns steadily
until the sequence switch 210 leaves po-
sition 5 at which time the extinguishment
120 of the lamp indicates to the operator that
selection has commenced at the district
switch. Furthermore, the advance of the
district sequence switch to position 2 com-
125 pletes a circuit from ground through the
upper right-hand contact of sequence switch
spring 213 (2+12), lower left-hand contact
of said spring (1+17), left-hand armature
and back contact of relay 204, upper left-
hand and lower left-hand contacts of se-
quence switch spring 209 (2), conductor
250, upper left-hand contact of sequence
switch spring 932 (1+11), lower right-hand
130

contact of said spring (1+4), winding of relay 900 to battery.

It may be noted at this point that conductor 250 is multiplied to contacts similar to 5 contact 209 of all trunks served by the trunk selector 920.

Relay 900 operates and closes a circuit from ground through its left-hand armature and front contact, lower right-hand contact 10 of sequence switch spring 934 (1+2), upper left-hand contact of said spring (1+1½), left-hand winding of relay 903 to battery. Relay 903 completes a circuit from ground through its inner right-hand armature and 15 front contact, upper right-hand contact of sequence switch spring 941 (1), winding of sequence switch magnet 910, to battery, driving said sequence switch out of position 1 and into position 2. As sequence switch 910 20 passes from position 1 to position 2, it closes the upper right-hand contact of spring 932 shortly before the opening of the upper left-hand contact of said spring. Consequently, relay 900 remains operated in a circuit from 25 battery through its winding, lower right-hand contact of spring 932 (1+4), upper right-hand contact of said spring (2+4), back contact and left-hand armature of relay 901, upper left-hand contact of spring 933 (2+14), lower left-hand contact of said 30 spring (1+2), to ground.

A circuit is now closed for the power magnet 912 of the trunk selector switch 920 and this switch will start in operation to hunt 35 for the set of terminals identifying the trunk 115, 116 taken for use. The circuit for the up-drive power magnet 912 leads from battery through the winding of said magnet, lower left-hand contact of sequence 40 switch spring 934 (2), lower right-hand contact of said spring (1+2), front contact and left-hand armature of relay 900 to ground. The brush shaft 914 is elevated and the brushes are driven over the terminals 45 of the bank until they encounter the terminals of the desired trunk. When this occurs, a circuit is closed from battery through the winding of test relay 901, upper left-hand contact of sequence switch spring 951 (2), brush 924, terminal 917, conductor 50 254, lower right-hand contact of sequence switch spring 222 (2), upper left-hand contact of said spring (2+3), back contact and outer right-hand armature of relay 204, 55 lower left-hand contact of sequence switch spring 225 (1+12), upper right-hand contact of said spring (1+7), to ground. Relay 901 energizes and opens the circuit of relay 900. Relay 900, however, remains actuated in a locking circuit from battery 60 through its contact and right-hand armature, commutator 928, brush 929, to ground for an instant longer. When the brushes 922, 923, 924, 925, 926 and 927 are accurately centered on the terminals of the se-

lected trunk, brush 929 engages an insulating portion of commutator 928 and relay 900 becomes deenergized to open the circuit of the up-drive power magnet 912, thereby 70 arresting the movement of the switch. Relay 901 immediately locks up in a circuit from battery through its winding, lower left-hand contact of sequence switch spring 951 (2+14), front contact and left-hand armature of relay 901, upper left-hand and 75 upper right-hand contacts of sequence switch spring 933 (2+14), left-hand armature and contact of relay 902, brush 927, terminal 921, conductor 251, lower left-hand contact of sequence switch spring 222 (2+3), and thence to ground as above traced at sequence switch spring 225. Relay 900 on releasing completes a circuit from 80 ground through its left-hand armature and back contact, upper left-hand contact of sequence switch spring 941 (2), winding of sequence switch magnet 910, to battery, driving said sequence switch out of position 2 and into position 3.

The circuits of the sender selector and 85 trunk selector switches are so arranged that both of these switches may be operating simultaneously, one to find the trunk taken for use by the operator and the other to find an idle common sender. At the time 90 the sequence switch 910 moved from position 1 into position 2, it closed the upper and lower left-hand contacts of sequence switch spring 945 shortly prior to the opening of the upper left-hand contact of sequence switch spring 934. Consequently, if the first sender, upon the identifying terminals of which the brushes of the sender selector 940 are normally standing, is busy, 95 the relay 903 is held operated by a new circuit closed prior to the opening of its original energizing circuit. This holding circuit may be traced from battery through the left-hand winding and contact and left-hand armature of relay 903, lower left-hand contact of sequence switch spring 945 (2+3), upper left-hand contact of said 100 spring (2+8), brush 964, terminal 958, conductor 1049, right-hand winding of relay 1300, lower contacts of sequence switch spring 1305 (2+18), to ground. With relay 903 energized in position 2 of sequence switch 910 a circuit is completed from battery through the winding of the up-drive power magnet 953, lower left-hand and upper right-hand contacts of sequence switch spring 952, front contact and inner right-hand armature of relay 903 to ground. The up-drive magnet 953 presses the depending portion of brush shaft 955 against the constantly rotating power drum and the switch is moved upwardly over the terminal bank to search for an idle register sender. So long as test brush 964 encounters the 105 terminals of busy senders, relay 903 remains 110

115

120

125

130

energized and the brush shaft 955 continues its upward movement. As soon as an idle sender is found, the circuit through the left-hand winding of relay 903 is opened. Relay 903, however, is maintained energized an instant longer by means of the circuit from battery through its right-hand winding, lower left-hand contact of sequence switch spring 947 (1+5), upper right-hand contact of said spring (1 $\frac{3}{4}$ +3), commutator 968, brush 969 to ground. When the brushes 962, 963, 964, 965, 966 and 967 are accurately centered on the terminals individual to the idle sender, brush 969 encounters an insulating segment of commutator 968 and relay 903 deenergizes to open the circuit of the power magnet 953. Sender selector 940, therefore, ceases its upward movement. Should the trunk selector 920 succeed in finding the trunk circuit 115, 116 prior to the time the sender selector 940 had located an idle sender, the sequence switch 910 advances as above described from position 2 into position 3. The movement of the sequence switch from position 2 into position 3 causes no influence in the operation of the sender selector switch as will be obvious from an inspection of the circuits. As soon as relay 903 becomes deenergized following the selection of an idle sender and as soon as sequence switch 910 reaches position 3, if it is not already in this position, a circuit is established from ground through the inner right-hand armature and back contact of relay 903, lower right-hand contact of sequence switch spring 941 (3), winding of sequence switch magnet 910 to battery, driving said sequence switch out of position 3 and into position 4.

At the time relay 901 operates, when the trunk circuit is found, it completes a circuit from battery through the winding of relay 904, front contact and right-hand armature of relay 901 to ground, causing the energization of relay 904. With relay 904 energized and sequence switch 910 in position 4, a circuit is established from battery through the right-hand winding of relay 903, lower left-hand contact of sequence switch spring 947 (1+5), upper left-hand contact of said spring (4+8), outer left-hand armature and contact of relay 904, brush 922, terminal 915, conductor 256, lower left-hand contact of sequence switch spring 212 (2), upper right-hand contact of said spring (2+12 $\frac{1}{2}$), to ground. Relay 903 becomes energized and completes a circuit from ground through its inner right hand armature and front contact, upper right-hand contact of sequence switch spring 941 (4), winding of magnet 910 to battery, moving the sequence switch out of position 4 and into position 5. Relay 903 remains actuated in position 5.

When sequence switch 910 reaches position 4 a circuit is closed from battery through the left-hand winding of relay 1300 lower right and upper left-hand contacts of spring 1303 (1), conductor 1048, terminal 957, brush 963, right-hand armature and contact of relay 906, lower contacts of spring 944 (4+5) to ground. Relay 1300 operates and locks in a circuit through its left-hand winding contact and armature, conductor 1049, terminal 958, brush 964, upper left-hand contact of spring 945 (2+8), lower right-hand contact of said spring (3 $\frac{3}{4}$ +16) to ground. Relay 1300 also closes a circuit from battery through the winding of sequence switch magnet 1310, lower left-hand contact of spring 1307 (1), front contact and right-hand armature of relay 1300 to ground.

Adjustment of the office and numerical keys and setting of translator switch.

The tandem operator, having received from the originating operator the name of the called office and the number of the desired line therein, proceeds to set up the designation on the keyboard. It will be assumed that the called mechanical office is represented by the seventh key 1633 in the horizontal row 1600 and the number 10 key 1632 in the vertical row 1610. Accordingly, the operator presses these two coordinate keys to record the designation of the office. It will further be assumed that the called line is a direct single party line having the number 2443. After recording the office designation, the operator then depresses the No. 2 thousands key 1617, the No. 4 hundreds key 1618, the No. 4 tens key 1619 and the No. 3 units key 1620. Since no stations registration is necessary for selective ringing on the called line, the operator omits to depress any of the station's keys and instead actuates the start key 1621.

Since the actuated coordinate horizontal key 1633 is located in the second group of five keys 1602, the translator switch 1700 will be caused to pass over the entire first group of twenty terminals and to search for a set of terminals of the second group of twenty corresponding to the vertical key 1632. Moreover, since the key 1633 is the second key in the group of five, the second of the five different sets of brushes on the translator will be chosen and tripped into engagement with the corresponding section of the terminal bank. Immediately that the horizontal key 1633 is actuated, a circuit is established from ground, conductor 1637, right-hand contacts of key 1633, conductor 1636, upper right-hand contact of sequence switch spring 1836 (1+1 $\frac{1}{2}$), winding of relay 1824 to battery. Relay 1824 becomes energized and closes a circuit from battery through sequence switch magnet 1810, lower

right-hand contact of sequence switch spring 1852, front contact and left-hand armature of relay 1824, back contact and outer right-hand armature of relay 1822 to ground, driving sequence switch 1810 out of position 1 and into position 2. As the sequence switch passes into position 1 $\frac{1}{4}$, a holding circuit is closed as follows for relay 1824: battery through the winding and right-hand armature and contact of said relay, contact and left-hand armature of relay 1825, upper left-hand contact of sequence switch spring 1851 (1 $\frac{3}{4}$ +7), to ground. With the sequence switch 1810 in position 2, the translator switch 1700 is set in operation to select the proper set of brushes as determined by the horizontal key. The circuit for the up-drive power magnet 1868, which causes the upward movement of the translator brush shaft 1734, may be traced from battery through the winding of said magnet, upper contacts of sequence switch spring 1855 (2), front contact and left-hand armature of relay 1824, to ground through the back contact and outer right-hand armature of relay 1822. The brush shaft of the translator switch is moved upwardly and as it approaches its successive brush tripping positions, the commutator brush 1733 encounters the corresponding segments 1753, 1754, 1755, 1756 and 1757. In the present instance, the second horizontal key being the one depressed in a group of five, the following circuit is completed when the brush 1733 encounters the second contact 1754: battery through the winding of relay 1825, lower right-hand contact of sequence switch spring 1835 (1 $\frac{3}{4}$ +6), upper left-hand contact of said spring (1 $\frac{3}{4}$ +2), brush 1733, contact 1754, next to the inner armature and contact of relay 1707, conductor 1635, left-hand contacts of key 1633, conductor 1634, lower left-hand contact of sequence switch spring 1851 to ground. Relay 1825 attracts its armatures and opens the locking circuit of relay 1824. Relay 1824 deenergizes and opens the circuit of the up-drive power magnet 1868 causing the translator switch to come to rest in position for tripping the proper set of brushes. Relay 1824 also completes a circuit from battery through the winding of sequence switch magnet 1810, lower left-hand contact of sequence switch spring 1852 (2), back contact and left-hand armature of relay 1824, back contact and outer right-hand armature of relay 1822 to ground, driving sequence switch 1810 out of position 2 and into position 3. In position 3 of the sequence switch a circuit is closed from battery through the winding of trip magnet 1869, upper left-hand contact of sequence switch spring 1833 (3+6), to ground. Magnet 1869 becomes energized and rotates the trip spindle preparatory to tripping the

selected set of brushes on the next upward movement of the brush shaft. 65

The relay 1824 is again energized in a circuit from battery through its winding, upper right-hand contact of sequence switch spring 1836 (3), conductor 1636, right-hand contacts of key 1633, conductor 1637, to ground. Relay 1824 locks up in the circuit previously traced through the contact and left-hand armature of relay 1825. Relay 1824 also closes a circuit from battery 70 through the winding of sequence switch magnet 1810, lower right-hand contact of spring 1852 (3), front contact and left-hand armature of relay 1824 to ground at the outer right-hand armature of relay 1822, 80 driving sequence switch 1810 out of position 3 and into position 4. In this position the above traced circuit is again closed for the up-drive power magnet 1868 through the upper contacts of sequence switch 85 spring 1855 and the brush shaft 1734 of the translator switch is moved upwardly. The tripped set of brushes 1735, 1736, 1737, 1738, 1739 and 1740 continue to move over the first group of twenty terminals. When 90 the commutator brush 1733 encounters the first contact 1760, belonging to the second group of terminals, a circuit is closed from battery through the winding of relay 1825, lower right-hand contact of spring 1835 95 (1 $\frac{3}{4}$ +6), the upper left-hand contact of said spring (3 $\frac{3}{4}$ +4), brush 1733, contact 1760, conductor 1871, lower left-hand contact of sequence switch spring 1837 (4), conductor 1636 and thence through the right-hand 100 contacts of the horizontal key 1633 to ground. Relay 1825 attracts its armatures opening the circuit of relay 1824 which becomes deenergized and opens the circuit of power magnet 1868. Relay 1824 in addition completes a circuit from battery through the winding of sequence switch magnet 1810, lower left-hand contact of spring 1852 (4), back contact and left-hand armature of relay 1824, back contact and outer right-hand armature of relay 1822 to ground, driving said sequence switch into position 5. 110

If at this time the operator has not depressed the coordinate vertical key 1632, further operation of the translator switch is delayed. If, however, the vertical key has been actuated, or as soon as the operator proceeds to actuate the same, a circuit is closed from battery through the winding of relay 1824, conductor 1872, lower left-hand contact of spring 1848 (5), lower right-hand contact of spring 1847 (5), conductor 1638, right-hand contacts of key 1632 to ground. Relay 1824 becomes energized and locks up 120 in the previously described circuit through the contact and left-hand armature of relay 1825, this latter relay having deenergized 125

when sequence switch 1810 moved from position 4 into position 5. Relay 1824 completes a circuit from battery through the winding of sequence switch magnet 1810, 5 lower right-hand contact of sequence switch spring 1852 (5), front contact and left-hand armature of relay 1824, to ground through the back contact and outer right-hand armature of relay 1822. Sequence 10 switch 1810 advances into position 6 where the power circuit for the up-drive magnet 1868 is again closed through the upper contacts of sequence switch spring 1855 and the left-hand armature of relay 1824. The 15 brushes of the translator switch are driven over the terminals in the second group of twenty to search for a set therein identified by the depressed vertical key. When the desired set of terminals are reached, 20 the commutator brush 1733 encounters the contact 1761 and a circuit is established from battery through the winding of relay 1825, lower right-hand contact of sequence switch spring 1835 (14+6), upper left-hand 25 contact of said spring (54+6), brush 1733, contacts 1761, conductor 1639, left-hand contacts of key 1632, conductor 1640, upper left-hand contact of sequence switch spring 1844 (5+6), to ground. Relay 1825 operates 30 and opens the energizing circuit of relay 1824. Relay 1824, however, remains energized for an instant longer in a holding circuit traceable from battery through its winding and right-hand armature and contact, conductor 1870, commutator 1762, 35 brush 1732 to ground. When the brushes of the translator switch are accurately centered on the selected set of terminals, commutator brush 1732 encounters an insulating segment of commutator 1762 and relay 1824 releases its armatures to open the power circuit of magnet 1868. The switch 1700 thereupon ceases its upward movement. Relay 1824 also completes a circuit from 40 battery through the magnet of sequence switch 1810, lower left-hand contact of sequence switch spring 1852 (6), back contact and left-hand armature of relay 1824 to ground at the outer right-hand armature 45 of relay 1822 for advancing sequence switch 1810 into position 7.

Before proceeding further with the registration of the office designation an explanation will be given of the effects produced 50 in the district selector switch by the depression of the office keys. It was noted that sequence switch 1810 advances into position 2 immediately in response to the actuation of the horizontal key. As the sequence switch 1810 enters position 14, a circuit is completed from battery through the magnet of sequence switch 210, lower left-hand contact of sequence switch spring 208 (12+10), upper left-hand contact of said 55 spring (2), conductor 253, terminal 918, brush 925, contact and inner right-hand armature of relay 904, upper contacts of sequence switch spring 949 (5), lower contact of sequence switch spring 983 (1), conductor 972, back contact and outer right-hand armature of relay 1706, upper and lower contacts of sequence switch spring 1719 (1+6), upper left-hand contact of 60 spring 1851 (14+7), to ground.

The allotter switch 980 which serves a plurality of trunk selector, sender selector units is at this time standing in position 1, the allotting position for the unit disclosed in the drawing. The sequence switch 210 energizes in the circuit just traced and advances from position 2 into position 3. When the district sequence switch 210 leaves position 2, it opens at its lower left-hand contact 212, the holding circuit through the right-hand winding of relay 903. Relay 903 65 becomes deenergized and closes a circuit from ground through its inner right-hand armature and back contact, lower right-hand contact of sequence switch spring 941 (5), winding of magnet 910 to battery. Sequence switch 910 thereupon advances from 70 position 5 into position 6.

In position 3 of sequence switch 210 a circuit is closed from battery through the right-hand winding of relay 204, upper right-hand contact of spring 214 (2+3), lower left-hand contact of spring 215 (3), to ground. Relay 204 operates and closes a circuit from battery through the winding of sequence switch magnet 210, lower left-hand contact of spring 211 (3), upper left-hand contact of said spring (3+12), front contact and left-hand armature of relay 204, 75 to ground through the lower left and upper right-hand contacts of spring 213. Sequence switch 210 advances into position 4 where relay 204 retracts its armatures and closes a circuit as follows: Battery through the winding of sequence switch magnet 210, upper contacts of spring 209 (4), back contact and left-hand armature of relay 204 to ground at sequence switch spring 213. Sequence switch 210 therefore, moves into position 5. As sequence switch 210 reaches 80 position 24 the holding circuit of relay 901 is modified to extend through the lower right-hand contact of spring 212 (24+16), and the upper right-hand contact of said spring (2+12), to ground. This circuit is completed shortly prior to the opening of the original holding circuit for relay 901 at the lower left-hand contact of spring 222.

Setting of translator registers in accordance 85 with the office designation.

When the sequence switch 1810 reaches position 7, a circuit is closed from battery through the winding of relay 1821, outer right-hand armature and contact of relay 130

1830, upper right-hand contact of sequence switch spring 1854 (7+8), to ground. Relay 1821 becomes energized and extends the impulse leads 1861, 1862, 1863, 1864, 1865 and 1866 from the translator brushes through to the relays 1808, 1809, 1811, 1812, 1813 and 1814. As the impulse machine 1790 rotates, these relays are operated in combinations determined by the contacts of 10 the impulse drum engaged by its brushes. With the particular combinations of the relays 1808, 1809, 1811, etc., energized when said impulse drum is in a certain position in its cycle, impulses are transmitted from the 15 drum over leads 1858, 1859, 1860 and 1887 to cause the energization of certain of the translator registers. When the impulse machine rotates to a new position a different combination of relays 1808, 1809, 1811, etc., 20 are operated and impulses are sent over the leads 1858, 1859, 1860 or 1887 to cause the operation of other translator registers. This procedure continues for a complete revolution of the impulse machine at the end of 25 which time the entire office record has been produced on the translator registers by means of impulses sent from the impulse machine.

In order that the transmission of impulses from the impulse machine may commence the instant relay 1821 operates regardless of what position the impulse machine may be in its cycle of rotation, a 30 counting device consisting of three pairs of 35 counting relays 1826, 1827, 1828, 1829, 1830 and 1831 is provided to measure off a complete revolution of the impulse machine. For simplicity, however, it will be assumed that the relative positions of the brushes and the 40 contacts of the impulse machine are as is shown in the drawing at the instant sequence switch 1810 reaches position 7 and relay 1821 operates. Consequently, an instant later the brushes 1776, 1777, 1778 and 1764 45 encounter the metallic segments 1783, 1782, 1779 and 1767 on the surface of the drum. A circuit is thereupon closed from battery through the contact 1783, brush 1776, terminal 1742, brush 1736, conductor 1865, armature 1873 of relay 1821, winding of relay 1809 to ground. A circuit is also closed from battery through the contact 1782, 50 brush 1777, terminal 1741, brush 1735, conductor 1866, armature 1874, winding of relay 1808 to ground. Consequently, relays 1808 and 1809 are energized and the remaining four relays 1811, 1812, etc., remain deenergized. At the same time a circuit is completed from battery through the contact 55 1779, brush 1778, inner right-hand armature and contact of relay 1821, contact and outer left-hand armature of counting relay 1830, winding of relay 1823 to ground. Relay 1823 operates and completes a circuit from 60 ground through its armature and contact, 65

left-hand armature and back contact of relay 1826, winding of relay 1827, to battery. Relay 1827 operates and completes a circuit from battery through its winding, winding of relay 1826, contact and armature of relay 1827, upper left-hand contact of sequence switch spring 1854 (64+17), to ground. Relay 1826, however, does not operate in this circuit since it is shunted out by the direct circuit to ground at the contact and 70 armature of relay 1823. Relay 1808 at its armature and contact closes a circuit for the energization of relay 1815 and relay 1809 closes a similar circuit for relay 1816. With relay 1815 operated a circuit is closed from 75 battery through the contact 1767 of the impulse machine, brush 1764, conductor 1858 next to the inner armature and contact of relay 1815, left-hand winding of relay 1890, to ground. Relay 1890 locks in a circuit from battery through its right-hand winding and contact inner right-hand armature to ground at the lower left-hand contact of sequence switch spring 1844. A circuit is 80 also closed from battery over the conductor 85 1858 through the next to the innermost armature and contact of relay 1816, left-hand winding of relay 1800, to ground. Relay 1800 locks up in a circuit to battery through 90 its right-hand winding and contact and inner right-hand armature to ground through the lower right-hand contact of sequence switch spring 1844 (7+11). The relay 1874 and the three relays associated therewith are not utilized for any specific purpose in 95 the present disclosure. If desirable their contacts may be connected to counting devices which will take a record of the total number of calls made of each of the several different classes. The energized relay 1800 100 gives a record of the class of the call being made and later will determine the setting of the class sequence switch in the sender. 105

The impulse machine by continuing to rotate, disengages its brushes from the first vertical row of contacts shown on the developed surface and advances them to the second vertical row of contacts thereby permitting the relays 1808 and 1809 to become deenergized. As the brush 1778 disengages the 110 contact 1779, the circuit of relay 1823 is opened and this relay becomes deenergized to remove the short-circuit from around the winding of relay 1826. Consequently, relay 1826 actuates and locks up in series with relay 1827. With the brushes of the impulse machine on the second vertical row of contacts, a new combination of impulse circuits is established. One of these circuits may be traced from battery through the contact 115 1789, brush 1771, terminal 1746, brush 1740, conductor 1861, armature 1875, conductor 1861, winding of relay 1814, to ground. Another circuit may be traced from battery through the contact 1787, brush 1773, ter- 120 125 130

55 terminal 1745, brush 1739, conductor 1862, armature 1876, winding of relay 1813, to ground. Another circuit leads from battery through the contact 1785, brush 1775, terminal 1743, brush 1737, conductor 1864, armature 1877, winding of relay 1811, to ground. Relays 1811, 1813 and 1814 operate and close energizing circuits, respectively, for relays 1817, 1819 and 1820. A circuit 10 is also completed from battery through the contact 1780, brush 1778, inner right-hand armature and contact of relay 1821, contact and outer left-hand armature of relay 1830, winding of relay 1823 to ground. Relay 15 1823 operates and closes a circuit from ground through its armature and contact, armature and front contact of relay 1826, armature and back contact of relay 1828, winding of relay 1829 to battery, causing 20 the energization of this latter relay. Relay 1829, upon operating, completes a circuit from battery through its winding and the winding of relay 1828 in series, contact and armature of relay 1829 and thence to ground as above traced through the upper 25 left-hand contact of sequence switch spring 1854. Relay 1828, however, remains inactive due to the direct circuit to ground through the armature and contact of relay 30 1823 which is maintained as long as the brush 1778 remains in engagement with contact 1780. In the second position of the impulse machine, battery is connected through the contact 1768 and brush 1765 to conductor 1859. A circuit is therefore completed from battery over the conductor 1859, through the next to the outer armature and contact of relay 1817, left-hand winding of relay 1802 to ground. Relay 1802 operates 35 and locks up in a circuit from battery through its right-hand winding and contact and right-hand armature to ground through the lower left-hand contact of sequence switch spring 1844 (7+11). A second circuit is closed from battery over the lead 40 1859, through the next to the outer armature and contact of relay 1819, left-hand winding of relay 1805 to ground. Relay 1805 energizes and locks in a circuit through its right-hand winding to ground at the sequence switch contact 1844. Still another circuit is completed from battery through the conductor 1859, next to the outer armature and contact of relay 1820, left-hand winding of relay 1806 to ground. Relay 1806 operates and locks up through its right-hand winding to ground at the sequence switch contact 1844.

45 The continued rotation of the impulse machine causes the brushes to disengage the second position contacts and to advance into engagement with the third vertical row of contacts. As the brush 1778 leaves contacts 1780 the circuit of relay 1823 is opened and 50 this relay deenergizes to open the shunt

around the winding of relay 1828. Relay 1828 thereupon operates and remains energized in series with relay 1829.

55 In the third position of the impulse machine a plurality of circuits are established. One of these may be traced from battery through the contact 1791, brush 1771, terminal 1746, brush 1740 and thence as above described through the winding of relay 1814 to ground. Another circuit leads from 60 battery through the contact 1784, brush 1776, terminal 1742, brush 1736, wiper 1865, armature 1873, winding of relay 1809 to ground. Relays 1809 and 1814 operate and respectively close energizing circuits for relays 1816 and 1820. Since brush 1766 is at 65 this time in engagement with contact 1769, battery potential is connected to the conductor 1860 and consequently a circuit is extended through the outermost armature and contact of relay 1816, left-hand winding of relay 1801, to ground. Another circuit is completed from battery over conductor 1860 through the outermost armature and contact of relay 1820, left-hand winding of relay 1807 to ground. Relays 70 1801 and 1807 lock in circuits through their right-hand windings and to ground at the lower right-hand contact of sequence switch 75 spring 1844.

80 The impulse machine continues to rotate, disengages its third position contacts permitting relays 1809 and 1814 to release, and moves into engagement with the vertical row 85 of contacts in the fourth position. A plurality of circuits are now completed, one of which may be traced from battery through the contact 1788, brush 1773, terminal 1745, brush 1739, conductor 1862, armature 1876, winding of relay 1813, to ground. Another circuit leads from battery through the contact 1786, brush 1774, terminal 1744, brush 1738, conductor 1863, armature 1878, winding of relay 1812 to ground. Relays 1812 90 and 1813 now operate and close circuits respectively for the energization of relays 1818 and 1819. A circuit is also closed from battery through the contact 1781, brush 1778, inner right-hand armature and contact of relay 1821 and contact and outer left-hand armature of relay 1830, winding of relay 1823 to ground. Relay 1823 completes a circuit from ground through its armature and contact, left-hand armature and front contact of relay 1826, left-hand armature and front contact of relay 1828, inner left-hand armature and contact of relay 1830, winding of relay 1831 to battery. Relay 1831 energizes and closes a circuit for itself in series 95 with relay 1830. Relay 1830, however, does not energize at this time since its winding is shunted by a direct circuit to ground at the contact and armature of relay 1823. With the impulse machine in its fourth position, or at the completion of a revolution, the 100

105

110

115

120

125

130

brush 1763 engages contact 1770 and battery potential is connected to the conductor 1887. A circuit is thereby closed from battery over the conductor 1887, through the innermost armature and contact of relay 1818, left-hand winding of relay 1803 to ground. A second circuit is closed from battery over the conductor 1861, through the innermost armature and contact of relay 1819, left-hand winding of relay 1804 to ground. Relays 1803 and 1804 operate and lock up in circuits through their right-hand windings to ground at sequence switch spring 1844. The impulse machine has now rotated through a complete revolution and the office record is recorded on the translator register relays. As soon as the brush 1778 leaves contact 1781, relay 1823 becomes deenergized and opens the shunt circuit around the winding of relay 1830, permitting this relay to operate in series with relay 1831. Relay 1830 at its outer right-hand armature opens the circuit of relay 1821 and this latter relay deenergizes to disconnect the impulse leads from the brushes of the translator switch whereby the continued rotation of the impulse machine will not cause the further sending of impulses into the translator register circuit.

30 *Setting of numerical registers from the operator's keyboard.*

At the time the sequence switch 1810 passes into position 7 following the operation 35 of the translator switch, the sequence switch 1710 is in position 1 and sequence switch 910 in position 6. A circuit is completed from battery through the inner right-hand armature and contact of relay 1822, winding of relay 1706, lower contacts of sequence switch 40 spring 1717 (1), upper right and lower right-hand contacts of sequence switch spring 1838 (6 $\frac{3}{4}$ +7), conductor 973, contact and outer left-hand armature of relay 908, lower left-hand and upper right-hand contacts of sequence switch 45 spring 937 (6+7), winding of relay 909, to ground at the front contact and outer right-hand armature of relay 904. Relays 1706 and 909 are operated in this 50 circuit and a new circuit is completed as follows: Battery through the inner right-hand armature and contact of relay 1822, winding of relay 1706, upper right and lower left-hand contacts of sequence switch 55 spring 1835 (7+11), contact and outer left-hand armature of relay 1706, conductor 974, winding of relay 908, contact and inner left-hand armature of relay 909, upper contacts of sequence switch 60 spring 937, winding of relay 909 to ground at the outer right-hand armature of relay 904. Consequently, relays 1706, 908 and 909 are all locked up in series with each other. Relay 908, upon 65 energizing, closes a circuit from ground through its outer right-hand armature and

front contact, lower left-hand contact of sequence switch spring 939 (6), winding of magnet 910 to battery, driving sequence switch 910 out of position 6 and into position 7. Relay 1706 also completes a circuit 70 which extends from battery through the windings of relays 1624, 1625, 1626 and 1627 in parallel to conductor 1641 through the front contact and outer right-hand armature of relay 1706, left-hand contacts of spring 75 1719 (1+6), upper left-hand contact of sequence switch spring 1851 (1 $\frac{3}{4}$ +7), to ground. Relays 1624, 1625, 1626 and 1627 operate and complete the control leads to the numerical keys. A circuit is now established 80 from battery through the winding of sequence switch magnet 1710, lower left-hand contact of sequence switch spring 1711 (1), front contact and inner right-hand armature of relay 1706, upper contact of sequence 85 switch spring 1718 (1), conductor 1642, contact and innermost armature of relay 1624 to ground through the contact 1616. Contact 1616 is common to the row of keys including 90 the stations and start key and is closed upon the depression of any one thereof. Sequence switch 1710, consequently, advances from position 1 into position 2.

In position 2 of sequence switch 1710 a circuit is closed from battery through the 95 resistance 1842, upper left-hand contact of sequence switch spring 1720 (2), thence to ground over two paths, one of which leads through the winding of relay 1703 and the other through the back contact and lower 100 armature of relay 1703 and the normally closed contact at the inner left-hand armature of relay 1704. Due to the shunt around the winding of relay 1703 this relay remains inert. A circuit is completed from 105 ground through the upper armature and contact of relay 1703, left-hand low resistance winding of relay 1704, lower right-hand contact of sequence switch spring 1714 (1+4), upper left-hand contact of 110 said sequence switch spring (2), conductor 1643, right-hand contacts of thousands key 1617 next to the outer armature and contact of relay 1626, upper left-hand contact of sequence switch spring 1728 (2), 115 lower right-hand contact of said spring (1+5), conductor 1792, outer left-hand armature and contact of relay 909, lower contact of sequence switch spring 936 (6+7), brush 965, terminal 959, conductor 120 1050, upper left-hand contact of sequence switch spring 1325 (1 $\frac{3}{4}$ +2), lower right-hand contact of said spring (1+2), conductor 1342, left-hand winding of relay 1511, to battery. Although relay 1511 is 125 marginal it becomes energized since only the low resistance of relay 1704 is included in series therewith. Relay 1511 locks up in a circuit from battery through its right-hand winding and contact and inner right- 130

hand armature, conductor 1343, upper left-hand contact of sequence switch spring 1321 ($1\frac{3}{4}+12$), to ground. Relay 1704 also operates and locks up in series with relay 5 1511 through its inner left-hand armature and make before break contact to ground. Relay 1704 in operating removes the shunt from around the winding of relay 1703 and this latter relay becomes energized. Another 10 circuit is closed from battery through the low resistance 1622 and high resistance 1623, left-hand contacts of key 1617, innermost armature and contact of relay 1627, conductor 1645, upper left-hand contact of 15 sequence switch spring 1725 ($1\frac{3}{4}+2$), lower right-hand contact of said spring (1+5), conductor 1793, right-hand armature and contact of relay 909, lower contact of sequence switch spring 943 (6+7), brush 966, 20 terminal 960, conductor 1051, lower left-hand contact of sequence switch spring 1326 ($1\frac{3}{4}+2$), lower right-hand contact of said spring (1+2), conductor 1344, right-hand winding of relay 1515, left-hand winding of 25 relay 1512 to ground. Relay 1512 being sensitive operates, but due to the marginal character of relay 1515, said latter relay does not energize since the high resistance 1623 is included in the circuit thereof. 30 Relay 1512 locks up in a circuit from battery through its right-hand winding and contact and right-hand armature to the grounded conductor 1543. Upon the energization of relay 1704 a circuit is closed 35 from battery through the low resistance 1722, right-hand armature and contact of relay 1704, high resistance 1721, lower right-hand contact of sequence switch spring 1724 (2), conductor 1794, front contact and inner right-hand armature of relay 908, brush 967, terminal 961, conductor 1052, left-hand winding of relay 1418, conductor 1420, lower left-hand contact of sequence 40 switch spring 1316 (2), winding of relay 1312 to ground. Relay 1312 operates, but due to the high resistance 1721 the marginal relay 1418 remains inactive. Relay 1312 completes a circuit from battery through sequence switch magnet 1310, armature and front contact of relay 1312, lower right-hand and upper left-hand contacts of sequence switch spring 1313, back contact and armature of relay 1311, to ground. Sequence switch 1310 moves from position 2 45 into position 3. In passing from position 2 into position 3, the sequence switch opens its upper left and lower right-hand contacts 1325, thereby opening the holding circuit of relay 1704. Relay 1704, upon deenergizing, completes a circuit from battery through the winding of sequence switch magnet 1710, upper right-hand contact 1711 (2), contact and left-hand armature of relay 1702, front contact and lower armature 50 of relay 1703, normally closed contacts at the inner left-hand armature of relay 1704 to ground, moving sequence switch 1710 out of position 2 and into position 3. In passing from position 2 into position 3, contact 1720 is opened and relay 1703 releases. 70 When relay 1704 deenergizes it opens at its right-hand armature and contact the circuit of relay 1312 and this relay becomes deenergized. 75 In position 3 of sequence switch 1710 a circuit is closed from battery through resistance 1842, lower right-hand contact of sequence switch spring 1720 (3), and thence to ground over two paths, one of which leads through the winding of relay 1701 and the other through the back contact and lower armature of relay 1701 and the normally closed contacts at the inner right-hand armature of relay 1702. Due to the shunt around the winding of relay 1701 it fails to operate at this time. Another circuit is closed from ground through the upper armature and contact of relay 1701, through the right-hand low and left-hand high resistance windings of relay 1702, lower left-hand contact of sequence switch spring 1725 (3), lower right-hand contact of said spring (1+5), conductor 1793 and thence as hereinbefore traced through the sender selector switch to conductor 1051, lower left-hand contact of sequence switch spring 1327 ($2\frac{1}{4}+3$), upper right-hand contact of said spring (2+3), conductor 1346, left-hand winding of relay 1509, to battery. Relay 1509 being marginal does not energize in series with the high resistance winding of relay 1702. Relay 1702, however, operates and closes a holding circuit for itself in series with relay 1509 through the inner right-hand armature and front contact of relay 1702. When relay 1702 operates it removes the shunt from around the winding of relay 1701 and this latter relay attracts its armatures. Another circuit is closed from battery through the low resistance 1622, left-hand contacts of key 1618, outermost armature and contact of relay 1626, conductor 1646, upper left-hand contact of sequence switch spring 1726 ($2\frac{3}{4}+3$), lower right-hand contact of sequence switch spring 1728 (1+5), conductor 1792 and thence as above traced through the sender selector to conductor 1050, lower left-hand contact of sequence switch spring 1318 ($2\frac{3}{4}+3$), upper right-hand contact of said spring (2+3), conductor 1345, right-hand winding of relay 1508, left-hand winding of relay 1510, to ground. Since only the low resistance 1622 is included in the circuit both relay 1510 and marginal relay 1508 are energized. 115 These relays lock up in circuits closed through their second windings to the grounded conductor 1343. 120 When relay 1702 operates it closes the circuit from battery through the low resistance 130 conductor 1050, lower left-hand contact of sequence switch spring 1318 ($2\frac{3}{4}+3$), upper right-hand contact of said spring (2+3), conductor 1345, right-hand winding of relay 1508, left-hand winding of relay 1510, to ground. Since only the low resistance 1622 is included in the circuit both relay 1510 and marginal relay 1508 are energized. 125 These relays lock up in circuits closed through their second windings to the grounded conductor 1343.

1722, outer right-hand armature and contact of relay 1702, high resistance 1721, lower right-hand contact of sequence switch spring 1709 (3), conductor 1795, inner left-hand armature and contact of relay 908, lower left and upper right-hand contacts of sequence switch spring 942 (6+7), brush 962, terminal 956, conductor 1047, right-hand winding of relay 1417, upper left-hand contact of sequence switch spring 1317 (3), winding of relay 1311, to ground. Relay 1311 becomes energized, but relay 1417 being marginal does not operate in series with the high resistance 1721. Relay 1311 completes a circuit from ground through its armature and front contact, upper right and lower left-hand contacts of sequence switch spring 1313 (3), back contact and armature of relay 1312, winding of sequence switch magnet 1310 to battery, driving said sequence switch into position 4. When sequence switch 1310 leaves position 3 it opens the circuit of relay 1702 and this relay becomes deenergized, and in turn, opens the circuit of relay 1311. Relay 1702 on releasing completes a circuit from battery through the winding of sequence switch 1710, lower right-hand contact of spring 1711 (3), contact and outer left-hand armature of relay 1704, front contact and lower armature of relay 1701, to ground at the normally closed contacts of relay 1702. Sequence switch 1710 advances out of position 3 and into position 4. In position 4 of sequence switch 1710 the circuit hereinbefore traced is closed from battery through resistance 1842, thence through the winding of relay 1703 and through the normally closed contacts of relay 1704 to ground, relay 1703 remaining deenergized. A circuit is also closed from ground through the upper armature and contact of relay 1703, left-hand and right-hand windings of relay 1704 in series, lower left-hand contact of sequence switch spring 1726 (4), lower right-hand contact of spring 1728 (1+5), conductor 1792 and thence to conductor 1050, upper left-hand contact of spring 1325 (3 $\frac{3}{4}$ +4), lower left-hand contact of said spring (3+4), conductor 1347, left-hand winding of relay 1407, to battery. Relay 1407 being marginal does not operate in series with the high resistance winding of relay 1704. Relay 1704, however, operates and removing the shunt from relay 1703 allows this latter relay to energize. Relay 1704 locks up at its inner left-hand armature and contact in series with relay 1407. Another circuit is closed from battery through the low resistance 1622, left-hand contacts of key 1619, innermost armature and contact of relay 1626, conductor 1647, upper right-hand contact of spring 1725 (3 $\frac{3}{4}$ +4), lower right-hand contact of said spring (1+5), conductor 1793, thence to

conductor 1051, lower left-hand contact of spring 1326 (3 $\frac{3}{4}$ +4), upper left-hand contact of said spring (3+4), right-hand winding of relay 1415, left-hand winding of relay 1408 to ground. Since only the low resistance 1622 is included in this circuit both relays 1415 and 1408 operate. These relays lock up in circuits extending over conductor 1421, lower right-hand contact of spring 1319 (1 $\frac{3}{4}$ +12), to ground. 75

When relay 1704 operates it closes a circuit from battery through the low resistance 1722, right-hand armature and contact of said relay, high resistance 1721, lower right-hand contact of sequence switch spring 1724 (4), conductor 1794, thence to conductor 1052, through the left-hand winding of relay 1409, lower right-hand contact of spring 1316 (4), winding of relay 1312 to ground. Relay 1409 being marginal does not operate, but relay 1312 energizes and completes a circuit from battery through the winding of sequence switch magnet 1310, armature and front contact of relay 1312, lower right and upper left-hand contacts of spring 1313, back contact and armature of relay 1311 to ground, driving said sequence switch into position 5. On leaving position 4 sequence switch 1310 opens the circuit of relay 1704 and this relay becomes deenergized. With relay 1704 deenergized and relay 1703 energized a circuit is closed from battery through the winding of sequence switch magnet 1710, upper right-hand contact of spring 1711 (4), contact and left-hand armature of relay 1702, front contact and lower armature of relay 1703 to ground at the normal contacts of relay 1702. Sequence switch 1710 advances from position 4 into position 5. When relay 1704 deenergizes, it opens the circuit of relay 1312 permitting this relay to release its armature. 95 100 105

In position 5 of sequence switch 1710 the above traced circuit is completed through the winding of relay 1701 and to ground at the right-hand contacts of relay 1702, relay 1701 remaining deenergized. Another circuit is established from ground through the upper armature and contact of relay 1701, right-hand low resistance winding of relay 1702, lower right-hand contact of spring 1729 (1+5), upper right-hand contact of said spring (5+6), conductor 1648, outermost armature and contact of relay 1624, right-hand contacts of key 1620, innermost 115 120 125 armature and contact of relay 1625, conductor 1649, lower right-hand contact of spring 1727 (5), lower right-hand contact of spring 1725 (1+5), conductor 1793, thence to conductor 1051, lower left-hand contact of spring 1327 (4 $\frac{3}{4}$ +5), lower right-hand contact of said spring (4+5), left-hand winding of relay 1405 to battery. Relay 1405 operates and locks up through its right-hand winding to the grounded conductor 130

1421. Relay 1702 also becomes energized and locks up through its inner right-hand armature and front contact to ground in series with the register relay 1405. The operation of relay 1702 permits the energization of relay 1701 as described. Still another circuit is completed from battery through the low resistance 1622, left-hand contacts of key 1620, next to the inner armature and contact of relay 1625, conductor 1650, upper right-hand contact of spring 1726 (4 $\frac{3}{4}$ +5), lower right-hand contact of spring 1728 (1+5), conductor 1792, thence to conductor 1050, lower left-hand contact of sequence switch spring 1318 (4 $\frac{3}{4}$ +5), upper left-hand contact of said spring (4+5), right-hand winding of relay 1404, left-hand winding of relay 1406 to ground. Since only the low resistance 1622 is included in the circuit, both relays 1404 and 1406 are operated. These relays lock up to the grounded conductor 1421. When relay 1702 operates it closes a circuit from battery through resistance 1722, outer right-hand armature and contact of relay 1702, high resistance 1721, lower right-hand contact of spring 1709 (5), conductor 1795 and, thence to conductor 1047, right-hand winding of relay 1416, upper right-hand contact of spring 1317 (5), winding of relay 1311, to ground. The high resistance 1721 prevents the operation of marginal relay 1416. Relay 1311, however, operates and closes the above traced circuit for driving sequence switch 1310 into position 6. Sequence switch 1310 on leaving position 5 opens the energizing circuit of relay 1702 and this relay becomes deenergized to close a circuit from battery through the winding of sequence switch 1710, lower right-hand contact of spring 1711 (5), contact and outer left-hand armature of relay 1704, front contact and lower armature of relay 1701, to ground at the normally closed contacts of relay 1702. Sequence switch 1710 moves from position 5 into position 6 and relay 1701 becomes deenergized.

Release of office and numerical keys.

Since the office and numerical keys are no longer needed in connection with the registration of the depressed keys on the operator's board, they are now restored. With sequence switch 1710 in position 6 a circuit is closed from ground over conductor 1637, thence through the windings of key release magnets 1609, 1608, 1607, 1606 and 1605 in parallel, conductor 1651, left-hand contacts of sequence switch spring 1727 (6), to battery. A second circuit is closed from ground over conductor 1637 through the windings of key release magnets 1611, 1612, 1613 and 1614 in parallel, conductor 1652, lower right-hand contact of spring 1726 (6 + 15), lower left-hand contact of spring

1728 (6), to battery. A third circuit is completed from ground over conductor 1637, winding of magnet 1615, right-hand contacts of key 1653 and thence over conductor 1652 to battery. The key release magnets are all energized and serve to permit the release of the keys which the operator has depressed. At the same time that sequence switch 1710 reached position 6 a plurality of parallel circuits were established for relay 1705, these circuits leading through the contacts of keys in each of the different rows. One of these circuits may be traced from battery through the winding of relay 1705, lower left-hand contact of spring 1723 (4 + 6), conductor 1636, right-hand contacts of key 1633 through the grounded conductor 1637. The circuit for the vertical row of keys may be traced from battery through the winding of relay 1705, lower right-hand contact of spring 1731 (4 + 6), conductor 1638, right-hand contacts of key 1632 to ground. Another branch leads from battery through the winding of relay 1705, lower left-hand contact of spring 1731 (4 + 6), conductor 1644, next to the outermost armature and contact of relay 1626, right-hand contacts of key 1617, conductor 1643, left-hand contacts of sequence switch spring 1714 (5 $\frac{3}{4}$ + 6), to ground. Another circuit may be traced from battery through the winding of relay 1705, upper right-hand contact of spring 1731 (4 + 6), conductor 1654, right-hand contacts of key 1618, conductor 1637, to ground. Still another circuit may be traced from battery through the winding of relay 1705, upper right-hand contact of spring 1731 (4 + 6), thence over conductor 1654, right-hand contacts of key 1619 to the grounded conductor 1637. Lastly, a path may be traced from battery through the winding of relay 1705, left-hand contacts of sequence switch spring 1730, conductor 1649, innermost armature and contact of relay 1625, right-hand contacts of key 1620, outermost armature and contact of relay 1624, conductor 1648, upper right and lower left-hand contacts of sequence switch spring 1729 to ground. Relay 1705 is energized and remains operative as long as any one of its several circuits is closed, or in other words, until all of the actuated keys have been released. When all keys have been released the relay 1705 deenergizes and closes a circuit from battery through the winding of sequence switch magnet 1710, upper left-hand contact of spring 1711 (6), armature and contact of relay 1705 to ground, driving the sequence switch out of position 6 and into position 7. When sequence switch 1710 leaves position 6 the circuits of the key release magnets and relays 1624, 1625, 1626 and 1627 are severed permitting the same to become deenergized.

Transfer of office record from translator registers to the sender registers.

At the time sequence switch 1710 reaches position 6 a circuit is closed from battery through the winding of relay 1824, upper left-hand contact of sequence switch spring 1836 (7), lower left-hand contact of sequence switch spring 1713 (6), to ground. 5 Relay 1824 operates and locks in a circuit through its right-hand armature and contact and left-hand armature of relay 1825 and through the upper left-hand contact of spring 1851, to ground. The operation of relay 1824 serves as an indication that the numerical record has been completely set up 10 on the registers of the sender. If at this time the translator registers have all been set from the impulse machine, or as soon 15 thereafter as such condition is brought about, a circuit is established from battery through the winding of sequence switch magnet 1810, upper right-hand contact of spring 1852 (7), contact and inner right-hand armature of relay 1830, front contact and left-hand armature of relay 1824, to ground at the outer right-hand armature of relay 1822. Sequence 20 switch 1810 advances to position 8 which is the position in which the transfer of the office record commences.

The class registration is the first to be transferred from the translator registers to the corresponding registers in the sender. In position 8 of sequence switch 1810 a circuit is closed from battery through resistance 1842, left-hand contact of spring 1839 (8), thence in parallel through the winding of relay 1703 and through the back contact and lower armature of said relay and the 25 normally closed contacts of relay 1704 to ground. Relay 1703 being shunted remains deenergized. Another circuit is closed from ground through the upper armature and contact of relay 1703, left and right-hand 30 windings of relay 1704, conductor 1879, contact and outer right-hand armature of relay 1801, upper right-hand contact of spring 1846 (8), conductor 1792, thence to conductor 1050, upper left-hand contact of spring 50 1325 (5 $\frac{3}{4}$ +12), upper right-hand contact of said spring (5+6), conductor 1334, right-hand winding of relay 1503 to battery. Since relay 1503 is marginal it fails to operate, but relay 1704 attracts its armatures 55 and locks up as above described, at the same time permitting the energization of relay 1703. Another circuit is closed from ground through the left-hand armature and contact of relay 1800, upper left-hand contact of 60 sequence switch spring 1843 (7 $\frac{3}{4}$ +8), conductor 1795, thence to conductor 1047, lower left-hand contact of spring 1315 (5 $\frac{3}{4}$ +6), upper left-hand contact of said spring (5+6), conductor 1331, right-hand winding 65 of relay 1500 to battery. Relay 1500 oper-

ates and locks up in a circuit from battery through its left-hand winding and contact and left-hand armature, conductor 1519, lower right-hand contact of sequence switch spring 1321 (1 $\frac{1}{4}$ +12), to ground. When relay 1704 operates a circuit is closed from battery through the low resistance 1722, right-hand armature and contact of said relay, conductor 1880, left-hand armature and contact of relay 1801, upper right-hand contact of spring 1847 (8), lower right-hand contact of spring 1848 (6+18), conductor 1794, thence to conductor 1052, through the right-hand winding of relay 1501, conductor 1335, upper left-hand contact of spring 1316 (6), winding of relay 1312, to ground. Relay 1501 operates and locks up to the grounded conductor 1519. Relay 1312 becomes energized and closes a circuit for driving sequence switch 1310 out of position 6 and into position 7. Sequence switch 1310 on reaching position 7 opens the holding circuit of relay 1704 and this relay becomes deenergized, in turn, opening the circuit of relay 1312. With relay 1704 deenergized and relay 1703 energized a circuit is closed from battery through the winding of sequence switch magnet 1810, upper right-hand contact of sequence switch spring 1853 (8), contact and left-hand armature of relay 1702, front contact and lower armature of relay 1703 to ground at the normally closed contacts of relay 1704. Sequence switch 1810 moves out of position 8 and into position 9, opening the holding circuit of relay 1703 at sequence switch spring 1839.

With sequence switch 1810 in position 9 and sequence switch 1310 in position 7 a circuit is closed from battery through the resistance 1842, right-hand contact of spring 1839 (9), thence to ground over the parallel circuits, one of which leads through the winding of relay 1701 and the other directly through the normally closed contacts of relay 1702. A circuit is also closed from ground through the upper armature and contact of relay 1701, right-hand winding of relay 1702, conductor 1881, upper contact of sequence switch spring 1845 (9), contact and left-hand armature of the district brush register relay 1802, contact and outer right-hand armature of the office brush register relay 1804, upper right-hand contact of spring 1850 (9), conductor 1793 and thence to conductor 1051, lower left-hand contact of spring 1327 (6 $\frac{1}{4}$ +7), upper left-hand contact of said spring (6+7), conductor 1338, left-hand winding of relay 1401 to battery. Relay 1401 operates since only the low resistance winding of relay 1702 is included in series therewith and locks through its right-hand winding to the grounded conductor 1519. Relay 1702 also operates and locks to ground at its inner right-hand armature and contact. Relay 1701 now becomes ener-

gized, the shunt around its winding having been removed. When relay 1702 operates it closes a circuit from battery through the low resistance 1722, outer right-hand armature and front contact of relay 1702, conductor 1880, upper and lower contacts of sequence switch spring 1882, outer right-hand armature and contact of office brush register relay 1805, upper right-hand contact of spring 1843 (9), conductor 1795 and thence to conductor 1047, left-hand winding of relay 1504, conductor 1520, lower right-hand contact of spring 1817 (7), winding of relay 1311 to ground. Both relays 1504 and 1311 operate, relay 1504 locking in a circuit through its right-hand winding and contact and inner right-hand armature, conductor 1521, lower right-hand contact of sequence switch spring 1309, to ground. Relay 1311 completes the above traced circuit for advancing sequence switch 1310 out of position 7 and into position 8. Sequence switch 1310 on leaving position 7 opens the holding circuit of relay 1702 and this relay releases to in turn open the energizing circuit of relay 1311. A circuit is now closed from battery through the winding of sequence switch magnet 1810, upper left-hand contact of spring 1853 (9), back contact and outer left-hand armature of relay 1704, front contact and lower armature of relay 1701 to ground at the normal contacts of relay 1702. Sequence switch 1810 moves out of position 9 and into position 10.

In its tenth position sequence switch 1810 establishes a circuit from battery through resistance 1842, left-hand contact of spring 1839 (10) and thence as already traced to ground over parallel paths, one including the winding of relay 1703. At the same time a circuit is established from ground through the upper armature and contact of relay 1703, both windings of relay 1704 in series, conductor 1879, contact and outer right-hand armature of district group register relay 1803, left-hand contacts of spring 1840, conductor 1792, thence to conductor 1050, upper left-hand contact of spring 1325 (5 $\frac{3}{4}$ +12), upper left-hand contact of spring 1324 (7 $\frac{3}{4}$ +8), conductor 1336, left-hand winding of relay 1413 to battery. Since relay 1413 is marginal it does not operate in series with the high resistance winding of relay 1704. Relay 1704, however, attracts its armatures and locks up as hereinbefore explained, permitting the energization of relay 1703. Another circuit is closed from battery through the low resistance 1856, left-hand armature and contact of register relay 1803, upper left-hand contact of spring 1850 (9 $\frac{1}{2}$ +10), conductor 1793 and thence to conductor 1051, lower left-hand contact of spring 1326 (5 $\frac{3}{4}$ +9), lower left-hand contact of spring 1323 (8 $\frac{3}{4}$ +9), conductor 1333, left-hand winding of relay 1506 to battery. Since only the low resistance winding of relay 1702 is included in the circuit traced, the marginal relay 1506 operates and locks to the grounded conductor 1521. Relay 1702 also energizes and locks as above explained permitting the operation of relay 1701. Relay 1702, upon operation, establishes a circuit from battery through the low resistance 1722, outer right-hand armature and contact of said relay, conductor 1880, left-hand armature and contact of relay 1807, left-hand contacts of spring 1849 (11), conductor 1795, thence to conductor 1047, right-hand winding of relay 1410, lower left and upper right-hand contacts of spring 1314 (9), winding of relay 1311, to ground. Both relays 1410 and 1311 are operated in 130

ing of relay 1402, left-hand winding of relay 1403 to ground. Both relays 1402 and 1403 become energized in this circuit and lock over their second windings to the grounded conductor 1519. When relay 1704 operates 70 it closes a circuit from battery through the low resistance 1722, right-hand armature and contact of said relay, high resistance 1721, upper right-hand contact of spring 1848 (10), lower right-hand contact of said 75 spring (6+18), conductor 1794 and thence to conductor 1052, right-hand winding of relay 1419, lower right and upper left-hand contacts of spring 1314 (8), winding of relay 1312, to ground. Relay 1419 does not 80 operate in series with the high resistance 1721, but relay 1312 does become energized and closes the hereinbefore traced circuit for moving sequence switch 1310 into position 9. Upon leaving position 8 said 85 sequence switch opens the holding circuit of relay 1704, which in turn, releases and opens the energizing circuit of relay 1312. A circuit is thereupon established from battery through the winding of sequence switch 90 magnet 1810, upper right-hand contact of spring 1853 (10), contact and left-hand armature of relay 1702, front contact and lower armature of relay 1703 to ground at the normal contacts of relay 1704, moving 95 sequence switch 1810 into position 11.

In position 11 of sequence switch 1810 the above traced circuit is established from battery through the resistance 1842 to 100 ground through the relay 1701 and also to ground in a parallel path. Another circuit is closed from ground through the upper armature and contact of relay 1701, right-hand low resistance winding of relay 1702, conductor 1881, lower contact of spring 1845 105 (11), contact and left-hand armature of office group register relay 1806, lower left-hand contact of spring 1850 (10 $\frac{3}{4}$ +11), conductor 1793 and thence to conductor 1051, lower left-hand contact of spring 1326 110 (5 $\frac{3}{4}$ +9), lower right-hand contact of spring 1323 (8 $\frac{3}{4}$ +9), conductor 1333, left-hand winding of relay 1506 to battery. Since only the low resistance winding of relay 1702 is included in the circuit traced, the 115 marginal relay 1506 operates and locks to the grounded conductor 1521. Relay 1702 also energizes and locks as above explained permitting the operation of relay 1701. Relay 1702, upon operation, establishes a circuit from battery through the low resistance 1722, outer right-hand armature and contact of said relay, conductor 1880, left-hand armature and contact of relay 1807, left-hand contacts of spring 1849 (11), conductor 1795, thence to conductor 1047, right-hand winding of relay 1410, lower left and upper right-hand contacts of spring 1314 120 (9), winding of relay 1311, to ground. Both relays 1410 and 1311 are operated in 125

this circuit, relay 1410 locking up through its left-hand winding to the grounded conductor 1521. Relay 1311 closes the above traced circuit for driving sequence switch 1310 out of position 9 and into position 10. On leaving position 9 sequence switch 1310 opens the holding circuit of relay 1702 which deenergizes to in turn open the circuit of relay 1311. Sequence switch 1810 is driven 10 out of position 11 and into position 12 by means of a circuit from battery through the winding of its magnet, upper left-hand contact of spring 1853 (11), contact and outer left-hand armature of relay 1704, 15 front contact and lower armature of relay 1701 to ground at the normally closed contacts of relay 1702.

Restoration of the translator switch.

- 20 At the time the sequence switch 1810 moves into position 8 following the completion of the numerical registration on the registers of the sender it prepares for the restoration to normal of the translator 25 switch 1700. The translator switch, however, should not be released at this time provided the office record has not been completely transferred from the impulse machine to the translator register relays. Consequently, the circuit for the downdrive power 30 magnet 1867 depends upon the arrival of sequence switch 1810 into position 8 and also upon the deenergized condition of relay 1821, which relay is released immediately 35 following the completion of the office registration on the translator registers. The circuit for the power magnet 1867 may be traced from battery through the winding of said magnet, back contact and outer right-hand armature of relay 1821, lower left-hand contact of sequence switch spring 1854 40 (8 + 16), to ground. Power magnet 1867 causes the downward movement of brush shaft 1734.
- 45 Following the transfer of the office record from the translator registers to the sender in the manner above discussed, the sequence switch 1810 finally arrives in position 12. When the translator switch is restored to its 50 normal position a circuit is closed from battery through the winding of relay 1821, lower left-hand contact of sequence switch spring 1855 (7 + 17), lower right-hand contact of said spring (7 $\frac{3}{4}$ + 16), normal position 55 segment 1796, brush 1732, to ground. With relay 1821 operated and sequence switch 1810 in position 12 a circuit is closed from battery through the winding of said sequence switch, upper left-hand contact of spring 1834 (12), front contact and outer right-hand armature of relay 1821, lower left-hand contact of spring 1854 (8 + 16), to ground, driving sequence switch 1810 out of position 12 and into position 16. When

sequence switch 1810 leaves position 11 the 65 register relays are released.

As sequence switch 1810 leaves position 11 it opens at the upper right and lower left-hand contacts of spring 1835 the circuit which up to this time maintains the energization of relays 1706, 908 and 909 and these 70 relays become deenergized. Relay 1706 closes a circuit from battery through the magnet winding of sequence switch 1710, right-hand contacts of spring 1716 (7 + 9), 75 back contact and inner right-hand armature of relay 1706, lower contact of spring 1718 (2 + 9), to ground. Sequence switch 1710 moves into position 10 where it is ready to advance through its remaining positions to 80 control the numerical registration in connection with a subsequent call. Sequence switch 1810 is driven into its normal position 1 by means of the following circuit: 85 battery through the winding of said sequence switch, upper right-hand contact of spring 1834 (16), left-hand contacts of spring 1716 (10), outer right front contact of relay 1821, lower left-hand contact of spring 1854 (8 + 16), to ground. On leaving position 17 sequence switch 1810 opens the holding circuit of relay 1821 and the counting relays 1826, 1827, 1828, etc., whereby 90 these relays all retract their armatures. The operator's keyboard and all associated equipment are now restored to normal condition 95 ready to be taken for use in connection with further calls.

Relay 908 which retracts its armatures at the time relay 1706 deenergizes completes 100 a circuit from battery through the winding of sequence switch magnet 910, lower right-hand contact of sequence switch spring 939 (7), back contact and outer right-hand armature of relay 908, to ground, driving 105 sequence switch 910 into position 8.

Setting of class sequence switch and preparation of sender for controlling selections.

The setting of the class sequence switch 110 1110 takes place as soon as the class designation has been recorded on the register relays 1500, 1501, 1502 and 1503. For the particular call being considered herein it is necessary to set the class sequence switch 1110 in position 10 and consequently relays 111 1500 and 1501 are operated, while the other two relays remain deenergized. Consider, that the sequence switch 1110, which may be in any of its positions, depending upon 120 where it was driven when last taken for use, is standing in position 2. A circuit is closed from battery through the winding of sequence switch magnet 1110, upper left-hand contact of spring 1138 (2), conductor 1140, 125 back contact and right-hand armature of relay 1502 to the grounded conductor 1332. Sequence switch 1110 moves out of position 2

and into position 3, and a circuit is closed from battery through the winding of said sequence switch, through the lower left-hand contact of spring 1138 (3), conductor 1141, back contact and right-hand armature of relay 1503 to the grounded conductor 1332. Sequence switch 1110 moves into position 4 where the above traced circuit is again closed at the upper left-hand contact of spring 1138, 10 said sequence switch then moves into position 5 where the circuit through the lower left-hand contact of spring 1138 is repeated and the sequence switch is advanced into position 6. This procedure continues, the 15 sequence switch 1110 advancing from one position to the next by the alternate closures of the two circuits traced until it reaches position 8. In this position a new circuit is closed from battery through the winding of 20 the sequence switch magnet, lower left-hand contact of spring 1139, conductor 1142, front contact and right-hand armature of relay 1500 to ground over the conductor 1332. Sequence switch 1110 moves into position 9 25 where the above described circuit is closed once more through the lower left-hand contact of spring 1138 and the sequence switch advances into position 10. By inspecting the several circuits leading to the contacts of 30 sequence switch springs 1138 and 1139 it will be found that they are all open in position 10 and hence the sequence switch comes to rest.

During the setting of the class sequence 35 switch 1110, relay 1400 is continually energized in parallel therewith and serves to hold up the advance of the sender sequence switch 1010 until the class sequence switch has been positioned. When the class sequence 40 switch no longer finds an energizing circuit, relay 1400 retracts its armatures and a circuit is established from battery through the winding of the sender sequence switch 1010, lower left-hand contact of spring 1034 45 (17+1), right-hand contacts of spring 1308 (10+11), conductor 1328, right-hand armature and contact of relay 1348, contact and left-hand armature of relay 1400 to ground. The sender sequence switch 1010 advances 50 out of position 1 and into position 2, where a circuit is established from battery through the winding of said sequence switch, lower right-hand contact of spring 1034 (2), upper right-hand contact of spring 1321 (10), to ground. Sequence switch 1010 immediately 55 moves into position 4.

Operation of the district selector switch.

In position 5 of the district sequence 60 switch 210 and position 4 of the sender sequence switch 1010 the fundamental circuit is established for controlling district brush selection. This circuit may be traced from battery through the right-hand winding of 65 relay 204, upper right-hand contact of spring 214 (5), lower left-hand contact of spring 224 (5+8), conductor 256, terminal 915, brush 922, contact and outer left-hand armature of relay 904, upper left-hand contact of spring 947 (4+8), lower right-hand contact 70 of said spring (8), brush 962, terminal 956, conductor 1047, lower left-hand contact of spring 1304 (10), conductor 1053, winding of the stepping relay 1000, contact and armature of counting relay 1006, lower left-hand contact of spring 1301 (10+12), upper right-hand contact of said spring (10), resistance 1045, lower left-hand contact of spring 1041 (4), upper right-hand contact 75 of said spring (2+6), to ground. Relay 204 80 energizes and closes a holding circuit for itself from battery, through its right-hand winding and contact and inner right-hand armature, lower left-hand contact of spring 214 (3+10), and thence to ground as described over the fundamental circuit. Relay 204 also completes a circuit from battery through the winding of the sequence switch magnet 210, lower left-hand contact of spring 211 (5), upper left-hand contact of 85 said spring (3+12), front contact and left-hand armature of relay 204 to ground through the contacts of spring 213. Sequence switch 210 moves into position 6 and the following circuit is established for the 90 up-drive power magnet 232: battery through the winding of said magnet, upper right-hand contact of spring 211 (6), upper left-hand contact of said spring (3+12), front 95 contact and left-hand armature of relay 204, 100 to ground through the contacts of spring 213. The power magnet 232 causes the upward movement of the brush shaft 235 for selecting the proper set of brushes.

The stepping relay 1000 which also energizes in the fundamental circuit closes a circuit from ground through the upper right-hand contact of spring 1019 (4), contact and armature of relay 1000, upper right-hand contact of spring 1018 (4), conductor 1059, 105 right-hand contact of spring 1322 (10), lower contact of spring 1030 (2+16), upper right-hand contact of spring 1029 (4), left-hand contact of spring 1132 of the routing switch 1120 which is standing in position 1 110 of this particular class of call, conductor 1143, left-hand armature and back contact of register relay 1412, outer right-hand armature and contact of relay 1401, conductor 1422, thence to conductor 1016 Fig. 10, armature and back contact of relay 1012, winding of relay 1013, upper left-hand contact 115 of spring 1023 (4), to battery. Relay 1013 becomes energized and closes a circuit through its winding and the winding of relay 1012 in series, contact and armature of relay 1013 to ground. Relay 1012, however, 120 cannot operate since its winding is shunted by the direct path to ground through the armature and contact of the stepping relay 125 130

1000. As the brush shaft 235 approaches the first brush tripping position, brush 240 encounters a metallic segment of commutator 236 and the following circuit is closed for 5 the relay 204: battery through the right-hand winding and contact and inner right-hand armature of said relay, lower left-hand contact of spring 214 (3+10), upper right-hand contact of spring 224 (5 $\frac{3}{4}$ +6), commutator 236, brush 240, to ground. This direct 10 circuit to ground shunts out the stepping relay 1000 in the fundamental circuit, which relay upon deenergizing opens the shunt around the winding of relay 1012. Relay 15 1012 thereupon operates and locks in series with relay 1013. As soon as brush 240 in its upward movement encounters the next insulating segment of commutator 236, relay 1000 operates and the stepping circuit is now 20 extended over the path above traced to conductor 1016, armature and front contact of counting relay 1012, armature and back contact of relay 1009, winding of relay 1011, upper left-hand contact of spring 1022 (4), 25 to battery. Relay 1011 operates and completes a circuit for itself in series with the winding of relay 1009, contact and armature of relay 1011 to ground. Relay 1009, however, being shunted by the stepping relay 30 1000 remains inactive. As brush 240 engages the next metallic segment of commutator 236, relay 1000 is shunted and relay 1009 operates in series with relay 1011. At the next energization of relay 1000, the stepping 35 circuit is extended by way of conductor 1016, armature and front contact of relay 1012, armature and front contact of relay 1009, conductor 1014, thence to conductor 1017, back contact and outer armature of relay 1005, winding of relay 1007, to battery. Relay 1007 operates and closes a circuit from 40 battery through its winding and thence through the winding of relays 1006 and 1008 in parallel, contact and armature of relay 1007, lower right-hand contact of spring 1019 (4), to ground. Upon the next shunting of the stepping relay 1000 relays 1006 and 1008 operate in series with relay 1007. Relay 1006 at its armature and contact 45 50 severs the fundamental circuit while relay 1008 closes a circuit from ground through its armature and contact, upper left-hand contact of spring 1034 (4), winding of sequence switch magnet 1010 to battery for driving this sequence switch out of position 4 and into position 6. Sequence switch 1010 in passing out of position 4 opens the holding circuits of the counting relays and they become deenergized. 55 60 As soon, following the opening of the fundamental circuit by relay 1006, as the brush 240 encounters the next insulating segment of the commutator 236, relay 204 becomes deenergized and completes a circuit as follows: battery through the winding of se- 65 quence switch magnet 210, upper contacts of spring 209 (6), back contact and left-hand armature of relay 204, to ground through the contacts of spring 213. Sequence switch 210 moves out of position 6 and into position 7. In position 7 a circuit is established from battery through the winding of the trip magnet 234, lower right-hand contact of spring 213 (7+8), upper right-hand contact of said spring (2+12), to ground. Trip 75 magnet 234 becomes energized preparatory to tripping the third set of brushes upon the next upward movement of the shaft 235. With sequence switch 210 in position 7 and the sender sequence switch in position 80 6, the fundamental circuit is again established from battery through the right-hand winding of relay 204, upper right-hand contact of spring 214 (7), thence as traced to ground at the contacts of sequence switch 85 spring 1041. Relay 204 operates and completes a holding circuit for itself as above described. Relay 204 also closes a circuit from battery through the winding of sequence switch magnet 210, lower left-hand 90 contact of spring 211 (7), upper left-hand contact of said spring (3+12), front contact and left-hand armature of relay 204 to ground through the contacts of spring 213. Sequence switch 210 moves into position 8 95 where the above traced circuit is again closed for the updrive power magnet 232. The stepping relay 1000 which also energizes in the fundamental circuit completes a circuit from ground through the upper left-hand contact of spring 1019 (6), armature and contact of relay 1000, lower contact of spring 1018 (6), conductor 1059, right-hand contact of spring 1322 (10), lower contact of spring 1030 (2+16), lower right-hand contact of spring 1029 (6), lower contact of spring 1131 (1), conductor 1144, left-hand armature and front contact of relay 1403, left-hand armature and back contact of relay 1413, right-hand armature and front contact of relay 1402, conductor 1423, thence to conductor 1058 Fig. 10, armature and back contact of counting relay 1060, winding of relay 1061, lower left-hand contact of spring 1023 (6), to battery. Relay 1061 operates 100 and closes a holding circuit from battery through its winding and the winding of relay 1060, contact and armature of relay 1061 to ground. Relay 1060, however, being shunted does not operate at this time. 105 As the brush shaft 235 approaches the first group selecting position brush engages a metallic segment of commutator 237 and the following circuit is closed for relay 204: battery through the right-hand winding and contact and inner right-hand armature of said relay, lower left-hand contact of spring 214 (3+10), lower right-hand contact of spring 224 (7 $\frac{3}{4}$ +8), commutator 237, brush 239, to ground. This direct path to ground 110 115 120 125 130

- shunts out the stepping relay 1000 of the fundamental circuit which opens the shunt around the winding of relay 1060, permitting this relay to operate in series with relay 1061. For each group selecting position passed over by the brush shaft an additional pair of counting relays are energized and locked until finally the relays 1007, 1006 and 1008 become energized. Relay 1006 opens the fundamental circuit while relay 1008 closes a circuit over its armature and contact and the upper left-hand contact of spring 1034 (6), for moving sequence switch 1010 into position 8. The energized counting relays are again released as sequence switch 1010 leaves position 6.
- As soon, following the opening of the fundamental circuit at the sender, as brush 239 engages an insulating segment of commutator 237, relay 204 deenergizes and opens the circuit of power magnet 232, causing the brush shaft to come to rest. Relay 204, furthermore, completes a circuit from battery through the winding of sequence switch magnet 210 upper contacts of spring 209 (8) back contact and left-hand armature of relay 204 to ground through the contacts of spring 213. Sequence switch 210 moves into position 9. In position 9 of sequence switch 210 a circuit is closed from battery through the right-hand winding of relay 204, upper right-hand contact of spring 214 (9+9 $\frac{1}{4}$), lower contact of spring 215 (9+9 $\frac{1}{4}$), to ground. Relay 204 becomes energized and locks up in the following circuit provided the first trunk in the group upon the terminals of which brushes 257, 258 and 259 are standing is busy: battery through the left-hand winding of relay 204, upper left-hand contact of spring 221 (9+10), front contact and outer right-hand armature of said relay, lower left-hand contact of spring 225 (1+12), lower right-hand contact of said spring (9+16 $\frac{1}{4}$), brush 259 to the grounded test terminal 246 of the busy trunk. Relay 204 completes a circuit from battery through the winding of sequence switch magnet 210, lower left-hand contact of spring 211 (9), upper left-hand contact of said spring (3+12), front contact and left-hand armature of relay 204, to ground to the contacts of spring 213, driving sequence switch 210 into position 10. The selected set of brushes 257, 258 and 259 are now driven upwardly over the selected group of terminals to search for an idle set thereof. The circuit of the up-drive power magnet 232 leads, as hereinbefore traced, through the contacts of sequence switch spring 211 and the front contact and left-hand armature of relay 204. Upon the test brush 259 reaching the test terminal of the first idle trunk, the energizing circuit of relay 204 is opened, but this relay remains operated for an instant longer by means of the following holding circuit:
- battery through the right-hand winding and contact and inner right-hand armature of said relay, lower left-hand contact of spring 214 (3+10), upper left-hand contact of spring 224 (10), commutator 238, brush 241, to ground. As the brushes 257, 258 and 259 are accurately centered on the terminals of the selected idle trunk, brush 241 encounters an insulating segment of commutator 238 and relay 204 releases its armatures to open the circuit of the up-drive power magnet 232, causing the switch to come to rest. Relay 204 also completes a circuit from battery through the winding of sequence switch magnet 210, upper contacts of spring 209 (10), back contact and left-hand armature of relay 204, through the contacts of spring 213, to ground, driving sequence switch 210 into position 11. Sequence switch 210 in position 11 closes the circuit for applying busy ground potential to the test terminal 246 of the selected trunk 247 248. This circuit may be traced from ground through the upper right-hand contact of spring 225 (10 $\frac{1}{4}$ +18), lower right-hand contact of said spring (9+16 $\frac{1}{4}$), brush 259 to the test terminal 246.
- Operation of office selector switch.*
- When sender sequence switch 1010 reaches position 8 a circuit is closed from battery through the winding of relay 1007, winding of relay 1008, right-hand contact of spring 1026 (8), conductor 1062, right-hand contacts of spring 1107 (9+11), conductor 1145, upper right-hand contact of spring 1321 (10), to ground. Relay 1008 becomes energized and closes a circuit from ground through its armature and contact of spring 1034 (8), winding of sequence switch 1010, to battery, driving said sequence switch out of position 8 into position 10. The fundamental circuit for controlling brush selection at the office selector is now established and may be traced from battery through the right-hand winding of relay 300, upper left-hand contact of spring 308 (1), left-hand contact of spring 306 (1+4), conductor 247, terminal 244, brush 257, upper right-hand contact of spring 215 (11), lower left-hand contact of spring 224 (11), conductor 256, thence as hereinbefore traced through the trunk selector and sender selector switches to conductor 1047, lower left-hand contact of spring 1304 (10), conductor 1053, winding of stepping relay 1000, contact and armature of relay 1006, lower left-hand contact of spring 1301 (10+12), upper right-hand contact of said spring (10), resistance 1045, lower contacts of spring 1041 (10), lower contact of spring 1105 (9+11), conductor 1148, lower right-hand contact of spring 1302 (10), conductor 1048, terminal 957, brush 963, right-hand armature and contact 130

of relay 906, lower right-hand contact of spring 944 (7+8), inner left-hand armature and contact of relay 904, brush 923, terminal 916, conductor 255, right-hand contact of spring 218 (11), brush 258, terminal 245, conductor 248, upper left-hand contact of spring 335 (1+4), lower right-hand contact of said spring (7+5), to ground. Relay 300 operates in this circuit and closes a holding circuit for itself from battery through its right-hand winding and front contact and inner right-hand armature, thence through its outer right-hand armature and contact, lower left-hand contact of spring 308 (1+4), left-hand contact of spring 306 (1+4), and thence over the fundamental circuit to ground as described. Relay 300 completes a circuit from battery through the winding of sequence switch 310, lower right-hand contact of spring 301 (1), front contact and left-hand armature of relay 300 to ground, driving sequence switch 310 out of position 1 into position 2.

In position 2 of the sequence switch a circuit is closed from battery through the up-drive power magnet 309, left-hand contacts of spring 302 (2), to ground at the front contact and left-hand armature of relay 300. Magnet 309 operates to cause the upward movement of the brush shaft 313 for selecting the proper set of brushes to be tripped. The stepping relay 1000, which also energizes in the fundamental circuit, completes a circuit from ground through the upper left-hand contact of spring 1019 (10), armature and contact of relay 1000, lower right-hand contact of spring 1018 (10), conductor 1059, thence as above traced through the lower contact of spring 1030, lower left-hand contact of spring 1029 (10), lower contact of spring 1130 (1), left-hand armature and back contact of register relay 1514, outer right-hand armature and contact of relay 1504, conductor 1522, lower right-hand contact of spring 1111 to conductor 1016 Fig. 10, armature and back contact of counting relay 1012, winding of counting relay 1013, upper left-hand contact of spring 1023 (10), to battery. Relay 1013 operates and closes a circuit for itself and relay 1012, but the latter relay remains deenergized since it is shunted out by the stepping relay 1000. As the brush shaft 313 approaches the first brush tripping position, commutator brush 324 encounters a metallic segment of commutator 327 and a circuit is closed as follows for shunting out the stepping relay 1000 in the fundamental circuit: battery through the right-hand winding and front contact and inner right-hand armature and outer right-hand armature and contact of relay 300, lower left-hand contact of spring 308 (1+4), lower right-hand contact of said spring (1 $\frac{1}{2}$ +2), commutator 327, brush 324, to ground. The stepping re-

lay 1000 becomes deenergized and opens the shunt to permit the energization of relay 1012 in series with relay 1013. For each brush tripping position passed by the brush shaft 313, an additional pair of counting relays are energized and locked until finally relays 1006, 1007 and 1008 are operated. Relay 1006 opens the fundamental circuit and relay 1008 closes the circuit hereinbefore traced for advancing the sender sequence switch 1010 out of position 10 and into position 12. 75

As soon, after the opening of the fundamental circuit at relay 1006, as the commutator brush 324 moves on to an insulating segment of commutator 327, relay 300 releases its armatures and opens the circuit of the up-drive power magnet 309. Relay 300 also closes a circuit from battery through the winding of sequence switch 310, lower left-hand contact of spring 301 (2), back contact and left-hand armature of relay 300 to ground, driving said sequence switch into position 3. In position 3 a circuit is closed from battery through the winding of the trip magnet 312, lower contact of spring 304 (3+7), to ground. The magnet 312 operates preparatory to tripping the selected set of brushes on the next upward movement of the brush shaft. 90

The fundamental circuit is closed again for group selection and corresponds precisely to the circuit previously traced for the brush selection operation. Relay 300 becomes energized and locks through its right-hand winding and right-hand armatures, and also closes a circuit from battery through the winding of sequence switch 310, lower right-hand contact of spring 301 (3), to ground at the front contact and left-hand armature of relay 300, driving sequence switch 310 out of position 3 and into position 4. The updrive power magnet 309 is energized once more in the circuit previously traced and the brush shaft 330 moves upwardly to select the proper group of terminals. 105 110

When the sender sequence switch 1010 reaches position 12 a circuit is closed from battery through the winding of relay 1005, upper left-hand contact of spring 1027 (17+13), lower left-hand contact of said spring (11+12), conductor 1063, spring 1139 (1), contact and inner right-hand armature of register relay 1410, conductor 1064, upper right-hand contact of spring 1319 (10), to ground. 115 120

The stepping relay 1000 also energizes in the fundamental circuit and prepares a circuit from ground through the upper right-hand contact of spring 1019 (12), contact and armature of relay 1000, upper right-hand contact of spring 1018 (12), thence over conductor 1059 to the lower contact of 125 130

spring 1030 (2+16), upper contact of said spring (12), lower contact of spring 1129 (1), left-hand armature and back contact of register relay 1505, outer right-hand 5 armature and contact of relay 1506, conductor 1523, thence to conductor 1016 Fig. 10, armature and back contact of relay 1012, winding of relay 1013, through the upper left-hand contact of spring 1023 (12), to 10 battery. Relay 1013 operates as before described and prepares a locking circuit for itself and the counting relay 1012.

In its upward movement the commutator brush 323 encounters a metallic segment of 15 commutator 328 for each group of trunk terminals passed over and closes a circuit as follows for shunting out the stepping relay 1000 in the fundamental circuit: battery through the right-hand winding and 20 front contact and inner left-hand armature and outer right-hand armature and contact of relay 300, lower left-hand contact of spring 308 (1+4) upper right-hand contact of said spring (3 $\frac{3}{4}$ +4), commutator 25 328, brush 323, to ground. For each group of trunks passed over, a pair of counting relays are operated and locked until finally the relays 1009 and 1011 are energized. Since relay 1005 is energized at this time 30 the stepping circuit is now extended through the armature and front contact of relay 1009, conductor 1014, thence to conductor 1017, inner armature and contact of relay 1005, armature and back contact of 35 relay 1065, winding of relay 1066, lower left-hand contact of spring 1023, to battery. Relay 1066 operates and closes a series holding circuit for itself and relay 1065, but relay 1065 does not operate since it is shunted 40 out by the stepping relay 1000. Hence, the brush shaft 313 continues its upward movement until all of the counting relays in the second group are operated and relay 1067 finally attracts its armature. The operation of relay 1067 extends the stepping 45 circuit over its armature and front contact, front contact and outer armature of relay 1005 and thence through the winding of relay 1007. Upon the next deenergization of 50 stepping relay 1000, relays 1006 and 1008 operate and the fundamental circuit is opened. Relay 1006 opens the fundamental circuit and relay 1008 closes the circuit hereinbefore traced for advancing sender 55 sequence switch 1010 out of position 12 and into position 14.

Following the opening of the fundamental circuit by relay 1006 the brush 323 moves on an insulating portion of commutator 328 60 and relay 300 becomes deenergized to open the circuit of power magnet 309, causing the brush shaft to come to rest with the selected set of brushes 314, 315 and 316 on the first set of terminals of the selected group. 65 Relay 300 also closes a circuit over its left-

hand armature and back contact for moving sequence switch 310 out of position 4 and into position 5.

In position 5 of sequence switch 310 a circuit is closed from battery through the left-hand winding of relay 300, upper right-hand and lower left-hand contacts of sequence switch spring 303 to ground. Relay 300 becomes energized and locks in the following circuit provided the first trunk 331, 70 332 in the group of trunks leading to the called mechanical office is busy: battery through the right-hand winding, front contact and inner right-hand armature of relay 300, outer right-hand armature and contact of said relay, lower right-hand contact of spring 305 (5+18), upper left-hand contact of said spring (5+6 $\frac{1}{2}$), test brush 316 to the grounded test terminal 319 of the busy trunk. Relay 300 also closes a circuit from 75 battery through the winding of sequence switch magnet 310, lower right-hand contact of spring 301 (5), front contact and left-hand armature of relay 300, to ground, driving sequence switch 310 out of position 80 5 and into position 6. Since the trunk is busy, relay 300 remains energized in position 6 and in so doing closes the above traced circuit for the up-drive power magnet 309 causing the selected set of brushes 314, 315 85 and 316 to be advanced over the terminals of the selected group to search for an idle trunk. When the first idle trunk is reached the operating circuit of relay 300 is opened, but this relay remains energized for an instant longer by means of a holding circuit from battery through its left-hand winding and upper contacts of sequence switch spring 303, commutator 329, brush 325 to ground. As soon as the brushes are 90 accurately centered on the terminals of the selected trunk the holding circuit is opened, and relay 300 becomes deenergized to open the circuit of the up-drive power magnet 309, terminating the upward movement of 100 105 the switch. Relay 300 also completes a circuit over its back contact and left-hand armature and sequence switch contact 301 for driving sequence switch 310 out of position 110 115 6 and into position 7.

In position 7 a circuit is closed through the left-hand winding of relay 300, upper right and lower left-hand contacts of spring 303 to ground, causing the energization of relay 300, which in turn, closes a circuit from battery through the magnet of sequence switch 310, lower right-hand contact of spring 301 (7), front contact and left-hand armature of relay 300 to ground. Sequence switch 310 moves out of position 7 and into 120 position 8. Relay 300 remains energized by means of the holding circuit from battery through its front contact and inner right-hand armature, outer right-hand armature and contact of said relay, lower 125 130

right-hand contact of spring 305 (5+18), conductor 249 and thence to the grounded test terminal 246. The selected trunk 331, 332 leading to the distant mechanical office is 5 rendered busy by means of the circuit from ground through the right-hand contact of spring 304 (6 $\frac{3}{4}$ +8 $\frac{1}{4}$), brush 316 to the test terminal 319.

10 *Operation of the incoming selector switch.*

With sequence switch 1010 in position 14 a circuit is closed from battery through the winding of sequence switch magnet 1310, upper left-hand contact of spring 1307 14 (10), lower left-hand contact of spring 1039 (14), to ground. Sequence switch 1310 moves into position 11. A circuit is now closed for advancing the sender sequence switch and may be traced from battery 20 through the left-hand winding of relay 400 Fig. 4, lower left-hand contact of spring 429 (1), upper right-hand contact of said spring (1+4), resistance 409, conductor 331, terminal 317, brush 314, upper contacts of 25 spring 306 (8), conductor 247, thence over the fundamental circuit as previously traced to conductor 1047, upper right-hand contact of spring 1304 (11), lower contact of spring 1020 (14+14 $\frac{3}{4}$), winding of relay 1001, 30 upper right-hand contact of spring 1055 (14+17), resistances 1054 and 1035, conductor 1068, conductor 1147, lower contact of spring 1042 (14+14 $\frac{3}{4}$), upper left-hand contact of spring 1302 (11), conductor 1048, 35 thence over the other side of the fundamental circuit to conductor 248, upper contacts of spring 307 (8), brush 315, terminal 318, conductor 332, resistance 411, lower contacts of spring 407 (1+8), to ground. Relay 1001 operates, but relay 400 does not receive sufficient current to energize in series with resistances 1054 and 1035. Relay 1001 closes a circuit from battery through the winding of relay 1003 to ground through the 40 contact and armature of relay 1001. It also completes a circuit from battery through the lower right and upper left-hand contacts of spring 1032, winding of relay 1002, to ground at the contact and armature of 45 relay 1001. Relays 1002 and 1003 become energized and a circuit is established from battery through the winding of sequence switch magnet 1010, upper right-hand contact of spring 1034 (14+17), upper right-hand contact of spring 1106 (10), conductor 1166 contact and outer right-hand armature of relay 1003 to ground. Sequence switch 50 1010 moves from position 14 through positions 15 and 16 and into position 1, and relays 1001, 1002 and 1003 become deenergized. In position 1 of said sequence switch a circuit is closed from battery through the winding of its magnet, lower left-hand contact of spring 1034 (17+1), right-hand contacts of spring 1308 (10+11), conductor 55

1328, right-hand armature and contact of relay 1348 to ground at the contact and left-hand armature of relay 1400. Sequence switch 1010 thereupon moves into position 2. Sequence switch 1310 is next driven from 70 position 11 into position 12 by means of the following circuit: battery through the winding of the magnet of said switch, upper right-hand contact of spring 1307 (11), lower right-hand contact of spring 1039 (2), 75 to ground.

The fundamental circuit is established for controlling brush selection at the incoming switch and may be traced as above described through the left-hand winding of relay 400 80 and over conductor 331 to conductor 1047, lower left-hand contact of spring 1304 (12), conductor 1053, winding of the stepping relay 1000, contact and armature of relay 1006, lower left-hand contact of spring 1301 85 (10+12), lower right-hand contact of said spring (11+12), left-hand winding of relay 1004, right-hand contacts of spring 1036 (2), upper left-hand contact of spring 1105 (10), conductor 1148, lower right-hand contact of spring 1302 (12), conductor 1048, thence over the other side of the fundamental circuit to ground at the lower contacts of spring 407. Due to the low resistance of 90 this circuit relay 400 becomes energized and locks in a circuit from battery through its left-hand winding, upper left-hand contact of spring 423 (1+8), front contact and inner right-hand armature of said relay, 95 right-hand contacts of spring 429 (1+4), thence over the fundamental circuit to ground. Relay 400 closes a circuit from battery through the winding of sequence switch 410, lower left-hand contact of spring 422 (1), to ground at the front contact and outer armature of relay 400, driving the sequence switch into position 2. In position 2 a circuit is closed from battery through the winding of the up-drive power magnet 425, lower right-hand contact of spring 421 (2), lower left-hand contact of said spring (1 $\frac{1}{4}$ +6), front contact and outer armature of relay 400 to ground. Magnet 425 causes 100 the upward movement of brush shaft 428. 110

It will be noted that the left-hand winding of relay 1004 is included in the fundamental circuit. At the same time a circuit is closed from battery through the right-hand winding of said relay, resistance 1038, upper right-hand contact of spring 1039 (2+18), 115 to ground. Relay 1004 is constructed to be both polarized and differential. With both windings energized and with the current flowing in the direction described through the left-hand winding, the resultant magnetic flux is insufficient to cause the attraction of the armature. Consequently, this relay remains inactive at the present time. 120

The stepping relay 1000, which energizes with relay 400 in the fundamental circuit, 125 130

- completes a circuit from ground through the upper left-hand contact of spring 1019 (2), armature and contact of relay 1000, lower right-hand contact of spring 1018 (2), 5 conductor 1059, left-hand contact of spring 1322 (12), lower left-hand contact of spring 1032 (18+12), upper right-hand contact of spring 1031 (2), conductor 1069, left-hand armature and front contact of register relay 1012, left-hand armature and front contact 10 1511, outer left-hand armature and back contact of relay 1515, conductor 1524, thence to conductor 1015 Fig. 10, armature and back contact of counting relay 1009, 15 winding of relay 1011, upper left-hand contact of spring 1022 (2), to battery. Relay 1011 operates and prepares a circuit for itself and relay 1009. As the brush shaft 428 approaches the first brush tripping position, brush 443 engages a metallic segment of commutator 446 and the following circuit is momentarily closed to shunt the stepping relay 1000: battery through the left-hand winding of relay 400, upper left-hand contact of spring 423 (1+8), upper right-hand contact of said spring (1 $\frac{1}{4}$ +2), commutator 446, brush 443, upper right-hand contact of spring 421 (1+2), lower left-hand contact of said spring (1 $\frac{1}{4}$ +6), front 20 contact and outer armature of relay 400 to ground. When the brush shaft reaches the next brush tripping position relays 1006, 1007 and 1008 are operated in a manner already described and the fundamental circuit is opened at the sender. Relay 1008 completes a circuit from ground through its armature and contact, upper left-hand contact of spring 1034 (2), winding of sequence switch magnet 1010 to battery and ground, 25 driving the sequence switch into position 4. As soon, after the fundamental circuit is opened at the sender, as brush 443 passes onto an insulating segment of the commutator 446, relay 400 retracts its armatures and opens the circuit of the power magnet 425. It also closes a circuit from battery through the winding of sequence switch magnet 410, upper left-hand contact of spring 422 (2), back contact and outer 30 armature of relay 400 to ground, driving said sequence switch into position 3. With sequence switch 410 in position 3 and the sender sequence switch in position 4 the fundamental circuit is established once 35 more and relays 400 and 1000 become energized. Relay 400 locks in the fundamental circuit and also completes a circuit from battery through the winding of sequence switch magnet 410, lower left-hand contact of spring 422 (3), front contact and outer armature of relay 400 to ground. Sequence switch 410 advances into position 4, where the circuit of the up-drive power magnet 425 is again closed and the brush shaft 428 resumes its upward movement. In positions 35
- and 4 of the sequence switch 410 a circuit is established from battery through the winding of trip magnet 427, left-hand contacts of spring 419 (3+4), to ground. The trip magnet 427 energizes and rotates the trip spindle whereby the selected set of brushes 433, 434 and 435 are tripped when the brush shaft resumes its upward movement in the group selection operation. 70
- Stepping relay 1000, upon energizing, 75 closes a circuit from ground through the upper right-hand contact of spring 1019 (4), armature and contact of said relay, upper contact of spring 1018 (4), conductor 1059, thence through the lower left-hand contact of spring 1032, lower left-hand contact of spring 1031 (4), conductor 1070, left-hand armature and back contact of relay 1418, outer right-hand armature and back contact of relay 1417, conductor 1424, thence to conductor 1017 Fig. 10 and back contact and outer armature of relay 1005, winding of relay 1007 to battery. Relay 1007 operates and prepares circuits for relays 1006 and 1008. As soon as the tripped set of brushes reaches the first group of terminals, brush 442 encounters a metallic segment of commutator 445 and a circuit is closed from battery through the left-hand winding of relay 400, upper left-hand contact of spring 423 (1+8), front contact and inner armature of relay 400, right-hand contacts of spring 429 (1+4), upper left-hand contact of spring 406 (3+4), upper right-hand contact of said spring (3 $\frac{1}{2}$ +4), commutator 445, brush 442 and thence to ground as above traced through the front contact and outer armature of relay 400. This circuit shunts out the stepping relay 1000, which deenergizes, and permits the operation of relays 1006 90 and 1008. Relay 1006 opens the fundamental circuit while relay 1008 operates to advance the sequence switch 1010 out of position 4 and into position 6 in the manner already well understood. 95
- As soon, after the interruption of the fundamental circuit at the sender, as brush 442 moves off the metallic segment of commutator 445, the circuit of relay 400 is opened and this relay retracts its armatures 100 to open the circuit of power magnet 425. Also, a circuit is closed from battery through the winding of sequence switch magnet 410, upper left-hand contact of spring 422 (4), back contact and outer armature of relay 400 to ground, driving said sequence switch 110 out of position 4 and into position 5. 115
- In position 5 of sequence switch 410 the relay 400 is immediately energized in a circuit from battery through its right-hand winding, upper right-hand contact of spring 432 (5+6), lower left-hand contact of said spring (5+5 $\frac{1}{4}$), to ground. Relay 400 operates and locks in the following circuit, provided the first trunk in the group, upon the 120 125 130

terminals of which the brushes 433, 434 and 435 are now resting, is busy: battery through the left-hand winding of relay 400, upper left-hand contact of spring 423 5 (1+8), front contact and inner armature of relay 400, upper right-hand contact of spring 419 (5+7), lower right-hand contact of said spring (5+18), brush 435 to the grounded test terminal 438 of the busy 10 trunk. Relay 400 establishes a circuit from battery through the winding of sequence switch magnet 410, lower left-hand contact of spring 422 (5), front contact and outer armature of relay 400 to ground, driving 15 the sequence switch into position 6. The brushes 433, 434 and 435 are now driven upwardly over the terminals of the selected group of trunks to search for an idle one therein. The power circuit for the up-drive 20 magnet 425 is closed in the manner hereinbefore explained. Upon reaching the first idle trunk of the group the circuit of relay 400 is opened, but this relay remains momentarily energized by means of a holding circuit, traceable from battery through the right-hand winding of said relay, upper right-hand contact of spring 432 (5+6), lower right-hand contact of said spring (6), commutator 447, brush 444 and thence to 25 ground through the outer armature and front contact of relay 400. When the brushes 433, 434 and 435 are accurately centered on the terminals 436, 437 and 438 of the idle trunk, brush 444 rests on an insulating segment of the commutator 447 and the holding circuit for relay 400 is opened. This relay now deenergizes and opens the power circuit, causing the brush shaft 428 to cease its upward movement. Relay 400, 30 furthermore, closes a circuit from battery through the winding of sequence switch magnet 410, upper left-hand contact of spring 422, to ground through the back contact and outer armature of said relay, where- 35 by the sequence switch 410 advances into position 7. The selected trunk is rendered busy by means of a circuit from ground through the upper left-hand contact of spring 419 (6 $\frac{3}{4}$ +16 $\frac{1}{4}$), lower right-hand contact of said spring (5+18), brush 435 and thence to the 40 multiples of test terminal 438. Relay 400 is again energized by means of a circuit from battery through its left-hand winding, lower contacts of spring 429 (7), upper 45 right-hand contact of spring 419 (5+7), upper left-hand contact of said spring (6 $\frac{3}{4}$ +16 $\frac{1}{4}$), to ground. Relay 400 closes a circuit from battery through the winding of sequence switch magnet 410, lower left-hand 50 contact of spring 422 (7), front contact and outer armature of relay 400 to ground, driving the sequence switch out of position 7 and into position 8. Relay 400 remains energized in position 8 by means of a circuit from battery through its left-hand winding, 55

upper left-hand contact of spring 423 (1+8), front contact and inner armature of relay 400, lower right-hand contact of spring 417 (7+8), brush 434, terminal 437, conductor 440, upper left-hand contact of spring 507 (17+15), lower right-hand contact of said spring (1+8 $\frac{1}{2}$), lower left-hand contact of spring 519 (1+8 $\frac{1}{2}$), to ground. As will be observed hereinafter relay 400 remains operated in this circuit until the final 75 selector sequence switch 510 leaves position 8 $\frac{1}{2}$ following the completion of units selection.

Operation of the final selector switch.

80

The apparatus is now in condition to effect brush selection at the final switch, and accordingly, the fundamental circuit is established as follows: battery through the right-hand winding of relay 540, lower left-hand contact of spring 505 (1), lower left-hand contact of spring 506 (15+6), conductor 439, terminal 436, brush 433, lower right-hand contact of spring 416 (10+8), upper right-hand contact of said spring 90 (8+9), resistance 409, conductor 331, thence over the fundamental circuit to conductor 1047, lower left-hand contact of spring 1304 (12), conductor 1053, winding of relay 1000, contact and armature of relay 1006, lower 95 left-hand contact of spring 1301 (10+12), lower right-hand contact of said spring (11+12), through the left-hand winding of relay 1004, right-hand contacts of spring 1036 (6), upper left-hand contact of spring 100 100 (10), conductor 1148, lower right-hand contact of spring 1302 (12), conductor 1048, thence over the other side of the fundamental circuit as traced to ground through the lower contacts of spring 407 (1+8). Relays 105 540 and 1000 operate, but due to the direction of the flow of current the relay 1004 remains inactive. Relay 540 locks in a circuit from battery through its right-hand winding, lower right-hand contact of 110 spring 514 (15+10), front contact and right-hand armature of relay 540, lower right-hand contact of spring 505 (1+6) lower left-hand contact of spring 506 (15+6), and thence to ground over the 115 fundamental circuit. Relay 540 closes a circuit from battery through the left-hand winding of relay 501, upper left-hand contact of spring 517 (1), front contact and left-hand armature of relay 540, upper 120 contact of spring 512 (1+11), to ground. Relay 501 becomes energized and locks in a circuit from battery through its left-hand winding, armature and contact of relay 503, front contact and left-hand armature of relay 501, conductor 441 to the grounded test terminal 438. Relay 501 establishes a circuit from battery through the winding of sequence switch magnet 510, lower contacts 125 of spring 511 (1), front contact and right- 130

hand armature of relay 501 to ground, driving sequence switch 510 from position 1 into position 2. In position 2 of the sequence switch a circuit is closed for the high-speed 5 up-drive power magnet 520, traceable from battery through the winding of said magnet, upper right-hand contact of spring 518 (2), front contact and left-hand armature of relay 540, upper contact of spring 512 (1+11), 10 to ground. The magnet 520 causes the brush shaft 524 to be moved upwardly at a high rate of speed.

The stepping relay 1000, upon energizing in the fundamental circuit, closes a circuit 15 from ground through the upper left-hand contact of spring 1019 (6), armature and contact of said relay, lower contact of spring 1018 (6), conductor 1059, and thence as traced through the lower left-hand contact 20 of spring 1032, lower right-hand contact of spring 1031 (6), conductor 1071, left-hand armature and front contact of register relay 1510, left-hand armature and back contact of relay 1509, right-hand armature and 25 front contact of relay 1508, conductor 1528, thence to conductor 1058 Fig. 10, armature and back contact of relay 1060, winding of relay 1061, lower left-hand contact of spring 1023 (6), to battery. Relay 1061 operates 30 and prepares a circuit for itself and relay 1060.

As the brush shaft 524 of the final selector approaches each brush tripping position the brush 532 encounters a metallic segment of 35 commutator 535 and a circuit is closed as follows in shunt of the stepping relay 1000 in the fundamental circuit: battery through the right-hand winding of relay 540, lower right-hand contact of spring 514 (15+10), front contact and right-hand armature of 40 relay 540, lower right-hand contact of spring 505 (1+6), upper right-hand contact of spring 506 (1 $\frac{1}{4}$ +2), commutator 535, brush 532, upper right-hand contact of spring 517 (1 $\frac{1}{4}$ +2), front contact and left-hand armature of relay 540 to ground at spring 512. When the brush shaft has reached the position 45 for tripping the proper set of brushes, counting relays 1006, 1007 and 1008 become energized. Relay 1006 opens the fundamental 50 circuit and relay 1008 closes the circuit for driving sequence switch 1010 out of position 6 and into position 8.

Immediately following the opening of the 55 fundamental circuit at relay 1006, brush 532 moves onto an insulating segment of commutator 535 and relay 540 retracts its armatures to open the circuit of the high speed magnet 520. Relay 540 also closes a circuit 60 from battery through the winding of sequence switch magnet 510, upper right-hand contact of spring 513 (2), back contact and left-hand armature of relay 540 to ground at spring 512. Sequence switch 510 moves 65 out of position 2 and into position 3 where

a circuit is closed for the trip magnet 522 traceable from battery through the winding of said magnet, lower right-hand contact of spring 519 to ground. Magnet 522 operates preparatory to tripping the chosen set of 70 brushes on the next upward movement of the shaft 524.

With sequence switch 510 in position 3 and sequence switch 1010 in position 8 the fundamental circuit is closed once more for 75 controlling group or tens selection at the final switch. Relay 540 operates and prepares the already described holding circuit for itself and also closes a circuit from battery through the winding of sequence 80 switch magnet 510, lower right-hand contact of spring 513 (3), front contact and left-hand armature of relay 540 to ground through the upper contact of spring 512. Sequence switch 510 is driven out of position 85 3 and into position 4. In position 4 the above traced circuit is again established for the high speed up-drive power magnet 520 and the brush shaft 524 resumes its upward movement.

The stepping relay 1000, energizing in the fundamental circuit, closes a circuit from ground through the upper right-hand contact of spring 1019 (8), contact and armature of relay 1000, upper contact of 90 spring 1018 (8), thence over conductor 1059, through the lower left-hand contact of spring 1032, upper left-hand contact of spring 1031 (8), conductor 1074, left-hand armature and front contact of register relay 1408, left-hand armature and back contact of relay 1407, right-hand armature and contact of relay 1415, conductor 1425, thence to conductor 1058 Fig. 10, armature and back contact of relay 1060, winding of relay 1061 to battery. Relay 1061 operates 100 and prepares a series circuit for itself and relay 1060. For each group of ten terminals passed over by the brushes 525, 526 and 527 a momentary circuit is closed as follows 105 to shunt the stepping relay 1000 in the fundamental circuit: battery through the right-hand winding of relay 540, lower right-hand contact of spring 514 (15+10), front contact and right-hand armature of 110 relay 540, lower right-hand contact of spring 505 (1+6), upper right-hand contact of said spring (3 $\frac{3}{4}$ +4), commutator 536, brush 531, upper right-hand contact of spring 517 (3 $\frac{3}{4}$ +4), front contact and left-hand armature of relay 540, to ground through the spring 512. After the stepping relay 1000 has been shunted the proper 115 number of times the last relays 1006, 1007 and 1008 are operated. Relay 1006 severs the fundamental circuit and relay 1008 closes a circuit for driving the sequence switch 1010 out of position 8 and into position 10.

As soon, following the opening of the 120

fundamental circuit at the sender, as brush 531 engages an insulated segment of commutator 536, relay 540 releases its armatures and opens the circuit of the high speed 5 magnet 520. Relay 540 in addition completes a circuit from battery through the winding of sequence switch magnet 510, upper right-hand contact of spring 513 (4), back contact and left-hand armature of relay 540 to ground through the sequence switch spring 512. Sequence switch 510 moves into position 5.

In position 5 of the sequence switch 510 and position 10 of sequence switch 1010, 15 the final closure of the fundamental circuit is effected to control the units selective movement of the switch. Relay 540, in the manner explained operates and locks up through its right-hand winding and 20 right-hand armature and front contact in the fundamental circuit and also closes the circuit already traced for advancing sequence switch 510 out of position 5 and into position 6. In position 6 the low speed 25 up-drive power magnet 521 is energized in a circuit from battery through the winding of said magnet, lower left-hand contact of spring 517 (6), front contact and left-hand armature of relay 540 to ground 30 through the spring 512. Magnet 521 causes the brush shaft 524 to move over the selected group of ten terminals at a comparatively low rate of speed.

The stepping relay 1000, upon energizing 35 in the fundamental circuit in series with relay 540, closes a circuit from ground through the upper left-hand contact of spring 1019 (10), armature and contact of said relay, lower contact of spring 1018 (10), 40 thence over conductor 1059 through the lower left-hand contact of spring 1032 (18 + 12), upper right-hand contact of spring 1032 (10), conductor 1075, left-hand armature and front contact of register relay 1406, 45 left-hand armature and front contact of relay 1405, outer left-hand armature and front contact of relay 1404, conductor 1426, thence to conductor 1057 Fig. 10, armature and back contact of counting relay 1072, 50 winding of relay 1073 to battery. Relay 1073 energizes and prepares a circuit for itself and relay 1072, the latter relay remaining deenergized due to the shunt through the armature and contact of the stepping relay 55 1000. For each set of terminals passed over by the brushes 525, 526 and 527, the relay 1000 is shunted and deenergized and a pair of counting relays are energized and locked until finally the counting relays 1006, 1007 60 and 1008 are actuated. Relay 1006 opens the fundamental circuit while relay 1008 closes a circuit for driving sequence switch 1010 out of position 10 and into position 12. The brushes 525, 526 and 527 thus reach 65 the terminals 528, 529 and 538 of the called

subscriber's line 500. Although the fundamental circuit is opened by the counting relay 1006, relay 540 remains energized for an instant in a circuit from battery through its right-hand winding, lower right-hand contact of spring 514 (15 + 10), front contact and right-hand armature of relay 540, lower right-hand contact of spring 505 (1 + 6), upper right-hand contact of spring 506 (5 $\frac{1}{4}$ + 6), commutator 535, brush 532 70 and thence as hereinbefore traced to ground at the upper left-hand contact of spring 512. As the brushes 525, 526, and 527 become accurately centered on the terminals of the called line, the circuit through the commutator brush 532 is opened and relay 540 deenergizes to open the circuit of the up-drive power magnet 521, causing the brush shaft to cease its upward movement. Relay 540 also closes a circuit from battery 75 through the winding of sequence switch magnet 510, upper right-hand contact of spring 513 (6), back contact and left-hand armature of relay 540, upper contact of spring 512 (1 + 11), to ground, driving 80 the sequence switch out of position 6.

Restoration of the sender, the sender selector and the trunk selector.

In position 12 of the sender sequence 85 switch 1010 a circuit is established from battery through the left-hand winding of relay 903, upper contact of sequence switch spring 936 (8), brush 965, terminal 959, conductor 1050, upper left-hand contact of 90 sequence switch spring 1325 (5 $\frac{1}{4}$ + 12), lower right-hand contact of spring 1324 (12), lower left-hand contact of spring 1019 (12), to ground. Relay 903 becomes energized and closes a circuit from ground 100 through its inner right-hand armature and front contact, upper right-hand contact of spring 941 (8), winding of sequence switch magnet 910, to battery, driving said sequence switch out of position 8 and into position 105 9. Upon leaving position 8 sequence switch 910 opens at the upper left-hand contact of spring 945, the circuit which up to this time has been maintaining the energization 110 of relay 1300. Relay 1300 releases and closes 115 a circuit from battery through the winding of sequence switch magnet 1310, lower right-hand contact of spring 1307 (2 + 17), back contact and right-hand armature of relay 1300 to ground, driving sequence switch 1310 120 out of position 12 and into position 18. Immediately that sequence switch 1310 reaches position 13, it closes a circuit from battery through the winding of the sender sequence switch magnet 1010, lower left-hand contact 125 of spring 1033 (2 + 18), upper left-hand contact of spring 1309 (13 + 18), to ground. The sender sequence switch 1010 leaves position 12 and advances through positions 14, 15 and 16 and into its normal position 130

1. With the sender sequence switch 1010 in position 1 a circuit is closed from battery through the winding of sequence switch magnet 1310, upper contacts of sequence switch spring 1306 (18), left-hand contacts of spring 1036 (1), conductor 1076, lower right and upper left-hand contacts of sequence switch spring 1221 (1), lower left-hand contact of sequence switch spring 1125 (1), to ground. Sequence switch 1310 thereupon moves out of position 18 and into position 1.

At the time the control sequence switch 1310 leaves position 12 it opens the several contacts of sequence switch springs 1309, 1321 and 1319 in order to permit the deenergization of the several register relays which have been operated to give record of the designation.

20 Sequence switch 910 on leaving position 8 closes a circuit from battery through the right-hand winding of relay 204 Fig. 2, lower right-hand contact of sequence switch spring 203 (11+12), lower left-hand contact of said spring (11), conductor 253, terminal 918, brush 925, front contact and inner right-hand armature of relay 904, winding of relay 905, lower contacts of sequence switch spring 949, to ground. Relay 204 25 operates and closes a circuit from battery through the winding of sequence switch magnet 210, lower left-hand contact of spring 211 (11), upper left-hand contact of said spring (3+12), front contact and left-hand armature of relay 204, lower left-hand contact of spring 313 (1+17), upper right-hand contact of said spring (2+12), to ground, moving sequence switch 210 into position 12. From position 12 the district 30 sequence switch 210 depends for its further advance upon the condition of the trunk circuit 115, 116 at the originating office. If the operator at the originating office has already inserted plug 105 of her cord circuit 35 in the jack 106, relay 114 is energized and the circuit previously traced is completed for the energization of relay 200. Consequently, relay 201 is energized and when the sequence switch 210 arrives in position 12 a 40 circuit is closed for relay 204 as follows: battery through the right-hand winding of said relay, lower right-hand contact of spring 203 (11+12), upper right-hand contact of said spring (12), front contact and armature of relay 201 to ground. Relay 204 45 operates and closes a circuit from battery through the winding of sequence switch magnet 210, lower left-hand contact of spring 211 (12), upper left-hand contact of said spring (3+12), front contact and left-hand armature of relay 204, to ground through the contacts of spring 203. Sequence switch 210 moves out of position 12 and into position 13. At the time the sequence switch 50 left position 11 the circuit for the flashing

of lamp 231 is opened at the lower left-hand contact of spring 223. The cessation of the signal 231 notifies the operator at the tandem switching office that all selections have been completed. In position 13 of sequence 55 switch 210 a circuit is closed from battery through the lamp 231, upper right-hand contact of spring 223 (12+18), outer right-hand armature and back contact of relay 204, upper left-hand contact of spring 222 (13+16), upper right-hand contact of said spring (2 $\frac{3}{4}$ +16), to ground. Lamp 231 burns steadily in this circuit.

As sequence switch 210 moves away from position 12 $\frac{1}{2}$ it opens at the upper right-hand contact of sequence switch spring 212

the holding circuit of relay 901. Relay 901 opens the circuit of relay 904 and this latter relay retracts its armatures. A circuit is then completed from battery through the winding of sequence switch magnet 910, lower left-hand contact of spring 948 (4+16), lower right-hand contact of said spring (2+14), back contact and outer right-hand armature of relay 904 to ground, driving sequence switch 910 out of position 9 into position 15. In position 15 both the trunk selector 920 and the sender selector 940 commence to restore to their normal positions. The circuit for the down-drive power magnet 913 of the trunk selector may be traced from battery through the winding of said magnet, lower contacts of spring 933 (15), to ground. The circuit for the down-drive power magnet 954 of the sender selector is traceable from battery through the winding of said magnet, lower right-hand contact and upper left-hand contact of sequence switch spring 942 (15+16), back contact and inner right-hand armature of relay 903 to ground. As soon as the trunk selector switch 920 is fully restored to its normal position a circuit is closed from battery through the winding of sequence switch magnet 910, left-hand contacts of sequence switch spring 948, normal position segment 931, brush 929 to ground. Sequence switch 910 advances into position 16. If the sender selector is already restored, or as soon as it does reach its normal position a circuit is established from battery through the right-hand winding of relay 903, spring 986 (15+16), normal position segment 971, brush 970 to ground. Relay 903 becomes energized and closes a circuit from ground through its inner right-hand armature and front contact, upper right-hand contact of sequence switch spring 941 (16), winding of sequence switch magnet 910, to battery, driving the sequence switch out of position 16 and into position 18 where it awaits allotment by the allotter switch 980. All apparatus used for associating the operator's keyboard and the register sender with the trunk circuit at the operator's position has 130

now been completely restored to its normal condition.

Testing and ringing on the called subscriber's line.

When the final selector sequence switch 510 leaves position 6 it moves forward into position 9 and on reaching position $8\frac{3}{4}$ the following circuit is closed: battery through 10 the right-hand winding of relay 540, lower right-hand contact of spring 514 (15+10), upper right-hand contact of said spring (8 $\frac{3}{4}$ +9), front contact and right-hand armature of relay 501 to ground. Sequence 15 switch 510 thereupon moves into position 12 which is the talking position.

At the time sequence switch 510 leaves position $8\frac{1}{2}$, the circuit hereinbefore traced for relay 400 at the incoming selector switch 75 is opened, and this relay becomes deenergized. A circuit is closed from battery through the winding of sequence switch magnet 410, upper left-hand contact of spring 422 (8), back contact and outer armature of relay 400 to ground, moving sequence switch 410 out of position 8 into position 10. Since the trunk is closed at the originating office and since the district selector switch has advanced to its talking position, position 13, a circuit is established from battery through the right-hand winding of relay 404, normal contacts at the outer right-hand armature of relay 402, upper left-hand winding of repeating coil 408, lower right-hand contact of spring 406 (10+18), lower left-hand contact of said spring (10+16), conductor 331, thence over the upper side of the talking circuit to conductor 247, terminal 244, brush 257, upper contacts of sequence switch spring 217, right-hand winding of relay 200, conductor 115, through the winding of polarized relay 113 as hereinbefore traced, returning over conductor 116, through the left-hand winding of relay 200, back contact and outer left-hand armature of relay 202, lower left-hand contact of spring 218 (11 $\frac{3}{4}$ +16), brush 258, terminal 245, thence over the lower talking conductor 105 to the conductor 332, upper left-hand contact of spring 407 (10+16), upper right-hand contact of said spring (10+18), lower left-hand winding of repeating coil 408, upper left-hand contact of spring 413 (10+18), lower left-hand contact of spring 413 (10), left-hand winding of relay 404 to ground. It will be observed that the current flowing in the circuit just traced through the windings of the polarized relay 113 at the outgoing end of the trunk circuit in the originating office is in the same direction as that which flowed in the circuit first completed through said relay at the time the originating operator inserted the plug 105 in the jack 106. Consequently, the relay 113 remains inoperative, the current flow being in the wrong direction to cause its energization. Relay 404 actuates 110 and closes a circuit for relay 403. Relay 403 establishes a circuit from battery through the left-hand winding of relay 400, contact and outer right-hand armature of relay 403, armature and contact of relay 401, upper left-hand contact of spring 421 115

(10+16), upper right-hand contact of said spring (10+10 $\frac{1}{2}$), lower right-hand contact of spring 424 (7+1), to ground. Relay 400 becomes energized and closes a circuit from 5 battery through the winding of sequence switch magnet 410, lower left-hand contact of spring 423 (9+10), front contact and outer armature of relay 400, to ground, driving sequence switch 410 out of position 10 and into position 11. In position 11 the circuit above traced for relay 404 is modified so as to lead from battery through its right-hand winding, over the upper side 15 of the talking circuit as described and re- turning over the lower side of the talking circuit through the lower left-hand winding of repeating coil 408, normal contacts of the left-hand armature of relay 402, contact and left-hand armature of relay 403, 20 left-hand winding of relay 404, to ground. In position 11 relay 400 also remains energized in a circuit from battery through its left-hand winding, contact and outer right-hand armature of relay 403, armature and 25 contact of relay 401, upper left-hand contact of spring 421 (10+16), lower left-hand contact of said spring (10 $\frac{1}{2}$ +13), to ground through the front contact and outer armature of relay 400.

30 Ringing current is now applied to the called subscriber's line. The circuit for the application of ringing current is first closed from the ringing source 450, lower right-hand contact of spring 420 (11+12), upper left-hand contact of said spring (11+13), winding of ringing cut-off relay 401, lower left-hand contact of spring 423 (11+3), front contact and inner armature of relay 400, lower right-hand contact of spring 417 35 (11+14), brush 434, terminal 437, conductor 440, upper left-hand contact of spring 507 (17+15), upper right-hand contact of said spring (14 $\frac{1}{2}$ +16), brush 526, terminal 529, thence over the loop of the called sub- 40 scriber's line 500, returning by way of terminal 528 and brush 525, lower right-hand contacts of spring 506 (15+16), lower left-hand contact of said spring (15+6), conductor 439, terminal 436, brush 433, lower right-hand contact of spring 416 (10+8), 45 lower left-hand contact of said spring (11+13 $\frac{1}{2}$), to ground. Due to the high resistance of the ringing circuit at the called substation, relay 401 fails to operate in this circuit. As soon, after the sequence switch 410 reaches position 11, as the interrupter cam 452 reaches the proper point in its rotation, spring 415 engages the upper contact, and a circuit is closed from ground 50 through said spring, upper right-hand contact of sequence switch spring 414 (11), right-hand winding of relay 402 to battery. Relay 402 operates and closes a circuit from ground through its inner right-hand armature and contact, lower right-hand contact 55 of spring 422 (11+12), winding of sequence switch magnet 410 to battery. This circuit is only momentarily closed since the interrupter spring 415 opens its upper contact immediately and, therefore, the sequence switch 410 only has time to move out of position 11 and into position 12 before relay 402 releases its armatures. It will be noted that during the brief energization of relay 402, the circuit of relay 404 is maintained as follows: battery through the right-hand winding of said relay, make before break contact at the outer right-hand armature of relay 402, right-hand contact of spring 412, upper left-hand winding of repeating coil 408, thence over the circuit previously traced, returning over the other side of the talking loop, through the lower left-hand winding of coil 408, upper left-hand contact of spring 413 (10+13), outer left-hand armature and make before break contact of relay 402, contact and left-hand armature of relay 403, left-hand winding of relay 404, to ground. It will also be noted that the current still flows in a direction opposite to that which is necessary to cause the operation of polarized relay 113. Later, as the interrupting cam 452 reaches another point in its cycle, the spring 415 engages its lowermost contact and a circuit is completed from ground through said spring, lower right-hand contact of sequence switch spring 414 (12), right-hand winding of relay 402 to ground. Relay 402 operates momentarily and closes the above traced circuit for driving sequence switch 410 out of position 12 and into position 13. In position 13 ringing current is applied to the called subscriber's line from the source of interrupted current 451 through the lower left-hand contact of spring 420 (13), upper left-hand contact of said spring (11+13), winding of relay 401 and thence as above traced to ground at the lower left-hand contact of spring 416. 60 The called subscriber, on removing his receiver from its switchhook in response to the ringing signal, reduces the resistance of the ringing circuit at the substation to permit the energization of the ringing cut-off relay 401. Relay 401 opens the holding circuit of relay 400 and this latter relay de-energizes to complete a circuit from battery through the winding of sequence switch magnet 410, upper left-hand contact of spring 422 (11+13), back contact and outer armature of relay 400, to ground, driving sequence switch 410 into position 14. In position 14 a circuit is established from battery through the right-hand winding of relay 400, upper right-hand contact of spring 432 (13 $\frac{1}{2}$ +15), lower left-hand contact of said spring (9+16), to ground. Relay 400 energizes and closes a circuit from battery 65 through the winding of sequence switch

magnet 410, lower left-hand contact of spring 422 (14), front contact and outer armature of relay 400 to ground. Sequence switch 410 moves into position 16 which is the talking position, and relay 400 retracts its armatures.

Since the called subscriber's receiver is off the switchhook a circuit is now completed from battery through the winding of supervisory relay 405, resistance 449, lower right-hand winding of repeating coil 408, upper left-hand contact of spring 417 (14+16), brush 434, terminal 451, conductor 440, thence over the lower side of the talking circuit through the loop of the called substation and returning over the upper side of the talking circuit to conductor 439, terminal 436, brush 433, lower right-hand contact of spring 416 (10+8), upper left-hand contact of said spring (13 $\frac{3}{4}$ +16), upper right-hand winding of repeating coil 408, resistance 453, to ground. Relay 405 operates and closes a circuit from ground through its contact and armature, upper left-hand contact of spring 414 (16), right-hand winding of relay 402 to battery. Relay 402 operates and modifies the circuit of relay 404 so that it now extends from battery through the right-hand winding of relay 404, make before break contact at the right-hand armature of relay 402, upper left-hand contact of spring 412 (15+18), lower left-hand winding of repeating coil 408, thence over the lower talking conductor, through the winding of polarized relay 113 and returning over the upper talking conductor through the upper left-hand winding of coil 408, upper right-hand contact of spring 413 (15+16), outer left-hand armature and make before break contact of relay 402, contact and left-hand armature of relay 403, to ground, through the left-hand winding of relay 404. The current now flows in the reverse direction, and accordingly, the polarized relay 113 at the originating office is energized. Relay 113 closes a circuit for shunting out the right-hand high resistance winding of relay 114. Relay 114 remains energized to hold the trunk closed and since the resistance in series with relay 107 is reduced, this latter relay receives sufficient current to attract its armature. Relay 107 closes a circuit from battery through its armature and contact, resistances 109 and 110, thence through the sleeve of the plug 105 and jack 106, left-hand winding of relay 114 to ground at the contact and armature of relay 113. This circuit shunts out the lamp 108 causing the same to extinguish, notifying the operator that the called subscriber has responded.

Release of the established connection.

At the termination of conversation the calling subscriber replaces his receiver to

the switchhook and the operator in the originating office receives the usual disconnect signal. The called subscriber also restores his receiver to the switchhook which results in the opening of the circuit of supervisory relay 405. Relay 405, in turn, opens the circuit of relay 402 which deenergizes and causes the reversal of the flow of current over the talking circuit including the polarized relay 113. Relay 113, consequently deenergizes and permits the inclusion of the high resistance winding of relay 114 in series with relay 107. Relay 107 as a result retracts its armature and the supervisory lamp 108 is again lighted to notify the operator that the called subscriber has hung up his receiver on the switchhook. She thereupon proceeds to take down the connection by removing plugs 102 and 105 of her cord circuit from their respective jacks 101 and 106. The removal of plug 105 from jack 106 opens the circuit of relay 114 and this relay deenergizes to open the holding circuit of relay 200 at the district selector in the tandem switching office. Relay 200, in turn, opens the circuit of relay 201 which deenergizes and completes a circuit from ground through its armature and back contact, upper left-hand contact of spring 215 (13+17), upper right-hand contact of spring 214 (13+17), right-hand winding of relay 204 to battery. Relay 204 operates and completes a circuit from ground through the interrupter 228, upper right-hand contact of spring 221 (13+17), front contact and outer right-hand armature of relay 204, upper right-hand contact of spring 223 (12+18), lamp 231 to battery. Another circuit is completed from ground through the interrupter 228, upper right-hand and lower left-hand contacts of spring 221 (13+17), front contact and left-hand armature of relay 204, lower left-hand contact of spring 213 (1+17), upper left-hand contact of said spring (13+17), lamp 243 to battery. Lamps 243 and 231 are flashed under the influence of interrupter 228 and serve to advise the operator in the tandem switching office that the connection is no longer required. She thereupon depresses her disconnect key 227 which closes the circuit from ground through the contacts of said key, left-hand contacts of spring 220 (2+17), winding of relay 202 to battery. Relay 202 energizes and closes a circuit from battery through the winding of sequence switch magnet 210, lower left-hand contact of spring 206 (12+17), contact and inner left-hand armature of relay 202, upper left-hand contact of spring 225 (12+17), upper right-hand contact of said spring (10 $\frac{3}{4}$ +18), to ground. Sequence switch 210 is driven from position 13 into position 18. In position 18 of sequence switch 210, the district selector switch 230 is restored to its normal position

by means of a circuit from battery through the winding of the down-drive power magnet 233, lower right-hand contact of spring 223 (18), upper right-hand contact of said 5 spring (12+18), lower left-hand contact of spring 225 (18), upper right-hand contact of said spring (10 $\frac{3}{4}$ +18), to ground. When the district selector switch is fully restored to its normal position, a circuit is established 10 from battery through the winding of sequence switch magnet 210, upper left-hand contact of spring 207 (7+18), normal position segment 242, brush 239 to ground. Sequence switch 210 thereupon moves out 15 of position 18 and into position 1, opening the circuit of the power magnet 233.

On leaving position 16 $\frac{1}{2}$ sequence switch 210 opens at the lower right-hand contact of spring 225 the holding circuit of relay 20 300. Relay 300 retracts its armatures and completes a circuit from battery through the winding of sequence switch magnet 310, lower left-hand contact of spring 301 (8+17), back contact and left-hand armature of relay 300 to ground. Sequence switch 310 moves out of position 8 and into position 18. Here a circuit is closed from battery through the winding of the down-drive power magnet 311, lower contacts of 25 spring 303 (18), to ground. Power magnet 311 causes the downward movement of the brush shaft 313, which on reaching its normal position, closes a circuit from battery through the winding of sequence switch 30 35 magnet 310, upper right-hand contact of spring 301 (3+18), normal position segment 326, brush 323 to ground. The sequence switch 310 moves into its normal position 1, opening the circuit of the power magnet 40 311.

At the time the originating operator removes the plug 108 from the jack 106 and relay 114 retracts its armatures, the circuit of relay 404 at the incoming switch is opened 45 and this relay releases. During the talking period, relay 400 has been energized in a circuit from battery through its left-hand winding, outer right-hand armature and contact of relay 403, lower left-hand contact of sequence switch spring 431 (14+16), lower right-hand contact of said spring (14 $\frac{3}{4}$ +16), front contact and outer armature of relay 400 to ground. Upon the deenergization 50 of relay 403, which occurs following the release of relay 404, the circuit of relay 400 is opened and this relay retracts its armatures. A circuit is now closed from battery through the winding of sequence switch magnet 410, upper left-hand contact 55 of sequence switch spring 422 (15+17), back contact and outer armature of relay 400 to ground, driving sequence switch 410 into position 18. In position 18 a circuit is 60 closed from battery through the winding of the down-drive power magnet 426, upper right-hand contact of spring 424 (18), to ground. The brush shaft 428 is restored to its normal position by magnet 426, and upon reaching such position, a circuit is established 65 from battery through the winding of sequence switch magnet 410, upper right-hand contact of spring 422 (3+18), normal position segment 448, brush 442, lower right-hand contact of spring 424 (7+1), to ground. Sequence switch 410 moves out of position 70 18 and into position 1, thereby opening the circuit of the power magnet 426.

Sequence switch 410 in moving out of position 16 $\frac{1}{2}$ opens at the upper left-hand contact of spring 419, the holding circuit of relay 501 at the final selector. Relay 501 becomes deenergized and closes a circuit from ground through its right-hand armature and back contact, upper left-hand contact of spring 511 (14+17), upper right-hand contact of said spring (14+15 $\frac{1}{2}$), left-hand winding of relay 540 to battery. Relay 540 operates and closes a circuit from battery through the winding of sequence switch magnet 510, lower right-hand contact of spring 513 (15), front contact and left-hand armature of relay 540, upper contact of spring 512 (12 $\frac{3}{4}$ +16), to ground. Sequence switch 510 moves out of position 15 and into position 16 and relay 540 retracts its armatures. Another circuit is now closed from battery through the winding of sequence switch magnet 510, upper right-hand contact of spring 513 (16), back contact and left-hand armature of relay 540, upper contact of spring 512 to ground, driving sequence switch 510 into position 17. Sequence switch 510 is now advanced into position 18 by means of a circuit from battery through the magnet of said sequence switch, lower right-hand contact of spring 511 (17), upper left-hand contact of said spring (14+17), back contact and right-hand armature of relay 501 to ground. In position 18 a circuit is established from battery through the winding of the down-drive power magnet 523, lower right-hand contact of spring 518 (18), upper right-hand contact of spring 517 (18), upper left-hand contact of spring 519 (13+1), to ground. The magnet 533 causes the brush shaft 524 to move downwardly and on reaching its normal position a circuit is established from battery through the winding of sequence switch magnet 510, upper left-hand contact of spring 513 (18), normal position segment 534, brush 531, upper left-hand contact of spring 519 (13+1), to ground. Sequence switch 510 moves from position 18 into position 1 and opens the power circuit 120 of the down-drive magnet 523. The entire 125

apparatus taken in connection with the establishment of the call is now restored to its normal condition.

5 *Establishment of a connection to a sub-tandem office.*

It will next be considered that the subscriber of line 100 in the originating manual office illustrated in Fig. 1 desires to converse with the subscriber of line 600 belonging to a distant terminating manual office which must be reached by means of a connection extending through the tandem switching office and through a sub-tandem office. In the same manner as hereinbefore described the answering operator in the originating office responds to the initiation of the call by inserting the plug 102 of her cord circuit in the jack of the calling line and orders the assignment of a trunk by the operator in the tandem switching office. The operator in the tandem switching office assigns the trunk 115, 116 into the jack 106 of which the originating operator inserts the plug 105 of her cord circuit. Furthermore, the operator in the tandem switching office depresses the assignment key 226, which causes, as has been seen, the operation of a trunk selector and sender selector unit. The trunk selector 920 operates to find the trunk taken for use by the operator and the sender selector 940 operates to seize an idle one of the common register senders, following which, the sequence switch 910 advances into position 6.

Since the connection which is to be established in this case is one requiring the selection of a trunk 333, 334 outgoing from the tandem switching office to the distant sub-tandem office, the office designation, which determines this selection, will be characterized by different combinations of horizontal and vertical keys of the operator's keyboard. Moreover, the connection is one of a different class than that previously considered, necessitating the transmission of code impulses by the sender to control a relay call indicator at the sub-tandem office. Hence, the office designation recorded on the horizontal and vertical keys will determine that for this particular class of calls, the class sequence switch 1110 will take a setting in position 6. Assume, that the terminating office containing the called subscriber's line 600 is identified by an office code which is expressed by the combination of the horizontal key 1633 and the vertical key 1656 and that the number of the line 600 is 2443. It will be noted that the designation of the subscriber's line 600 has been assumed to correspond closely to that of the subscriber's line 500, previously considered in connection with the establishment of a connection to a full mechanical office. The numerical designations are identical and the

only difference in the office designations as represented on the operator's keyboard is that in the present case the vertical key 1656 is required, while in the former case key 1632 was used. It will be understood, of course, that these two designations might differ very radically their similarity being assumed for simplicity and in order to avoid as far as possible the necessity of repeating the detailed description of the setting of the sender registers.

In response to the depressed horizontal key 1633 the sequence switch 1810 is driven into position 2, where the translator switch 1700 is advanced to select and trip a set of brushes, following which, the sequence switch moves into position 4 where the tripped set of brushes are driven over the first group of twenty terminals, following which, the sequence switch 1810 moves into position 6 and the selected set of brushes resume their upward movement to search for a set of terminals identified by the depressed vertical key. When the translator reaches the set of terminals 1747, 1748, 1749, 1750, 1751 and 1752, which are represented by the vertical key 1656, a circuit is closed from battery through the winding of relay 1825, lower right-hand contact of spring 1835 (1 $\frac{3}{4}$ +6), upper left-hand contact of said spring (5 $\frac{3}{4}$ +6), brush 1733, terminal 1797, conductor 1649, left-hand contacts of key 1656, conductor 1640 and thence to ground as previously traced. Relay 1825 operates as described to stop the upward movement of the translator switch and the sequence switch 1810 moves into position 7.

In the manner hereinbefore explained the district sequence switch 210 advances into position 3 and sequence switch 910 moves into position 7.

Relay 1821 is operated to extend the impulse conductors from the brushes of the translator switch through to the relays 1808, 1809, 1811, etc., and assuming the impulse machine will be in the position illustrated in the drawing, the brushes immediately encounter the first vertical row of terminals shown on the developed surface of the drum. A circuit is now closed from battery through the contact 1782, brush 1777, terminal 1747, brush 1735, conductor 1866, through the winding of relay 1808, to ground. Relays 1808 and 1815 are operated. Still another circuit is closed as hereinbefore traced for the relay 1823 which causes the energization of the first counting relay 1827. Battery potential is now applied through the contact 1767, brush 1764 to conductor 1858, thence through the next to the inner armature and contact of relay 1815, left-hand winding of relay 1890 to ground. Relay 1890 is operated and locks as above explained.

In the second position of the impulse ma-

chine a circuit is closed from battery through the contact 1798, brush 1772, terminal 1752, brush 1740, conductor 1861, thence through the winding of relay 1814 to ground. Another circuit is closed from battery through the contact 1787, brush 1773, terminal 1751, brush 1739, conductor 1862, thence through the winding of relay 1813 to ground. Another circuit leads from battery through the contact 1785, brush 1775, terminal 1749, brush 1737, conductor 1864, thence through the winding of relay 1811 to ground. Relays 1811, 1813 and 1814 and their corresponding relays 1817, 1819 and 1820 are operated. At the same time battery potential is applied through the contact 1768, brush 1765 to the conductor 1859. A circuit is therefore traceable from conductor 1859 through the next to the outer armature and contact of relay 1817, left-hand winding of relay 1802 to ground. Another circuit leads from conductor 1859, through the next to the outer armature and contact of relay 1819, relay 1805 to ground. A third circuit leads from conductor 1859 through the next to the outer armature and contact of relay 1820, relay 1806 to ground. Relays 1802, 1805 and 1806 operate and lock as previously described.

In the third position of the impulse machine a plurality of circuits are closed, one of which leads from battery, through the contact 1799, brush 1772, terminal 1752, brush 1740, conductor 1861, thence through the winding of relay 1814, to ground. Relays 1814 and 1820 are operated. Battery potential is also applied through the contact 1769, brush 1766 to conductor 1860. A circuit is therefore closed from conductor 1860, through the outer armature and contact of relay 1820, left-hand winding of relay 1807 to ground. Relay 1807 operates and locks up as hereinbefore explained.

Finally, in the fourth position of the impulse machine a plurality of circuits are established, one of which may be traced from battery through the contact 1883, brush 1772, terminal 1752, brush 1740, conductor 1861, and thence through the winding of relay 1814 to ground. Another circuit leads from battery through the contact 1788, brush 1773, terminal 1751, brush 1739, conductor 1862, thence through the winding of relay 1813 to ground. Still another circuit may be traced from battery through the contact 1786, brush 1774, terminal 1750, brush 1738, conductor 1863, winding of relay 1812 to ground. Still another circuit may be traced from battery through contact 1884, brush 1885, terminal 1748, brush 1736, conductor 1865, relay 1809 to ground. Relays 1809, 1812, 1813, 1814 and relays 1816, 1818, 1819 and 1820 become energized. In position 4 of the impulse machine, battery potential is applied through the contact

1770 and brush 1763 to conductor 1861. A circuit is therefore closed from conductor 1861 through the inner armature and contact of relay 1818, left-hand winding of relay 1803 to ground. Another one is closed from conductor 1861, through the inner armature and contact of relay 1819, left-hand winding of relay 1804 to ground. Another circuit is closed from conductor 1861, through the inner armature and contact of relay 1820, left-hand winding of relay 1888, to ground. Still another circuit is closed from conductor 1861 through the inner armature and contact of relay 1816, left-hand winding of relay 1886 to ground. Relays 1886, 1803, 1804 and 1888 are operated and remain energized in their locking circuits. Following the completion of the registration on the translator register relays, the brushes of the translator switch are disconnected from the impulse leads.

During the time the office record is being set up on the translator register relays, the numerical record is transferred in identically the same manner as before described to the numerical registers of the selected register sender. Since the same numerical keys are depressed on the operator's keyboard, the same numerical registers, shown in each of the five different groups in Figs. 14 and 15, will be operated. Following the transfer of the numerical records to the sender, the sequence switch 1810 moves into position 8 and the transfer of the class, district brush, district group, office brush and office group registrations from the translator register relays to the corresponding registers of the sender commences. By tracing the impulse circuits in the manner similar to that explained in detail in connection with the previous call, it will be found that for the particular translator register relays which are now energized the following class, district brush, district group, office brush and office group registers in the sender will be energized:

Class relays 1427 and 1502.

District brush relay 1401.

District group relays 1402 and 1419.

Office brush relays 1513 and 1504.

Office group relays 1507, 1506 and 1410.

Following the restoration of the operator's keyboard and other equipment, the sequence switch 910 advances out of position 7 and into position 8.

Setting of the class sequence switch.

Assume, that the class sequence switch 1110 is still standing in position 10, to which position it was driven in connection with the full mechanical call previously considered. With the register relay 1502 operated and the remaining relays 1500, 1501 and 1503 deenergized, circuits are prepared for advancing the class sequence switch 1110 from

position 10 into position 6. In position 10 a circuit is closed from battery through the winding of sequence switch magnet 1110, upper right-hand contact of spring 1138 (10), conductor 1156, front contact and right-hand armature of relay 1502 to ground over conductor 1332. In position 11 of the sequence switch a circuit is closed from battery through the winding of its magnet, 5 lower left-hand contact of spring 1138 (11), conductor 1141, back contact and right-hand armature of relay 1503 to the grounded conductor 1332. In positions 12, 13, 14 and 15, the two circuits above traced are alternately 10 closed at the upper right-hand and lower left-hand contacts of sequence switch spring 1138 and the class switch 1110 continues to move into position 16. In position 16 a circuit is closed from battery through the winding of sequence switch magnet 1110, lower right-hand contact of spring 1139 (16), conductor 1157, back contact and right-hand armature of relay 1500 to the grounded conductor 1332. Sequence switch 1110 moves 15 into position 17 where the above traced circuit is closed at the lower left-hand contact of sequence switch spring 1138 and the sequence switch moves out of position 17 into position 1 and thence by the same circuit 20 into position 2. In position 2 a circuit is closed from battery through the winding of sequence switch magnet 1110, upper left-hand contact of spring 1139 (2), conductor 1158, back contact and right-hand armature 25 of relay 1501 to ground, over conductor 1332. Sequence switch 1110 advances into position 3 where the previously traced circuit is closed for moving it into position 4. In position 4 the circuit at the upper left-hand contact of spring 1139 is closed once 30 more and the sequence switch 1110 advances into position 5 from whence it moves into position 6 by means of a circuit closed at the lower left-hand contact of spring 1138. In position 45 From an inspection of the various circuits it will be noted that in position 6 of the sequence switch 1110, no circuit is closed, and consequently, the sequence switch fails to advance further.

50 During the movement of the class sequence switch 1110, the relay 1400 is continually energized in parallel therewith. Immediately that the class switch reaches position 6 and stops, relay 1400 retracts its armatures, 55 which operation indicates that the connection about to be established is one intended for a sub-tandem call indicator office and that the office record already established on the office registers should, therefore, be reproduced on the secondary routing registers 1100. The deenergization of relay 1400 causes the closure of a circuit from battery 60 through the winding of sequence switch 1120, lower left-hand contact of spring 1118 (1), upper left-hand contact of spring 1109

(6), right-hand armature and contact of relay 1400, conductor 1159, upper right-hand contact of spring 1305 (8+11), lower left-hand contact of said spring (2+18), to ground. The sequence switch 1120 moves 70 into position 2 where a circuit is closed for selectively positioning said sequence switch in accordance with the particular combination of office brush registers 1513, 1504 and 1514 which are energized. This circuit may 75 be traced from battery through the winding of the magnet of said sequence switch, left-hand armature and front contact of relay 1427, conductor 1149, upper left-hand contact of spring 1121 (2+8), conductor 1160, upper left-hand contact of spring 1111 (6), conductor 1522, contact and outer right-hand armature of register relay 1504, back contact and left-hand armature of relay 1514, conductor 1526, right-hand contact of 80 spring 1109 (6), conductor 1161, right-hand armature and contact of relay 1400, conductor 1159 and thence to ground as previously traced through the contacts of spring 1305. The sequence switch 1120 becomes energized 85 in this circuit and moves from position 2 through its succeeding positions into position 9. It will be noted that other circuits lead from the contacts of springs 1119 and 1121, but upon attempting to trace 90 these, it will be found that they are all open at the contacts of the office brush register relays. Consequently, the routing switch 1120 comes to rest in position 9 where it 95 will select one of the secondary registers 100 1100 to effect a reproduction of the office registration. During the movement of sequence switch 1120, the relay 1348 is continually energized in a parallel circuit therewith. When, however, the sequence switch 105 ceases its operation, the circuit of relay 1348 is simultaneously opened and this relay becomes deenergized, whereby a circuit is established from ground through the left-hand armature and contact of said relay, conductor 1428, lower left-hand contact of 110 spring 1155 (9), winding of secondary register relay 1150 to battery. Relay 1150 becomes energized.

115 *Operation of the district and office selector switches.*

During the setting of the class sequence switch 1110 and the routing sequence switch 1120, the sender is held inactive, pending a 120 determination of the particular class of connection it must control. As soon as these two switches are positioned, however, both relays 1400 and 1348 are deenergized and a circuit is established for advancing the 125 sender sequence switch out of its normal position preparatory to controlling the district selector switch in its brush selective movement. The circuit for advancing the 130 sender sequence switch 1010 out of position

1 into position 2 may be traced from battery through the winding of the magnet of said sequence switch, lower left-hand contact of spring 1034 (17+1), right-hand contacts 5 of spring 1308 (10+11), conductor 1328 and thence as hereinbefore traced through the armatures and contacts of relays 1348 and 1400 to ground. From position 2 the sequence switch 1010 is moved into position 4 10 as hereinbefore explained.

Since the district sequence switch 210 is now in position 5 and the sender sequence switch 1010 is in position 4 the fundamental circuit is established and relays 204 and 15 1000 are operated. Sequence switch 210 moves into position 6 where the up-drive power magnet 232 is energized and the brush shaft 235 commences its upward movement to select the proper set of brushes. The 20 stepping relay 1000, upon energizing in the fundamental circuit establishes a circuit from ground through the upper right-hand contact of spring 1019 (4), contact and armature of relay 1000, upper contact of 25 spring 1018 (4), conductor 1059, thence as previously traced through the lower contact of spring 1030 (2+16), upper right-hand contact of spring 1029 (4), right-hand contact of spring 1132 (2+11), conductor 1162, 30 outer left-hand armature and contact of register relay 1150, conductor 1151, thence to conductor 1016 Fig. 10, armature and back contact of counting relay 1012, winding of relay 1013 to battery. When the 35 brush shaft has reached the position for tripping the proper set of brushes, relays 1006, 1007 and 1008 operate. The fundamental circuit is opened and sequence switch 1010 moves into position 6.

40 Sequence switch 210 moves into position 7, the fundamental circuit is again established, relays 204 and 1000 operate, sequence switch 210 advances into position 8, the brush shaft is moved upwardly in the group 45 selecting operation and the selected set of brushes are tripped. The stepping relay 1000, when operating, closes the stepping circuit from ground through the upper left-hand contact of spring 1019 (6), armature 50 and contact of relay 1000, thence as previously traced through the lower contact of spring 1030, lower right-hand contact of spring 1029 (6), upper contact of spring 1131 (2+11), conductor 1163, inner left-hand armature and contact of relay 1150, 55 conductor 1152, thence to conductor 1057 Fig. 10, armature and back contact of counting relay 1072, winding of relay 1073 to battery. When the proper group of trunks has 60 been reached all the counting relays will have been energized and the fundamental circuit is opened and the sender sequence switch 1010 moves out of position 6 into position 8, from whence it advances into position 10 as before described. Trunk hunting 65

takes place at the district switch in the manner already explained, an idle trunk 247, 248 leading to an office selector is chosen and sequence switch 210 goes into position 11.

Following the selection of an idle office 70 switch 330 the fundamental circuit is again established, relays 300 and 1000 are operated, sequence switch 310 moves into position 2 and the brush shaft 313 commences its upward movement. Relay 1000, operating in the fundamental circuit, closes a circuit from ground through the upper left-hand contact of spring 1019 (10), armature and contact of relay 1000, thence as previously traced through the lower contact of 80 spring 1030, lower left-hand contact of spring 1029 (10), upper contact of spring 1130 (2+11), conductor 1164, inner right-hand armature and contact of relay 1150, conductor 1154, thence to conductor 1017 85 Fig. 10, back contact and outer armature of relay 1005, winding of relay 1007, to battery. When the first brush tripping position is reached, relay 1006 and 1008 operate, the fundamental circuit is opened and sequence 90 switch 1010 moves into position 12.

Group selection at the office switch takes place and in this case the stepping circuit is completed from ground through the upper right-hand contact of spring 1019 (12), contact and armature of relay 1000 and thence as previously traced through the lower contact of spring 1030, upper contact of spring 1030 (12), upper contact of spring 1129 (2+11), conductor 1165, outer right-hand armature and contact of relay 1050, conductor 1153, thence to conductor 1058 Fig. 10, armature and back contact of relay 1060, winding of relay 1061 to battery. Since the routing sequence switch 1120 is standing in 100 position 9, the following circuit is established when the sender sequence switch 1010 reaches position 12: battery through the winding of relay 1005, upper left-hand contact of spring 1027 (17+13), lower left-hand contact of said spring (11+12), conductor 1063, lower left-hand contact of spring 1139 (9), to ground. The operated condition of relay 1005 determines as hereinbefore described that the additional group 110 of five counting relays must be operated before the fundamental circuit can be opened. This means that the office selector will choose a group of trunks in the second or upper half of the brush section. As already noted 115 the connection of the various contacts of springs 1137, 1136, 1138 and 1139 of the routing sequence switch 1120 to ground is a matter of arbitrary choice and serves to enable the shifting of the trunks in the office 120 and district office switches from one part of the bank to another to suit traffic convenience.

Following group selection at the office selector, trunk hunting takes place and the 130

sequence switch 310 advances into position 8. When the sender sequence switch 1010 moves out of position 12 and into position 14 following office group selection, a circuit is closed from battery through the winding of sequence switch magnet 1310, upper left-hand contact of spring 1307 (10), lower left-hand contact of spring 1039 (14), to ground, driving sequence switch 1310 into position 11.

Preparation of the register sender for transmitting code impulses to relay call indicator in sub-tandem office.

15 The district and office switches 230 and 330 in the tandem switching office having been selectively operated to choose a trunk 333, 334 leading to the distant sub-tandem operator's position, preparation must now be 20 made in the register sender to transmit codes of impulses in accordance with the office and numerical designations to give to the sub-tandem operator a visual indication which enables her to determine the name of 25 the office being called and the number of the wanted line therein.

At the time the routing switch 1120 is moved out of position 1, a circuit is closed from battery through the winding of the 30 impulse sequence switch 1210, contact of spring 1222 (1), upper right-hand contact of spring 1125 (2+11), to ground, driving sequence switch 1210 into position 7. The fact that the routing switch 1120 takes up 35 some position between positions 2 and 11 inclusive indicates that a tandem office connection is about to be established and in anticipation of this fact, the impulse sequence switch 1210 takes up a setting in 40 position 7 in readiness to commence the transmission of code impulses representing the tandems designation. As soon as the sender sequence switch 1010 leaves position 12 and moves into position 14 a circuit is 45 closed from ground through the lower left-hand and upper right-hand contacts of spring 1025 (13+15), conductor 1077, upper left-hand contact of spring 1118 (2+11), winding of sequence switch magnet 1120 to 50 battery, driving sequence switch 1120 out of position 9 and into position 12.

With the sender sequence switch 1010 in position 14 and the control sequence switch 1310 in position 11 a circuit is established 55 from battery through the right-hand winding of relay 616, Fig. 6, normal contacts at the right-hand armature of relay 615, conductor 601 of the trunk circuit, back contact and inner armature of relay 614, conductor 633, terminal 320, brush 314, thence over the upper side of the talking circuit to conductor 1047, upper right-hand contact of spring 1304 (11), lower contact of spring 1020 (14+14 $\frac{3}{4}$), winding of relay 1001, 60 upper right-hand contact of spring 1055

(14+17), resistance 1054, resistance 1035, conductor 1068, conductor 1147, lower contact of sequence switch spring 1042 (14+14 $\frac{3}{4}$), upper left-hand contact of spring 1302 (11), conductor 1048, thence over the other side of the circuit hereinbefore traced to the office selector brush 315, terminal 321, conductor 334, outer armature and back contact of relay 614, normal contacts at the left-hand armature of relay 615, left-hand winding of relay 616 to ground. Relay 1001 operates in this circuit and closes a circuit from ground through its armature and contact, winding of relay 1003 to battery. It also closes a circuit from ground through 80 its armature and contact, winding of relay 1002, upper left-hand and lower right-hand contacts of spring 1032 (14+15), to battery. Relays 1003 and 1002 becomes energized and a circuit is closed from battery through the winding of sequence switch magnet 1010, upper right-hand contact of spring 1033 (14), upper left-hand contact of spring 1106 (1+9), conductor 1166, contact and outer right-hand armature of relay 1003, 85 to ground, driving sequence switch 1010 into position 15. Here another circuit is closed from battery through the winding of sequence switch magnet 1010, lower right-hand contact of spring 1033 (15), conductor 1078, left-hand contact of spring 1101 (6), right-hand contacts of spring 1123 (12), upper left-hand contact of spring 1220 (7), to ground, moving sequence switch 1010 out of 90 position 15 and into position 16. It will be noted that the advance of the sender sequence switch 1010 from position 15 into position 16 depends upon sequence switch 1120 being in position 12 and sequence switch 1210 being in position 7. This dependence 95 insures that the sender sequence switch 1010 cannot pass into position 16, which is the position where the transmission of code impulses commences, until all conditions for the transmission of such impulses are favorable, that is, until the routing switch 1120 is in position 12 and the impulse switch 1210 is in position 7. In position 16 of the sender sequence switch, the circuit in which relay 100 100 105 110 115 120 125 130 135 140 145 150 155 160 165 170 175 180 185 190 195 200 205 210 215 220 225 230 235 240 245 250 in so doing closes a circuit as follows: ground through the armature and contact of said relay, inner left-hand armature and back contact of relay 618, winding of relay 620, contact and inner left-hand armature of relay 621 to battery. Relay 620 operates and closes a locking circuit as follows, independently of the inner left-hand armature of relay 621: battery through the inner right-hand armature and contact of relay 620, winding of said relay and thence to ground at the contact and armature of relay 616. Relay 620 at its outer right-hand armature and front contact closes a circuit for the assignment lamp 623, the illumination of which notifies the operator that a connection has been extended to the trunk 601, 602 from the distant tandem switching office.

In response to the assignment signal 623 the operator actuates the assignment key 622 individual to the trunk 601, 602. The key 622 is for the purpose of associating with the trunk 601, 602, the call indicator mechanism shown in Figs. 7 and 8 to receive the codes of impulses which are presently to be transmitted. The depression of key 622 closes a circuit from battery through the winding of relay 723, conductor 731, right-hand winding of relay 617, front contact and left-hand armature of relay 620, right-hand contacts of key 622, conductor 732, contact and armature of relay 726, back contact and outer armature of relay 724, to ground. A branch of this circuit extends through the winding of relay 727, but due to the direct path to ground relay 727 cannot operate. Relays 723 and 617 become energized and a new circuit for these relays is established from battery through the winding of relay 723, conductor 731, through both windings of relay 617 in series, contact and inner left-hand armature of said relay to ground at the inner right-hand armature and contact of relay 627. Relay 617 establishes a circuit from ground through its contact and right-hand armature, winding of relay 621, back contact and outer left-hand armature of relay 627 to battery. Relay 621 operates and a circuit is closed from battery through the inner right-hand armature and contact of relay 620, front contact and outer left-hand armature of relay 621, winding of relay 619 to ground. Relay 619 becomes energized and closes a circuit from battery through the winding of relay 618, contact and right-hand armature and winding of relay 619 to ground. Relay 618, however, does not energize since its winding is shunted out by the circuit from battery through the inner right-hand armature and contact of relay 620 to ground through the winding of relay 619. Relay 619 also closes a circuit from battery through its left-hand armature and contact, winding of relay 614, contact and outer left-hand armature of relay 617, conductor 635,

winding of relay 726, back contact and inner armature of relay 724 to ground. Relays 614 and 726 become energized. Relay 726 opens the shunt around the winding of relay 727 previously mentioned, but relay 727 remains deenergized since the circuit thereof is opened at the right-hand contacts of key 622 as soon as the operator releases the key.

When relay 614 becomes energized it opens the circuit of relay 616 in the sub-tandem office and relay 1001 at the sender. Relay 616 retracts its armature and opens the circuit of relay 620 which thereupon deenergizes and removes the short-circuit from around the winding of relay 618. Relay 618 now becomes energized in series with relay 619 over the circuit previously traced. The release of relay 620 completes a circuit from battery through the lamp 623, outer right-hand armature and back contact of relay 620, right-hand armature and front contact of relay 621, through the interrupter 636 to ground. The lamp 623 ceases to burn steadily and instead is intermittently flashed by the constantly rotating interrupter 636. This flashing signal will continue throughout the period in which the relay call indicator is being operated. Relay 614 at its armatures and front contacts extends the incoming conductors 333 and 334 over conductors 633 and 634 to the receiving relays 700, 701 and 702.

Setting of call indicator in accordance with the office designation.

When relay 1001 becomes deenergized it opens the circuits of relays 1003 and 1002, the purpose of which is to initiate the movement of the impulse sequence switch 1210 which starts out from position 7 and rotates into position 17 to transmit codes of impulses over the impulse circuit in accordance with the office designation. The circuit for sequence switch 1210 may be traced from battery through the winding of its magnet, 110 lower left-hand contact of spring 1219 (7), conductor 1223, lower contacts of spring 1024 (16), contact and inner armature of relay 1003, conductor 1079, contact of sequence switch spring 1102 (1+7), to ground. 115

As hereinbefore explained the relays 700 and 701 are sensitive and polarized to respond to currents of opposite direction, while relay 702 is marginal and only operates on strong currents regardless of direction. The relay 700 is polarized in such a manner that it will operate in response to a current of positive polarity flowing from the source over the conductor 634 and returning to the source by way of the conductor 633. 120 Relay 701 is polarized in such a manner that it only responds to currents of a negative polarity flowing from the source over the conductor 634 and returning to the source by way of conductor 633. 125

While the impulse switch 1210 passes through positions $7\frac{1}{4}+8$ a circuit is closed from ground, which represents the positive pole of battery, through the upper contact 5 of spring 1200 ($7\frac{1}{4}+8$), conductor 1224, lower right-hand and upper left-hand contacts of spring 1025 (16), conductor 1080, contacts of spring 1113 (1+9), conductor 1167, back contact and outer left-hand armature of relay 1003, upper contact of spring 1020, upper right-hand contact of spring 1304 (11), conductor 1047, terminal 956, brush 962, thence over the circuit previously traced through conductor 247, through office 15 selector brush 314, terminal 320, conductor 333, inner armature and front contact of relay 614, conductor 633, windings of relays 700, 701 and 702 in series, returning by way of conductor 634, front contact and outer 20 armature of relay 614, conductor 334, terminal 321, brush 315, thence over conductor 248 to the brush 963 of the sender selector 940, terminal 957, conductor 1048, upper left-hand contact of spring 1302, upper contact 25 of spring 1042 ($14\frac{3}{4}+16$), inner left-hand armature and back contact of relay 1003, conductor 1081, contacts of spring 1115 (1+9), conductor 1168, lower contact of spring 1203 ($7\frac{1}{4}+8$), upper contact of said 30 spring ($7\frac{1}{4}+8$), conductor 1225, thence to conductor 1422 Fig 14, contact and outer right-hand armature of the district brush register relay 1401, back contact and left-hand armature of relay 1412, conductor 1143, lower contact of spring 1216 ($6\frac{3}{4}+9$), lower contact of spring 1217 ($7\frac{1}{4}+8$), conductor 1226, lower contact of spring 1128 (12), low resistance 1134, conductor 1169, upper right-hand contact of spring 1022 40 (16), to the negative pole of battery. The circuit just traced is the impulse circuit over which the codes of impulses are transmitted to the switching relays 700, 701 and 702 in the sub-tandem office to determine the setting of the relay call indicator. Since at 45 this particular instant the current in the impulse circuit flows from the positive pole of battery over that side of the circuit which leads to conductor 633, through the relay 700, 701 and 702 in series and returning to the negative pole of battery by way of conductor 634 and the other side of the impulse circuit, sensitive relay 701 operates and relay 700 remains deenergized. Furthermore, the current being strong in character due to the fact that only the low resistance 1134 is included in the circuit, the marginal relay 702 operates. Relay 701 closes a circuit from ground through the 50 outer right-hand armature and contact of relay 722, outer armature and contact of relay 723, conductor 733, armature and contact of relay 701, left-hand armature and back contact of relay 703, left-hand winding of relay 704, left-hand winding of relay 703 to battery. Relay 704 becomes operated, but relay 703 remains deenergized since it does not receive sufficient current in series with the left-hand winding of relay 704 to operate. Relay 704 when operated completes a 70 circuit from battery through the left-hand winding of relay 703, left-hand winding of relay 704, right-hand winding of relay 703, contact and inner right-hand armature of relay 704 to the grounded conductor 733. 75 This circuit includes both windings of relay 703, but this relay still remains deenergized since its right-hand winding is shunted out by the circuit traced through the contact and armature of relay 701. Relay 702, which 80 also becomes energized, closes a circuit from ground through its armature and contact, outer right-hand armature and back contact of relay 703, outer left-hand armature and back contact of relay 707, conductor 734, left-hand winding of relay 735, conductor 736, to battery. Relay 735 operates and locks in a circuit from battery through its left-hand winding and right-hand winding in series, contact and inner right-hand armature of said relay, conductor 733, contact and outer armature of relay 723, contact and outer right-hand armature of relay 722 to ground. When relay 704 operates it closes 85 a circuit from ground over conductor 733, outer right-hand armature and contact of said relay, right-hand armature and back contact of relay 707, winding of relay 706, to battery. Relay 706 operates and closes a 90 circuit from battery through its winding and the winding of relay 707 in series, right-hand armature and contact of relay 706, to ground, over conductor 733. Relay 707, however, remains deenergized since its winding is shunted by the circuit to ground through the contact and outer right-hand armature of relay 704. As the impulse sequence switch 1210 moves out of position 8 it 95 opens the impulse circuit and relays 701 and 702 become deenergized. Relay 701 opens the shunt circuit around the right-hand winding of relay 703 and this relay becomes 100 energized in series with relay 704. 105 As the impulse switch 1210 passes through positions $9\frac{1}{4}+9\frac{1}{2}$ a circuit is closed from the positive pole of battery through the upper contact of spring 1200 ($9\frac{1}{4}+9\frac{1}{2}$), conductor 1224, thence as hereinbefore traced to conductor 633, windings of relays 700, 701 and 702 in series, conductor 634 and returning to conductor 1168, lower contact of spring 1203 ($9\frac{1}{4}+9\frac{1}{2}$), conductor 1227, conductor 1228, high resistance 1133, conductor 1056, lower right-hand contact of spring 1023 (16), to the negative pole of battery. The current 115 flowing in this circuit is of the proper polarity to cause the operation of relay 701 and is also weak due to the inclusion of the high resistance 1133. Consequently, relay 701 energizes, but the marginal relay 702 re- 120 125 130

mains inert. When relay 701 operates it closes a circuit from ground over conductor 733, through the armature and contact of relay 701, left-hand armature and front contact of relay 703, left-hand winding of relay 703 to battery. This circuit maintains the energization of relay 703 and causes the relay 704 to be shunted out. Relay 704 thereupon releases its armatures. The shunt around the winding of relay 707 is still maintained as follows: battery through the winding of relay 706, back contact and right-hand armature of relay 707, contact and inner right-hand armature of relay 703 to the grounded conductor 733. When the impulse switch 1210 passes out of position 9 $\frac{1}{4}$, it opens the circuit of relay 701, which in turn, becomes deenergized to open the circuit of relay 703. Relay 703 releases its armatures and opens the shunt around the winding of relay 707. Thereupon, relay 707 energizes in series with relay 706 and these relays remain energized independently of the relays 703 and 704. The movement of the impulse sequence switch 1210 from position 7 through position 9 $\frac{1}{4}$ has caused the successive energization and deenergization of relays 703 and 704. The first two switching relays 706 and 707 have been operated and locked and the proper selecting relay 735 of the tandem hundreds group has been energized to determine the illumination of the necessary one of the tandem hundreds lamps.

As sequence switch 1210 passes through positions 10 $\frac{3}{4}$ +11 a circuit is closed from ground through the upper contact of spring 1200 (10 $\frac{3}{4}$ +11), conductor 1224, thence to conductor 633, through the windings of relays 700, 701 and 702 in series, returning over the other side of the impulse circuit to conductor 1168, lower contact of spring 1203 (10 $\frac{3}{4}$ +11), conductor 1227, conductor 1228, high resistance 1133, conductor 1056, lower right-hand contact of spring 1023 (16), to the negative pole of battery. The direction of current in this circuit is such as to operate the sensitive relay 701, but due to the high resistance 1133 the marginal relay 702 remains inactive. Relay 701 closes a circuit from the grounded conductor 733 through its armature and contact, left-hand armature and back contact of relay 703, left-hand winding of relay 704, left-hand winding of relay 703 to battery. Relay 704 operates while relay 703 remains deenergized. Relay 704 closes the circuit traced from battery through the left-hand winding of relay 703, left-hand winding of relay 704, right-hand winding of relay 703, contact and inner right-hand armature of relay 704 to the grounded conductor 733. Relay 703 remains deenergized since its right-hand winding is shunted by the relay 701. Relay 704, on operating, closes a circuit from the grounded conductor 733, outer right-hand armature and contact of relay 704, right-hand armature and front contact of relay 707, right-hand armature and back contact of relay 709, winding of relay 708 to battery. Relay 708 operates and closes a circuit from battery through its winding and the winding of relay 709 in series, inner right-hand armature and contact of relay 708 to the grounded conductor 733. Relay 709 does not operate at this time since its winding is shunted out by the direct circuit to ground through the outer right-hand armature and contact of relay 704. As the sequence switch 1210 leaves position 11, it opens the circuit of relay 701 and this relay deenergizes and opens the shunt around the right-hand winding of relay 703. Relay 703, therefore, operates in series with the relay 704.

In passing through positions 12 $\frac{1}{4}$ +12 $\frac{1}{2}$, sequence switch 1210 closes a circuit from the positive pole of battery through the upper contact of spring 1200, conductor 1224, thence over the impulse circuit to conductor 633, through the windings of relay 700, 701 and 702 in series, conductor 634, thence over the other side of the impulse circuit to conductor 1168, lower contact of spring 1203 (12 $\frac{1}{4}$ +12 $\frac{1}{2}$), conductor 1227, outer right-hand armature and front contact of relay 1419, conductor 1229, lower contact of spring 1213 (12+12 $\frac{1}{4}$), conductor 1230, lower contact of spring 1127 (12), low resistance 1134, conductor 1169 and thence to the negative pole of battery. Due to the direction of flow of current in this circuit, relay 701 operates and since only the low resistance 1134 is included the marginal relay 702 also becomes energized. Relay 701 closes a circuit from battery through the left-hand winding of relay 703, front contact and left-hand armature of said relay, contact and armature of relay 701 to ground, causing the relay 704 to be shunted out and released. The shunt around the winding of relay 709 is still maintained as follows: battery through the winding of relay 708, back contact and right-hand armature of relay 709, front contact and right-hand armature of relay 707, contact and inner right-hand armature of relay 703 to the grounded conductor 733. Relay 702 closes a circuit from ground through its armature and contact, outer right-hand armature and front contact of relay 703, inner left-hand armature and front contact of relay 707, inner left-hand armature and back contact of relay 709, conductor 737, left-hand winding of relay 838 to battery. Relay 838 operates and locks in a circuit from battery through its two windings in series, front contact and inner right-hand armature of relay 838 to the grounded conductor 733. As sequence switch 1210 moves out of position 12 $\frac{1}{2}$, it opens the circuit of relays 702 and 701 and these relays become deenergized. Relay 701

opens the holding circuit of relay 703 and this relay, on deenergizing, removes the shunt from around the winding of relay 709. Relay 709 thereupon energizes and locks in series with relay 708.

As the impulse sequence switch 1210 passes through positions $13\frac{3}{4}+14$, a circuit is closed from the positive pole of battery through the upper contact of spring 1200 ($15\frac{1}{4}+15\frac{1}{2}$), conductor 1224, thence to conductor 633, through the windings of relays 700, 701 and 702 in series, returning by way of conductor 654, to conductor 1168, lower contact of spring 1203 ($15\frac{1}{4}+15\frac{1}{2}$), conductor 1227, outer right-hand armature and contact of register relay 1410, conductor 1429, upper contact of spring 1213 ($15+15\frac{3}{4}$), conductor 1230, lower contact of spring 1127 (12), low resistance 1134 and thence to the negative pole of battery. Relays 701 and 702 again become operated and relay 701 closes a shunt circuit around the winding of relay 704, permitting relay 703 to remain energized and causing the release of relay 704. Relay 703 in the manner above described holds the shunt circuit closed around the winding of relay 711. Relay 702 closes a circuit from ground through its armature and contact, outer right-hand armature and front contact of relay 703, inner left-hand armatures and front contacts of relays 707 and 709, inner left-hand armature and back contact of relay 711, conductor 740, left-hand winding of relay 801, to battery. Relay 801 operates and locks in a circuit including its two windings. When sequence switch 1210 leaves position $13\frac{3}{4}$, it opens the circuit of relays 702 and 701. Relay 701 opens the circuit of relay 703 which becomes deenergized, and in turn, opens the shunt circuit around the winding of relay 711. Relay 711, therefore, operates and locks in series with relay 710. Three codes of impulses characterizing the designation of the terminating office have thus been transmitted and have caused the energization of the proper relays in each of the three groups designated, tandem hundreds, tandem tens and tandem units, to select lamps which will indicate this designation to the operator.

Relay 702 completes a circuit from ground through its contact and armature, outer right-hand armature and back contact of relay 703, outer left-hand armature and front contact of relay 707, outer left-hand armature and front contact of relay 709, outer left-hand armature and back contact of relay 711, conductor 739, left-hand winding of relay 800 to battery. Relay 800 energizes and locks in a circuit from battery through its two windings in series, contact and inner right-hand armature of said relay to the grounded conductor 733. When sequence switch 1210 leaves position 14 it opens the impulse circuit and relays 701 and 702 become deenergized. Relay 701 opens the shunt around the right-hand winding of relay 703 and this relay operates in series with relay 704.

Sequence switch 1210 in moving through positions $15\frac{1}{4}+15\frac{1}{2}$ completes a circuit

from the positive pole of battery through the upper contact of spring 1200 ($15\frac{1}{4}+15\frac{1}{2}$), conductor 1224, thence to conductor 633, through the windings of relays 700, 701 and 702 in series, returning by way of conductor 70 654, to conductor 1168, lower contact of spring 1203 ($15\frac{1}{4}+15\frac{1}{2}$), conductor 1227, outer right-hand armature and contact of register relay 1410, conductor 1429, upper contact of spring 1213 ($15+15\frac{3}{4}$), conductor 75 1230, lower contact of spring 1127 (12), low resistance 1134 and thence to the negative pole of battery. Relays 701 and 702 again 80 become operated and relay 701 closes a shunt circuit around the winding of relay 704, permitting relay 703 to remain energized and causing the release of relay 704. Relay 703 in the manner above described holds the shunt circuit closed around the winding 85 of relay 711. Relay 702 closes a circuit from ground through its armature and contact, outer right-hand armature and front contact of relay 703, inner left-hand armatures and front contacts of relays 707 and 709, inner left-hand armature and back contact of relay 711, conductor 740, left-hand winding of relay 801, to battery. Relay 801 operates and locks in a circuit including its two windings. When sequence switch 1210 90 leaves position $13\frac{3}{4}$, it opens the circuit of relays 702 and 701. Relay 701 opens the circuit of relay 703 which becomes deenergized, and in turn, opens the shunt circuit 95 around the winding of relay 711. Relay 711, therefore, operates and locks in series with relay 710. Three codes of impulses characterizing the designation of the terminating office have thus been transmitted and have 100 caused the energization of the proper relays in each of the three groups designated, tandem hundreds, tandem tens and tandem units, to select lamps which will indicate this designation to the operator.

The impulse sequence switch 1210 after 110 leaving position $15\frac{1}{2}$ advances into position 17 where a circuit is closed as follows for driving it into position 18: battery through the winding of the magnet of said sequence switch, lower right-hand contact of spring 1218 (17), upper contacts of spring 1124 115 (12), to ground. In position 18 of the impulse sequence switch the routing sequence switch 1120 is advanced into position 13 by means of a circuit from battery through the winding of the magnet of sequence switch 1120, lower right-hand contact of spring 1118 (12), conductor 1170, lower left-hand contact of spring 1220 (18), to ground. In position 13 of the routing sequence switch 120 a circuit is closed from battery through the winding of sequence switch magnet 1210, upper right-hand contact of spring 1219 (18), upper left-hand contact of spring 1125 125 (13), to ground. Sequence switch 1210 moves into position 1 and a circuit is closed 130

from battery through the winding of said sequence switch, lower left-hand contact of spring 1219 (1), conductor 1223, lower contacts of spring 1024 (16), contact and 5 inner right-hand armature of relay 1003, conductor 1079, contact of spring 1102 (1+7), to ground. The impulse sequence switch 1210 thereupon leaves position 1 and rotates into position 7 and from thence into 10 position 17 for the purpose of sending a second series of code impulses corresponding to the stations and numerical designation of the called subscriber's line in the desired office.

15 *Setting of call indicator in accordance with the numerical designation.*

As sequence switch 1210 passes through positions $1\frac{3}{4}+2$ a circuit is closed from the 20 positive pole of battery through the upper contact of spring 1200, conductor 1224, thence to conductor 633, winding of relays 700, 701 and 702, returning over conductor 634 to conductor 1168, lower contact of 25 spring 1203 ($1\frac{3}{4}+2$), conductor 1227, conductor 1228, high resistance 1133, thence over conductor 1056 to the opposite pole of battery. Due to the high resistance 1133, only the polarized relay 701 becomes 30 operated. Relay 701 causes the energization of relay 704 as above described. Relay 704 completes a circuit from the grounded conductor 733, outer right-hand armature and front contact of relay 704, right-hand armatures and front contacts of relays 707, 709 35 and 711, right-hand armature and back contact of relay 713, winding of relay 712 to battery. Relay 712 operates and closes a circuit for itself and the winding of relay 713. Relay 713 is shunted, however, and remains deenergized. As sequence switch 1210 40 leaves position 2 the shunt around the right-hand winding of relay 703 is removed and this relay operates in series with relay 704. Sequence switch 1210 in passing through 45 positions $3\frac{1}{4}+3\frac{1}{2}$ closes the impulse circuit in identically the same manner as last traced and relay 701 alone becomes energized. Relay 701, on operating, closes a circuit for the 50 left-hand winding of relay 703 in shunt of the winding of relay 704, causing this latter relay to become deenergized. Relay 703 also maintains the shunt around the winding of relay 713. As sequence switch 1210 leaves 55 position $3\frac{1}{2}$, it opens the circuit of relay 701 which permits the deenergization of relay 703. Relay 703, removing the shunt from the winding of relay 713, allows this latter 60 relay to operate and lock in series with relay 712.

Sequence switch 1210, on moving through positions $4+4\frac{1}{4}$, completes a circuit from the positive pole of battery through the lower contact of spring 1200 ($4+4\frac{1}{4}$), conductor 1168, thence to conductor 634, through the

windings of relays 702, 701 and 700 in series and returning to conductor 1224, lower contact of spring 1201 ($4+4\frac{1}{4}$), upper contact of said spring ($3\frac{3}{4}+4\frac{1}{2}$), conductor 1231, thence to conductor 1524 Fig. 15, back contact and outer left-hand armature of register relay 1515, front contact and left-hand armature of relay 1511, front contact and left-hand armature of relay 1512, conductor 1069, upper contact of spring 1207 75 ($3\frac{3}{4}+6$), upper contact of spring 1208 ($4+5\frac{3}{4}$), conductor 1232, upper contact of spring 1126 (13), high resistance 1135, low resistance 1134, conductor 1169 and thence to the opposite pole of battery. The current 80 flowing in this circuit is in the proper direction to cause the energization of relay 700, but relay 702 remains inoperative due to the inclusion of the high resistance 1135. Relay 700 completes a circuit from the grounded conductor 733, through the armature and contact of said relay, left-hand armature and back contact of relay 704, outer left-hand armatures and front contacts of relays 706, 708, 710 and 712 in series, outer left-hand armature and back contact of relay 714, conductor 742, left-hand winding of relay 802 to battery. Relay 802 operates and locks in a circuit from battery through its two windings in series, front contact and inner right-hand armature of said relay to the grounded conductor 733. As sequence switch 1210 moves out of position $4\frac{1}{4}$, relay 700 becomes deenergized.

The impulse sequence switch 1210 moving 95 through positions $4\frac{3}{4}+5$ completes a circuit from the positive pole of battery through the upper contact of spring 1200 ($4\frac{3}{4}+5$), conductor 1224, thence to conductor 633, through the windings of relay 700, 701 and 702 and returning to conductor 1168, lower contact of spring 1203 ($4\frac{3}{4}+5$), conductor 1227, conductor 1228, high resistance 1133, conductor 1056, thence to the opposite pole 100 of battery. Relay 701 operates, but relay 702 remains deenergized. Relay 701 closes the circuit hereinbefore traced for relay 704. Relay 704 completes a circuit from the grounded conductor 733, through the outer right-hand armature and front contact of 105 said relay, right-hand armatures and front contacts of relays 707, 709, 711 and 713, right-hand armature and back contact of relay 715, winding of relay 714 to battery. Relay 714 operates and closes a circuit for 110 itself and relay 715, but the latter relay remains deenergized due to the shunt around its winding. As sequence switch 1210 leaves 115 position 5, relay 701 deenergizes and permits the energization of relay 703.

In positions $6\frac{1}{4}$ to $6\frac{1}{2}$ of sequence switch 1210, the impulse circuit is established over the identical path last traced and relay 701 again becomes energized. Relay 701 this 120 time closes a shunt circuit around the wind- 125

ing of relay 704, which relay becomes de-energized. The shunt around the winding of relay 715, however, is still maintained through the contact and inner right-hand armature of relay 703. In leaving position $6\frac{1}{2}$, sequence switch 1210 opens the circuit of relay 701, which in turn, opens the circuit of relay 703. Relay 703 becomes de-energized and opens the shunt around the winding of relay 715, which latter relay operates and locks in series with relay 714.

In position $7\frac{3}{4}+8$ of sequence switch 1210 a circuit is closed from the positive pole of battery through the upper contact of spring 1200 ($7\frac{3}{4}+8$), conductor 1224, thence to conductor 633, through relays 700, 701 and 702 and returning by way of conductor 634 to conductor 1168, lower contact of spring 1203 ($7\frac{3}{4}+8$), conductor 1227, conductor 1228, high resistance 1133, conductor 1056 to the opposite pole of battery. Relay 701 operates and closes the circuit previously traced for relay 704. Relay 704 completes a circuit from the grounded conductor 733, through the outer right-hand armature and contact of said relay, right-hand armatures and front contacts of relays 707, 709, 711, 713 and 715 in series, right-hand armature and back contact of relay 717, winding of relay 716 to battery. Relay 716 operates and prepares a holding circuit for itself in series with the winding of relay 717. Relay 717, however, remains inoperative since its winding is shunted at this time. In leaving position 8, sequence switch 1210 opens the impulse circuit and relay 701 deenergizes to in turn permit the energization of relay 703 in series with relay 704.

In position $8\frac{1}{2}+8\frac{3}{4}$ of sequence switch 1210 a circuit is closed from the positive pole of battery, through the lower contact of spring 1200 ($8\frac{1}{2}+8\frac{3}{4}$), conductor 1168, thence to conductor 634 through the windings of relays 702, 701 and 700, conductor 633 and returning to conductor 1224, lower contact of spring 1201 ($8\frac{1}{2}+8\frac{3}{4}$), contact of spring 1202 ($8\frac{1}{2}+9$), conductor 1233, thence to conductor 1528 Fig. 15, contact and right-hand armature of register relay 1508, back contact and left-hand armature of relay 1509, front contact and left-hand armature of relay 1510, conductor 1071, lower contact of spring 1206 ($6\frac{3}{4}+9$), upper contact of spring 1208 ($7+8\frac{3}{4}$), conductor 1232, upper contact of spring 1126 (13), high resistance 1135, low resistance 1134, conductor 1169 and thence to the negative pole of battery. The polarity of current in this circuit is such as to cause the operation of relay 700, but due to the high resistance 1135, relay 702 remains inoperative. Relay 700 completes a circuit from the grounded conductor 733, armature and contact of relay 700, left-hand armature and front contact of relay 704, inner left-hand armatures and front contacts of relays

708, 710, 712, 714 and 716 in series, inner left-hand armature and back contact of relay 718, conductor 743, left-hand winding of relay 803 to battery. Relay 803 operates and closes a circuit from battery through its two windings in series, contact and inner right-hand armature of said relay to the grounded conductor 733. As sequence switch 1210 leaves position $8\frac{3}{4}$, it opens the impulse circuit and relay 700 deenergizes.

In position $9\frac{1}{2}+9\frac{1}{2}$ of sequence switch 1210 a circuit is established from the positive pole of battery through the upper contact of spring 1200, conductor 1224, through the windings of relays 700, 701 and 702 and returning by way of conductor 634 to conductor 1168, lower contact of spring 1203 ($9\frac{1}{2}+9\frac{1}{2}$), conductor 1227, conductor 1228, high resistance 1133, conductor 1056 to the negative pole of battery. Relay 701 operates in this circuit and closes a holding circuit for the left-hand winding of relay 703 in shunt of the relay 704. Relay 704 becomes de-energized, but the shunt around the winding of relay 717 is still maintained through the inner right-hand armature and contact of relay 703. When sequence switch 1210 leaves position $9\frac{1}{2}$ it opens the impulse circuit and relay 701 deenergizes to permit the release of relay 703. The de-energization of relay 703 causes the opening of the shunt circuit around the winding of relay 717 and this relay operates and locks in series with relay 716.

In position $10\frac{3}{4}+11$ of sequence switch 1210, a circuit is closed from the positive pole of battery through the upper contact of spring 1200, conductor 1224, thence over the path previously traced through the windings of relays 700, 701 and 702 and returning to conductor 1168, through the lower contact of the spring 1203 ($10\frac{3}{4}+11$), conductor 1227, conductor 1228, high resistance 1133, conductor 1056, and thence to the opposite pole of battery. Relay 701 becomes energized and relay 702 remains inert. Relay 701 closes the previously traced circuit for relay 704 and relay 703 remains de-energized. Relay 704 closes a circuit from the grounded conductor 733, through the outer right-hand armature and contact of relay 704, left-hand armatures and front contacts of relays 707, 709, 711, 713, 715 and 717 in series, right-hand armature and back contact of relay 719, winding of relay 718 to battery. Relay 718 operates and closes a holding circuit for itself in series with relay 719, but relay 719 cannot operate due to the shunt around its winding closed through the armature and contact of relay 704. As sequence switch 1210 leaves position 11, it opens the circuit of relay 701 which becomes de-energized and permits the energization of relay 703.

As sequence switch 1210 passes through

- position $11\frac{1}{2}+11\frac{3}{4}$ a circuit is closed from the positive pole of battery through the lower contact of spring 1200 ($11\frac{1}{2}+11\frac{3}{4}$), conductor 1168, thence over the impulse circuit 5 through the windings of relays 701, 702 and 700 and returning over the opposite side of the impulse circuit to conductor 1224, lower contact of spring 1201 ($11\frac{1}{2}+11\frac{3}{4}$), contact of spring 1202 ($11\frac{1}{4}+12$), conductor 1233, 10 thence to conductor 1425 Fig. 14, contact and right-hand armature of register relay 1415, back contact and left-hand armature of relay 1407, front contact and left-hand armature of relay 1408, conductor 1074, 15 upper contact of spring 1206 ($9\frac{3}{4}+12$), upper contact of spring 1208 ($10+11\frac{3}{4}$), conductor 1232, upper contact of spring 1126 (13), high resistance 1135, low resistance 1134, conductor 1169 and thence to the negative pole of battery. Current in this circuit is in the proper direction to cause the energization of relay 700, but due to the high resistance the marginal relay 702 cannot operate. Relay 700 completes a circuit from 20 the grounded conductor 733 through its armature and contact, left-hand armature and front contact of relay 704, inner left-hand armatures and front contacts of relays 708, 710, 712, 714, 716 and 718, left-hand armature and back contact of relay 720, conductor 744, left-hand winding of relay 804 to battery. Relay 804 operates and closes a holding circuit for itself from battery through its two windings in series, contact 25 and inner right-hand armature of said relay to the grounded conductor 733. As sequence switch 1210 leaves position $11\frac{3}{4}$, relay 700 deenergizes.
- In position $12\frac{1}{4}+12\frac{1}{2}$ of sequence switch 40 1210 a circuit is closed from the positive pole of battery through the upper contact of sequence switch spring 1200 ($12\frac{1}{4}+12\frac{1}{2}$), conductor 1224, thence over the path previously traced through the windings of relays 700, 701 and 702 and returning by way of conductor 634 to conductor 1168, lower contact of spring 1203 ($12\frac{1}{4}+12\frac{1}{2}$), conductor 1227, conductor 1228, high resistance 1133, conductor 1056 and thence as previously traced 45 to the negative pole of battery. Relay 701 operates and in so doing closes a circuit for the left-hand winding of relay 703 in shunt of the winding of relay 704. Relay 704 deenergizes, but the shunt circuit around the winding of relay 719 is still maintained through the inner left-hand armature and contact of relay 703. Upon sequence switch 50 1210 leaving position $12\frac{1}{4}$, it opens the impulse circuit and relay 701 becomes deenergized to permit the deenergization of relay 703. Since both relays 703 and 704 are deenergized, the shunt around the winding of relay 719 is opened and this relay operates in series with relay 718.
- In position $13+13\frac{1}{4}$ of sequence switch 55 60 65 70 75 80 85 90 95 100 105 110 115 120 125 130
- 1210 a circuit is established from the positive pole of battery through the lower contact of spring 1200 ($13+13\frac{1}{4}$), conductor 1168, thence to conductor 634 through the windings of relays 702, 701 and 700, conductor 633 and thence to conductor 1082, lower contact of spring 1204 ($13+13\frac{1}{4}$), conductor 1234, thence to conductor 1426 Fig. 14, front contact and outer left-hand armature of relay 1404, front contact and left-hand armature of relay 1405, front contact and left-hand armature of relay 1406, conductor 1075, contact of spring 1205 ($12\frac{3}{4}+15$), upper contact of spring 1208 ($13+14\frac{3}{4}$), conductor 1232, upper contact of spring 1126, high resistance 1135, low resistance 1134 and thence to the opposite pole of battery. Current in this circuit is in such a direction as to cause the operation of relay 700 alone. Relay 700 operates and completes a circuit from grounded conductor 733 through its armature and contact, left-hand armature and back contact of relay 704, left-hand armature and front contact of relay 706, outer left-hand armatures and front contacts of relays 708, 710, 712, 714, 716 and 718, conductor 745, left-hand winding of relay 805 to battery. Relay 805 operates and locks up through its two windings to the grounded conductor 733. As sequence switch 1210 leaves position $13\frac{1}{4}$, relay 700 becomes deenergized.
- In position $13\frac{3}{4}+14$ of the impulse sequence switch, a circuit is established from the positive pole of battery through the upper contact of spring 1200 ($13\frac{3}{4}+14$), conductor 1224, thence to conductor 633, through the windings of relays 700, 701 and 702 in series, conductor 634, returning to conductor 1168, through the contact of spring 1204 ($13\frac{3}{4}+14$), conductor 1234, thence to conductor 1426, Fig. 14, front contact and outer right-hand armature of register relay 1404, front contact and left-hand armature of relay 1405, front contact and left-hand armature of relay 1406, conductor 1075, contact of spring 1205 ($12\frac{3}{4}+15$), lower contact of spring 1208 ($13\frac{3}{4}+14$), conductor 1235, upper contact of spring 1128 (13), low resistance 1134, conductor 1169, to the negative pole of battery. The flow of current in this circuit is in such a direction as to cause the operation of relay 701 and being strong in character also causes the energization of relay 702. Relay 701 completes the circuit hereinbefore traced for the operation of relay 704. Relay closes a circuit from the grounded conductor 733, through the outer right-hand armature and contact of said relay, right-hand armatures and front contacts of relays 707, 709, 711, 713, 715, 717 and 719 in series, inner right-hand armature and contact of relay 721, winding of relay 720 to battery. Relay 720 operates and prepares a series circuit for itself and relay 721,

but this latter relay cannot operate due to the shunt upon its circuit closed through the armature and contact of relay 704. Relay 702, on operating, completes a circuit from ground through its armature and contact, outer right-hand armature and back contact of relay 703, outer left-hand armatures and contacts of relay 707, 709, 711, 713, 715, 717 and 719, conductor 746, left-hand winding of relay 806 to battery. Relay 806 becomes energized and closes a locking circuit including its two windings and the grounded conductor 783. As sequence switch 1210 leaves position 14 the impulse circuit is opened and relays 701 and 702 become deenergized. Relay 701 opens the shunt around the right-hand winding of relay 703 and this relay becomes energized in series with relay 704.

20. In position $15\frac{1}{4} + 15\frac{1}{2}$ of the impulse sequence switch 1210, a circuit is closed from the positive pole of battery through the upper contact of spring 1200 ($15\frac{1}{4} + 15\frac{1}{2}$), conductor 1224 and thence to conductor 633, through the windings of relays 700, 701 and 702, conductor 634 and returning to conductor 1168, lower contact of spring 1203 ($15\frac{1}{4} + 15\frac{1}{2}$), conductor 1227, conductor 1228, high resistance 1133, conductor 1056 and thence to the negative pole of battery. Relay 701 alone operates in this circuit and in so doing closes a circuit through the left-hand winding of relay 703 in shunt of the winding of relay 704. Relay 704 deenergizes, but the shunt circuit around the winding of relay 721 is maintained through the inner right-hand armature and contact of relay 703. When sequence switch 1210 finally leaves position $15\frac{1}{2}$, it opens the impulse circuit and relay 701 becomes deenergized, in turn, permitting the deenergization of relay 702. With both relays 703 and 704 deenergized, the shunt around the winding of relay 721 is opened and this relay operates in series with relay 720.

Release of the register sender.

Before proceeding to describe the further operation at the sub-tandem office in connection with the selection and illumination of the proper indicator lamps and the acts performed by the operator in response to the designation displayed, the restoration of the register sender and associated equipment at the tandem switching office will be considered. Immediately that the impulse sequence switch 1210 arrives in position 17, a circuit is closed from battery through the left-hand winding of relay 903 Fig. 9, left-hand contact of spring 936 (8), brush 965, terminal 959, conductor 1050, upper left-hand contact of spring 1325 ($5\frac{3}{4} + 12$), lower left-hand contact of spring 1324 (11), resistance 1046, upper contacts of spring 1040 (16), conductor 1083, lower contacts of

spring 1124 (13), lower left-hand and upper right-hand contacts of spring 1221 (17), to ground. Relay 903 becomes energized and in the same manner as hereinbefore described drives the sequence switch 910 out of position 8 and into position 9, causing the deenergization of relay 1300 and also causing the energization of relay 204 of the district selector to advance sequence switch 210 out of position 11 and into position 12. As hereinbefore seen, the advance of the district selector sequence switch 210 brings about the release of the trunk selector 920 and the sender selector 940. Upon the deenergization of relay 1300 a circuit is completed from battery through the winding of sequence switch magnet 1310, lower right-hand contact of spring 1307 (2+17), back contact and right-hand armature of relay 1300 to ground. Sequence switch 1310 leaves position 11 and moves into position 18. The sender sequence switch 1010 is restored to its normal position in the manner already described, as soon as sequence switch 1310 moves from position 12 into position 13. With the sender sequence switch 1010 in position 1 and sequence switch 1310 in position 18 a circuit is closed from battery through the winding of the impulse sequence switch 1210, upper left-hand contact of spring 1219 (2+18), conductor 1236, lower contacts of spring 1040 (17+1), upper contacts of spring 1323 (13+18), to ground. In position 1 of sequence switch 1210 a circuit is closed from battery through the winding of sequence switch magnet 1120, upper right-hand contact of spring 1118 (2+18), contacts of spring 1218 (1), conductor 1236, lower contacts of spring 1040 (17+1), upper contacts of spring 1323 (13+18), to ground. Sequence switch 1120 moves out of position 13 and into position 1. A circuit is therewith closed from battery through the winding of sequence switch magnet 1310, contacts of spring 1306 (18), left-hand contacts of spring 1036 (1), conductor 1076, lower right and upper left-hand contacts of spring 1221 (1), lower left-hand contact of spring 1125 (1), to ground, driving sequence switch 1310 out of position 18 and into position 1.

As sequence switch 1310 left position 12 it opened the holding circuits of all energized register relays, permitting them to release. The register sender has thus been completely restored to its normal condition.

Display of the designation on the call indicator lamps and extension of the connection to the terminating office.

When the last of the code impulses have been received from the tandem switching office and the last two progression relays 720 and 721 are operated, the designation

is at once displayed on the indicator lamps before the operator in the sub-tandem office. The designation of the called office in which the wanted subscriber's line 600 terminates is represented by the lamps 747, 807 and 808. These lamps bear the ordinals 2, 5 and 7, respectively, whereby the code number identifying the called office is 257. As hereinbefore explained these tandem lamps 10 might be labelled with letters of the alphabet and so selected that the three letters displayed would be an abbreviation of the name of the called office.

At the time relay 712 operates a circuit is 15 closed from battery through the winding of relay 729, contact and outer right-hand armature of relay 712 to ground. Later, when relay 718 becomes operated a circuit is closed from battery through the winding of 20 relay 730, contact and outer right-hand armature of relay 718 to ground. Again when relay 721 becomes operated another circuit is closed from battery through the winding of 25 relay 728, contact and left-hand armature of relay 721 to ground. Relays 728, 729 and 730 are operated in these circuits and serve to provide circuits for the illumination of the selected lamps.

The circuit for the illumination of lamp 30 747 may be traced from battery through the right-hand armature and contact of relay 710, conductor 748, outer left-hand armature and back contact of relay 750, left-hand armature and front contact of relay 735, inner left-hand armature and back contact of 35 relay 751, through the lamp 747, front contact and outer right-hand armature of relay 735, outer left-hand armature and contact of relay 751, back contact and outer right-hand armature of relay 752, conductor 749, 40 contact and outer right-hand armature of relay 708 to ground.

The circuit for the display of the tandem tens lamp 807 may be traced from battery 45 through the inner right-hand armature and contact of relay 729, conductor 754, through the lamp 807, back contact and left-hand armature of relay 813, back contact and outer right-hand armature of relay 814, back contact and left-hand armature of relay 815, front contact and inner right-hand armature 50 of relay 838, to ground, over conductor 733. The circuit for the illumination of the tandem units lamp 808 may be traced from battery through the outer right-hand armature and contact of relay 729, conductor 755, 55 through the lamp 808, back contact and inner left-hand armature of relay 816, front contact and left-hand armature of relay 800, front contact and inner right-hand armature 60 of relay 801 to the grounded conductor 733.

It will be recalled that the called subscriber's line 600 was assumed to be at an ordinary direct line, no provision being

necessary for party selective ringing. Accordingly, none of the stations relays 756, 757, 758 and 759 have been operated. With all of these relays deenergized a circuit is established from battery through the lamp 760 contact and outer right-hand armature of relay 756, contacts and left-hand armatures of relays 756, 757, 758 and 759 in series, conductor 761, outer right-hand armature and contact of relay 716, to ground, over conductor 733. The illuminated lamp 760 which bears the ordinal 0 informs the operator that party ringing is unnecessary.

It will further be recalled that the numerical designation of the called line as originally set up on the operator's keyboard is 2 4 4 3. Hence, the codes of impulses corresponding to the numerical designation have selected the proper relays for causing the illumination of the No. 2 thousands lamp 809, the No. 4 hundreds lamp 810, the No. 4 tens lamp 811 and the No. 3 units lamp 812. The circuit for lamp 809 is traceable from battery through the outer left-hand armature and contact of relay 730, conductor 762, outer left-hand armature and back contact of relay 818, left-hand armature and back contact of relay 819, outer right-hand armature and front contact of relay 802, through the lamp 809, contact and outer right-hand armature of relay 818 to the grounded conductor 733. The circuit for the illumination of lamp 810 may be followed from battery through the inner left-hand armature and contact of relay 730, conductor 763, outer left-hand armature and back contact of relay 820, inner left-hand armature and back contact of relay 821, outer right-hand armature and back contact of 90 relay 822, left-hand armature and front contact of relay 803, through the lamp 810, front contact and outer right-hand armature of relay 803, conductor 764, contact and outer right-hand armature of relay 730 to the grounded conductor 733. The circuit for lamp 811 may be traced from battery through the contact and middle right-hand armature of relay 720, conductor 771, outer left-hand armature and back contact of relay 823, left-hand armature and back contact of relay 824, outer right-hand armature and back contact of relay 823, left-hand armature and front contact of relay 804, through the lamp 811, front contact and outer right-hand armature of relay 804, conductor 770, outermost right-hand armature and contact of relay 720 to the grounded conductor 733. The circuit for lamp 812 may be traced from battery through the middle right-hand armature and contact of relay 721, conductor 772, outer left-hand armature and back contact of relay 826, left-hand armature and front contact of relay 806, inner left-hand armature and front contact of relay 805, through the lamp 812, back contact and in-

ner right-hand armature of relay 826 to the grounded conductor 733.

At the time relay 721 operated it closed a circuit from ground through its left-hand armature and contact, armature and contact of relay 727, winding of relay 724 to battery. Relay 724 becomes energized and opens the circuit of relay 614. Relay 614 becomes deenergized and disconnects the incoming conductors 333 and 334 from the conductors 633 and 634 leading to the call indicator mechanism and extends said incoming conductors through to the windings of relay 616. Provided the originating operator in the office illustrated in Fig. 1 had inserted the plug 105 of her cord circuit in the jack 106 of the assigned trunk 115 116 prior to the time the district selector sequence switch 210 reached position 12, relay 200 being operated at the time said sequence switch moved into such position closed a circuit for relay 201, which in turn, caused the advance of the sequence switch 210 into the talking position, position 13. Consequently, upon the deenergization of relay 614, the relay 616 is operated in a circuit from battery through its right-hand winding, normal contacts of the right-hand armature of relay 615, conductor 601, back contact and inner armature of relay 614, conductor 333, thence over the upper side of the talking circuit through the windings of polarized relay 113 in the originating office and returning over the lower side of the talking circuit to conductor 334, outer armature and back contact of relay 614, normal contacts and left-hand armature of relay 615, through the left-hand winding of relay 616 to ground. Relay 616 operates, but the flow of current is in such a direction as not to cause the operation of the polarized relay 113.

The operator in the sub-tandem office observing the designation displayed before her on the indicator lamps communicates by means of an order wire (not shown) with the operator in the particular terminating office represented by the code on the tandem lamps and requests the assignment of an idle trunk. The terminating operator assigns the trunk 605, 606 for use and notifies the sub-tandem operator of its identity. At her convenience the operator in the sub-tandem office seizes the plug 603 of the trunk circuit and inserts it in the jack 604 of the assigned trunk 605 606 leading to the terminating office. The insertion of the plug in the jack completes a circuit from battery through the winding of relay 627, sleeve of plug 603, sleeve of jack 604, to ground. Relay 627 at its outer left-hand armature and back contact opens the circuit of relay 621 which becomes deenergized and opens the interrupting circuit of the assignment lamp 623. Relay 627 at its inner

right-hand armature and back contact opens the holding circuit of relay 617 and 723. Relay 723 becomes deenergized and removes ground from the conductor 733 which permits the deenergization of all operated relays in the call indicator mechanism and the consequent extinguishment of the indicator lamps. Relay 617 also becomes deenergized and opens the circuit of relay 614 to prevent the reenergization of this relay, when relay 724 in the call indicator mechanism retracts its armatures. Relay 616, on operating in series with the talking circuit, closes a circuit from battery through the winding and front contact and inner left-hand armature of relay 618, contact and armature of relay 616, to ground. This circuit maintains the energization of relay 618, but shunts out the relay 619 which up to this time has been operated in series with relay 618. Consequently, relay 619 becomes deenergized.

The insertion of plug 603 in the jack 604 also completes a circuit from battery through the left-hand winding of relay 628 at the terminating office, contact and outer armature of relay 629, conductor 605, tip of jack 604, tip of plug 603, outer right-hand armature and contact of relay 627, conductor 601, contact and inner right-hand armature of relay 618, winding of relay 625, conductor 602, ring of plug 603, ring of jack 604, inner armature and contact of relay 629, through the right-hand winding of relay 628, to ground. Relay 625 becomes operated and closes a circuit from battery through the winding of relay 626, front contact and armature of relay 625, contact and inner left-hand armature of relay 627, front contact and outer right-hand armature of relay 618, to ground. Relay 626 operates and closes a holding circuit for itself from battery through its winding and contact and right-hand armature and thence to ground through the contact and inner left-hand armature of relay 627 and the front contact and outer right-hand armature of relay 618.

The terminating operator having received orally the number of the called subscriber's line 600 seizes the plug 612 of the cord in which terminates the trunk which she assigned and inserts it in the jack 613 of the line. A circuit is closed from battery through the winding of relay 637, contact and outer armature of relay 632, sleeve of plug 612, sleeve of jack 613 to ground. Relay 637 operates and closes the circuit for the illumination of the supervisory lamp 638. The terminating operator by means of the usual ringing key (not shown in this disclosure) applies ringing current to the called subscriber's line. When the called subscriber answers, a circuit for the supervisory relay 632 is established and this re-

lay operates to open the circuit of relay 637 causing the extinguishment of lamp 638. Relay 632 also closes a circuit from battery through the winding of relay 629, contact 5 and left-hand armature of relay 632 to ground. Relay 629 actuates and disconnects battery current from the trunk conductors 605 and 606 whereby relay 625 at the sub-tandem office retracts its armature. 10 Upon the deenergization of relay 625, a circuit is closed from battery through the winding of relay 615, left-hand armature and contact of relay 626, back contact and armature of relay 625, contact and inner left- 15 hand armature of relay 627, front contact and outer right-hand armature of relay 618 to ground. Relay 615 operates and reverses the direction of current through the windings of the polarized relay 113 in the originating office. Relay 113 attracts its armature and shunting out the right-hand winding of relay 114 permits the energization of 20 relay 107, which in turn, causes the extinguishment of lamp 108 as previously explained. The originating operator is thereby notified that the called subscriber has answered.

At the completion of conversation the called subscriber replaces his receiver to the 25 switchhook, causing the deenergization of relay 632, and consequently, the energization of relay 625. Relay 625 releases relay 615 which reverses current over the talking circuit through the polarized relay 113. Relay 113 deenergizes and the originating operator is given the disconnect signal. From this point, the restoration of the switches in the tandem switching office proceeds in the manner already described in detail. As 30 soon as the talking circuit is opened by the deenergization of relay 114 when the originating operator removes the plug 105 from the jack 106, relay 616 becomes deenergized and opens the holding circuit of relay 618. 35 A circuit is then closed from battery through the outer left-hand armature and front contact of relay 627, lamp 624, back contact and outer right-hand armature of relay 618 to ground. The illumination of the lamp 624 40 notifies the operator at the sub-tandem office that conversation has been completed. She thereupon seizes the plug 603 and withdraws it from the jack 604 and relays 626 and 627 become deenergized.

55 What is claimed is:

1. In a telephone system, connecting circuits, automatic selective switches having access to said circuits, a variably operable switch controlling register, means for setting said register in accordance with designations, means controlled in accordance with the setting of said register for operating said switches to select one of said connecting circuits, a second variably operable switch controlling register, means effective when cer-

tain designations are registered on said first register for setting the second register in accordance with such designations, means controlled in accordance with the setting of one of said registers for operating said switches 70 to select another of the connecting circuits, a selective mechanism, and means controlled over said last connecting circuit in accordance with the setting of the other of said registers for operating said selective mechanism. 75

2. In a telephone system, connecting circuits, automatic selective switches having access to said circuits, a variably operable switch controlling register, means for setting said register in accordance with designations, means controlled in accordance with the setting of said register for operating said switches to select one of said connecting circuits, a second variably operable 80 switch controlling register, means controlled by said first register when certain designations are registered thereon for setting the second register in accordance with the setting of such first register, means controlled in accordance with the setting of one of said registers for operating the selective switches to select another of the connecting circuits, a selective mechanism, and means controlled over said last connecting circuit in accordance with the setting of the other of said registers for operating said selective mechanism. 85

3. In a telephone system, connecting circuits, automatic selective switches having access to said circuits, a variably operable switch controlling register, means for setting said register in accordance with designations, means controlled in accordance with said register for operating said switches to select one of the connecting circuits, a second variably operable switch controlling register, means rendered effective only when certain designations are registered on said first register for setting the second register in accordance with the setting of such first register, means controlled in accordance with the setting of one of said registers for operating said switches to select another of the connecting circuits, a selective mechanism, and means controlled over said last connecting circuit in accordance with the setting of the other of said registers for operating said selective mechanism. 100

4. In a telephone system, connecting circuits, automatic selective switches having access to said circuits, a variably operable register, means for setting said register in accordance with designation, means controlled in accordance with the setting of said register for operating said switches to select one of said connecting circuits, a secondary variably operable register arranged to be set from said first register, means effective when certain designations are registered on the 105 110 115 120 125 130

first register for rendering the second register inoperative, means effective when a particular designation is registered on the first register for setting the second register in accordance with the setting of said first register, means controlled in accordance with the setting of one of said registers for operating said switches to select another of the connecting circuits, a selective mechanism, and means controlled over said last connecting circuit in accordance with the setting of the other of said registers for operating said selective mechanism.

5. In a telephone system, connecting circuits, automatic switches having access to said circuits, a plurality of variably operable registers, means for setting said registers in accordance with designations, means controlled in accordance with the setting of said registers for operating the selective switches to select one of said connecting circuits, a secondary variably operable register, means effective when certain designations are registered on said first mentioned registers for setting the secondary register in accordance with such designations, means controlled in accordance with the setting of said secondary register for operating the selective switches to select another of the connecting circuits, a selective mechanism, and means controlled over said last connecting circuit in accordance with the setting of said first mentioned register for operating said selective mechanism.

35. 6. In a telephone system, connecting circuits, automatic selective switches having access to said circuits, a plurality of variably operable registers, means for setting said registers in accordance with designations, means controlled in accordance with the setting of said registers for operating the selective switches for selecting one of said connecting circuits, a secondary variably operable register, means effective when certain designations are registered on said first mentioned registers for setting the secondary register in accordance with the setting of a particular one of said first mentioned registers, means controlled in accordance with the setting of said secondary register for operating the selective switches to select another of the connecting circuits, a selective mechanism at the distant end of such connecting circuit and means controlled over said last mentioned connecting circuit in accordance with the setting of said first mentioned registers for operating said selective mechanism.

7. In a telephone system, connecting circuits, automatic selector switches having access to said circuits, a register consisting of a plurality of relays, means for variably operating said relays to set the register in accordance with designations, means controlled in accordance with the setting of said

register for operating the selective switches to select one of said connecting circuits, a second register consisting of a plurality of variably operable relays, means effective when certain designations are registered on said first register for operating the relays of said second register to set the same in accordance with the setting of such first register, means controlled in accordance with the setting of one of said registers for operating the selective switches to select another of the connecting circuits, a selective mechanism and means controlled over the last connecting circuit in accordance with the setting of the other of said registers for operating said selective mechanism.

8. In a telephone system, an office, a plurality of trunks outgoing from said office, automatic selective switches for extending connections over said trunks, a register sender in said office for controlling said switches and including a variably operable register, means for setting said register to correspond to designations, means operable in accordance with the setting of said register for controlling the movement of the automatic switches to select an outgoing trunk, a second variably operable register, means effective when said first register is set to correspond to a particular designation to set the second register in accordance with the setting of such first register, means operable in accordance with the setting of one of said registers for controlling the automatic switches to select another of the outgoing trunks, a selective mechanism at the distant end of the last named trunk, and means controlled over such trunk for operating the selective mechanism in accordance with the setting of the other of said registers.

9. In a telephone system, an office, a plurality of distant offices, trunks leading from said first office to each of said distant offices, selective switches in the first office for extending connections over said trunks, a variably operable register, means for setting said register to correspond to the designation of one of said distant offices, means controlled by the register for operating the selective switches to select a trunk to such office, a second variably operable register, means effective when the first register is set to correspond to the designation of a particular one of the distant offices to set said second register in accordance with such designation, means controlled by one of the registers for operating the selective switches to select a trunk to said particular office, selectively operable devices in such particular office, and means controlled by the other of said registers over the trunk for operating the selective devices in said particular office.

10. In a telephone system, trunk circuits,

- automatic selective switches having access to said trunks, a variably operable register, means for setting said register in accordance with designations, means controlled by said register in accordance with the setting thereof for operating selective switches to select one of said trunks, a second variable operable register, means effective when certain designations are registered on said first 5
- register for setting the second register in accordance with the setting of said first register, means controlled by said second register in accordance with the setting thereof for operating the selective switches 10 to select another of said trunks, a selective mechanism and means controlled over said last trunk by said first register in accordance with the setting thereof for operating said selective mechanism. 15
11. In a telephone system, a plurality of trunks, automatic selective switches having access to said trunks, a plurality of primary registers each consisting of a group of relays, means for variably setting said registers in accordance with designations, means controlled by said registers in accordance 20 with the setting thereof for operating the selective switches to select one of said trunks, a secondary register consisting of a group of relays, means effective when certain designations are registered on said primary registers for setting said secondary register in accordance with the setting of such primary registers, means controlled in 25 accordance with the setting of said secondary register for operating the selective switches to select another of said trunks, a selective mechanism at the distant end of said last mentioned trunk and means controlled by said primary registers in accordance 30 with the setting thereof over the last mentioned trunk for operating said selective mechanism. 35
12. In a telephone system, an office and an operator's position therein, outgoing trunks, selective switches for extending connections over said trunks, a keyboard at the operator's position for recording designations, a variably operable register, means 40 for setting said register to correspond to the designations recorded on the keyboard, means controlled by said register in accordance with the setting thereof for operating the selective switches to select one of the 45 outgoing trunks, a second variably operable register, means effective when said first register is set in accordance with certain designations to set said second register to correspond to such designations, means controlled by one of said registers in accordance with the setting thereof for operating said switches to select another of the outgoing trunks, a selective mechanism and means controlled over said last mentioned 55 trunk by the other of said registers in accordance with the setting thereof for operating 60
13. In a telephone system, an office and an operator's position therein, outgoing trunks, selective switches for extending connections over said trunks, a keyboard at the operator's position for recording designations, a variably operable register, means for setting said register to correspond to the designations recorded on the keyboard, means controlled by said register in accordance with the setting thereof for operating the selective switches to select one of the outgoing trunks, a second variably operable register, means effective when said first register is set in accordance with certain designations to set said second register to correspond to such designations, means controlled by said second register in accordance with the setting thereof for operating said selective switches to select another of the outgoing trunks, an indicating mechanism and means controlled over said last trunk by said first register in accordance with the setting thereof for operating said indicating mechanism. 70 75 80 85 90
14. In a telephone system, trunk circuits, automatic selective switches having access to said trunks, a variably operable register, means for setting said register in accordance with designations, means controlled in accordance with the setting of said register for operating said switches to select one of said trunks, a register setting device, a second register, means effective when certain 95 designations are registered on said first register for operating the register setting device in accordance with the setting of such first register, means for setting said second register in accordance with the operation of said register setting device, means controlled in accordance with the setting of one of said registers for operating said switches to select another of the trunk circuits, a selective mechanism and means controlled over the last trunk circuit in accordance with the setting of the other of said registers for operating said selective mechanism. 100 105 110
15. In a telephone system, a plurality of trunks, automatic selective switches having access to said trunks, a variably operable register, means for setting said register to correspond to the designations recorded on the keyboard, means controlled by said register in accordance with the setting thereof for operating the selective switches to select one of the outgoing trunks, a second variably operable register, means effective when certain designations are registered on said first register for operating said routing switch to a position corresponding to the setting of said first register, means for setting said second register in accordance with the position taken by said routing switch, means controlled in accordance with the setting of one of said registers for operating 115 120 125 130

said selective switches to select another of said trunks, a selective mechanism and means controlled over said last trunk in accordance with the setting of the other of said registers for operating said selective mechanism.

16. In a telephone system, a plurality of trunks, selective switches having access to said trunks, a plurality of variably operable registers, means for setting said registers to correspond with designations, means controlled in accordance with the setting of said registers for operating the selective switches to select one of said trunks, a multi-position routing switch, a secondary variably operable register, means effective when certain designations are registered on said first registers for operating said routing switch to a position corresponding to the setting of a particular one of such registers, means for setting said secondary register in accordance with the position taken by said routing switch, means controlled in accordance with the setting of said secondary register for operating the selective switches to select another of said trunks, a selective mechanism, and means controlled over said last trunk in accordance with the setting of said first register for operating said selective mechanism.

17. In a telephone system, an office, a first called office, a tandem office, a second called office, trunks interconnecting said first mentioned office with said first called office, trunks interconnecting the first mentioned office with said tandem office, selective switches at said first office for extending connections over said trunks, a variably operable register and means for setting the same, means when said register is set in accordance with the designation of the first called office for controlling the selective switches to select a trunk to such office, a second variably operable register, means when the first register is set in accordance with the designation of the second called office to set said second register to correspond with such designation, means controlled by one of said registers for operating the selective switches to select a trunk to the tandem office, an indicating device at the tandem office, means controlled over the trunk by the other of said registers for operating the indicating device to indicate the designation of said second called office, and means for extending a connection from the tandem office to said second called office.

18. In a telephone system, an office, a first called office, a tandem office, a second called office, trunks interconnecting said first mentioned office with said first called office, trunks interconnecting the first mentioned office with said tandem office, selective switches at said first office for extending connections over said trunks, a variably oper-

able register and means for setting the same, means when said register is set in accordance with the designation of the first called office for controlling the selective switches to select a trunk to such office, a second variably operable register, means when the first register is set in accordance with the designation of the second called office to set said second register in accordance with such designation, means controlled by said second register for operating the selective switches to select a trunk to the tandem office, an indicating device at the tandem office, means controlled over the trunk by said first register for operating the indicating device to indicate the designation of said second called office, and means for extending a connection from the tandem office to said second called office.

19. In a telephone system, an office, a first called office, a tandem office, a second called office, trunks interconnecting said first mentioned office with said first called office, trunks interconnecting the first mentioned office with said tandem office, selective switches at said first office for extending connections over said trunks, a variably operable register and means for setting the same, means when said register is set in accordance with the designation of said first called office for controlling the selective switches to select a trunk to such office, a second variably operable register, means when the first register is set in accordance with the designation of the second called office to set said second register in accordance with such designation, means controlled by one of said registers for operating the selective switches to select a trunk to the tandem office, an indicating mechanism at the tandem office, an impulse device at said first mentioned office for transmitting impulses over the trunk to said tandem office, means dependent upon the setting of the other of said registers for controlling the transmission of said impulses, means responsive to such impulses for operating said indicating mechanism to indicate the designation of said second called office, and means for extending a connection from the tandem office to said second called office.

20. In a telephone system, an office, a first called office, a tandem office, a second called office, trunks interconnecting said first mentioned office with said first called office, trunks interconnecting the first mentioned office with said tandem office, selective switches at said first office for extending connections over said trunks, a variably operable register and means for setting the same, means when said register is set in accordance with the designation of the first called office for controlling the selective switches to select a trunk to such office, a second variably operable register, means when the first register is set in accordance with the designation

of the second called office to set said second register in accordance with such designation, means controlled by said second register for operating the selective switches to 5 select a trunk to the tandem office, an indicating device at the tandem office, means controlled over the trunk by the other of said registers for operating the indicating device to indicate the designation of said

second called office, means for operating said 10 indicating device to indicate the designation of the called line in said second called office, and means for extending a connection from the tandem office to said second called office.

In witness whereof, I hereunto subscribe 15 my name this 31st day of May A. D., 1921.

FRANKLIN A. STEARN.
